UNITED STATES PATENT OFFICE.

LOUIS F. DIETER, OF BUFFALO, NEW YORK.

METHOD OR PROCESS OF ROLLING OR FORMING CAR-WHEELS OR OTHER CIRCULAR BODIES.

1,243,051.

Specification of Letters Patent. Patented Oct. 16, 1917.

Original application filed June 15, 1911, Serial No. 633,343. Divided and this application filed October 10, 1916. Serial No. 124,921.

To all whom it may concern:

Be it known that I, LOUIS F. DIETER, a citizen of the United States, residing at Buffalo, in the county of Erie and State of New York, have invented novel and useful methods or Processes of Rolling or Forming Car-Wheels or other Circular Bodies, of which the following is a specification, accompanied by eleven sheets of drawings.

10 The features of my invention claimed herein are part of the invention of my original application filed June 15, 1911, Serial No. 633,343, which original application, in accordance with the requirement of the Patent Office, has been divided. The present application is a division from the said original application, and, for carrying out my invention, I prefer to use an apparatus or mill, such for instance, as shown and described in my said original application and, the parts of such an apparatus or mill shown in the accompanying drawings are illustrative of parts of my said original application.

15 The subject matter of the present invention is also described in my allowed application for patent filed June 15, 1911, Serial No. 633,343, allowed January 23, 1917, of which this application is a division, and in my co-pending application for patent filed January 10, 1917, Serial No. 141,558; and it is also described or partly described in and certain features of the invention not herein claimed are claimed in the following co-pending applications filed by me, viz: Application for patent filed November 20, 1916, Serial No. 132,372, and application for patent filed November 22, 1916, Serial No. 132,815.

20 My invention relates to the manufacture of completely rolled car wheels, disk-wheels or other circular objects from properly heated ingots, blooms, blanks or other work-pieces.

25 The primary object of my invention is to provide for the manufacture of car wheels and the like in an economical, commercial, expeditious and efficacious manner, whereby the whole car wheel may be completely rolled and dished or not dished from a properly heated ingot, bloom, blank or other work-piece, including the forming, at the opposite sides of the work-piece, of a rudimentary bore, or a part thereof, in a simple and

thoroughly practicable manner with the 55 same heat and before the finished rolled dished or undished wheel, as the case may be, is removed from the apparatus or mill, while at the same time securing a uniform and maximum density and homogeneity in 60 the metal therein which contributes materially to the strength and durability thereof; for instance, the metal, when being rolled from the blank or other work-piece into a car wheel or other circular object according to my invention, is, especially in the tread and flange or rim portion, not expanded radially, thereby producing incipient cracks in the tread and flange portions or in the peripheral face of the rim, but is 65 truly rolled and increases in density with increased working, thus giving to the metal both its due maximum strength and maximum resistance to wear. In other words, this invention of rolling produces the same 70 effect in the metal of the rim portion as if the web portion of the wheel were not in existence and the rim portion rolled its total width on its inner peripheral surface or surfaces, as is done on its outer peripheral surface consisting of the tread and flange. 75

A further object of my invention is to provide method by which a properly heated ingot, bloom, blank or other work-piece may be centered or pierced or penetrated and 80 centered, or both centered and pierced or penetrated at one or both sides and also supported, and therefrom, with the same heat and in the same apparatus or mill, a car wheel or other circular article may be completely rolled or formed, and by which method the time required in so producing car wheels or other circular articles is much 85 lessened and the cost of making such wheels or other articles is enormously reduced. 90

Another object of my invention is to provide a continually and automatically acting clamping process or method to prevent the work-piece from becoming loose between its supporting means; that is to say, for instance, the metal in a properly heated work-piece is very soft in comparison with the metal in its normal or cold condition and therefore has not the required resistance, which is absolutely necessary for firmly supporting the work-piece, and on which account the work-piece will become loose between or on its supporting means during the 95 100 105

operating process against the work-piece if the work-piece would be centrally supported or held by means of screws or similar mechanism. To avoid this, I put the work-piece automatically into a continually clamped condition between its supporting means, by applying pressure acting continually and automatically against the opposite ends of the hub or against the opposite sides of the center portion of the work-piece and thereby, the work-piece or wheel at its hub or center portion, while supported by the piercers or centers, is also automatically put into clamped condition, which prevents said hub or center portion from becoming loose on its supporting means and from being forced out of its true axial or central and desired lateral positions with respect to the rim portion of the work-piece or wheel during the rolling or operating processes &c., and said constant clamping force or constant clamping pressure automatically and continually remains during said operating processes, and for moving the work-piece or its hub or center portion axially in either direction while the same is so supported and so firmly clamped, all as hereinafter fully described.

Another object of my invention is to provide, in an apparatus or mill for rolling car wheels or other circular bodies, novel method for centering or piercing and centering, or penetrating and centering a heated work-piece at one or both sides thereof to the desired depth or depths, of regulating the depth of the piercing or penetrating action, and rotatably supporting the heated work-piece so that the latter may be rolled or operated on, all its surfaces, or may be rolled or operated on, as and where desired, for rolling or forming a lateral extension or hub portion onto a properly heated work-piece while centering and piercing or penetrating the same or for rolling or forming said lateral extension or hub portion either before or after the work-piece has been centered and pierced or penetrated.

Another object of my invention is the provision therein of novel method for completely centering and piercing or penetrating and supporting properly heated ingots, blooms, blanks or other work-pieces and rolling and dishing the work-piece to desired form while so supported; for rolling, forming or shaping a hub portion on a work-piece whereby the hub is formed smooth on all its surfaces to its desired form or shape without leaving a raised portion or fin which would have to be removed afterward by turning or other costly means; for rolling or forming the inner peripheral face or faces of the marginal or rim portion of a work-piece or wheel sufficiently inclined outwardly toward the outer peripheral face of the work-piece or wheel so that the rolling produces the same effect or

approximately the same effect as the mean of the rim portion as if the web portion of the wheel were not in existence and the rim portion rolled its total width on its inner peripheral surface or surfaces as is done on its outer peripheral surface consisting of the tread and flange, and then rolling the same to desired finished form or shape; for rolling of the total peripheral face of the work-piece or wheel first to beaked form, as and for the purpose hereinafter described, and then rolling the so beaked peripheral face to desired finished form without leaving a raised portion or fin which would have to be removed afterward by turning or other costly means.

Another object of my invention is to provide novel method for dishing, undishing or redishing car wheels or other circular objects while rotating; for rolling metal from the rim portion onto the web portion during the rolling and dishing process; for rolling and dishing car wheels or other circular objects, or for rolling undished or dished car wheels or other circular undished or dished objects; for centering a work-piece and sizing and compressing the hub portion thereof while in heated condition; and for decreasing the diameter of the bore in a car wheel or other circular work-piece by diametrically compressing the metal of the hub portion of the work-piece.

Further objects of my invention are to provide novel method for rolling a car wheel or other circular, or approximately circular, work-piece so as to cause the metal in the same to flow in radial lines, or substantially so, for the purpose of forming successively or alternately the web, the hub and the rim of said car wheel or other work-piece; for limiting the lateral flow of metal at the hub portion or at the marginal or rim portion, or at both said hub and rim portions; for rolling the peripheral face or flanged tread of the rim portion of said car wheel or other work-piece to true circular form and thereby also uniformly condensing the metal in said rim portion to the maximum; for rerolling, reforming or reworking a car wheel or other similar object; and, for utilizing car wheels or reworking the same to form other circular objects therefrom.

Further objects of my invention are to provide novel method for indicating the progressing or diminishing diameters of the work-piece, wheel or other article during the rolling process and also indicating when the wheel or other article is rolled to its finished diameter and for rolling the peripheral face of the work-piece or wheel to a predetermined diameter indicated by said indicator; for indicating the radial position of the herein named edging and web rolling rolls from the center of the work-piece, and for setting

or positioning such rolls to any desired radial position from the center of the work-piece, all while in operation; for rolling or forming a heated circular, or approximately 5 circular, work-piece into a car wheel or other circular body by first rolling or forming the hub and adjacent web portion and then rolling and forming the marginal or rim and the web portions to desired form, 10 by which rolling process or steps, in whole or part, any surplus of metal in a heated work-piece may be forced either to flow into the inner peripheral portion of the rim or into the web portion adjacent the rim portion, or into both, or forced to flow into any 15 other portion or portions of the wheel or other object which is to be formed from said work-piece, without leaving a raised circular portion or fin anywhere on the so finished 20 rolled wheel or other finished object, and whereby the metal is forced to flow either toward the center or hub portion or toward the peripheral or rim portion thereof, within the latter and peripheral thereto; and in 25 which invention the work-supporting means are entirely removed from the finished wheel or other finished article before the same is removed from the apparatus or mill; and, whereby during the rolling process the diameter 30 of the ingot, bloom, blank or other work-piece may either be increased, decreased, or retained about the same, and, whereby may be formed the hub portion, the web portion, the rim portion, and the 35 flange and tread of a car wheel or similar article by rolling and, during rolling also be formed into either dished or undished form, and whereby car wheels or other similar objects may be rolled to a true circular form 40 of desired diameter and width and, whereby the finished car wheel or other finished object after being bored coaxial with the axis of its peripheral face and fitted or forced onto its axle or shaft, may be practically 45 balanced.

The above-mentioned objects of my invention and others which will hereinafter appear, reduce the cost of operation in the manufacture of car wheels or other circular 50 objects. The production of car wheels and the like is thereby greatly cheapened, the output increased and the metal, for instance, in the tread and flange of the peripheral face and the whole rim portion of 55 car wheels uniformly condensed to its maximum, thereby giving the metal in said peripheral face and rim portion its due maximum and uniform strength and its due maximum and uniform resistance to wear and thereby 60 the said peripheral face and rim portion of the car wheel is also rolled smooth on all its surfaces to the desired form or shape without leaving a raised circular portion or fin which would have to be removed afterward 65 by turning or other costly means.

It is, of course, understood that the various steps in the method herein described for centering or piercing and centering or penetrating and centering and, rolling or forming either dished or undished car wheels or 70 other circular bodies may all be performed, in accordance with my invention, in the same apparatus or mill with one heat, or each of said steps may be effected with a separate heat treatment of the work-piece 75 and separate operation. For instance:— The ingot, bloom, blank or other work-piece may be centered or pierced and centered, or penetrated and centered, and then removed from the apparatus or mill employed for carrying out my invention. After this operation the work-piece may be removed to be rolled at some future time; or, if desired, the ingot, bloom, blank or other work-piece may be rolled to a preliminary form or shape and 80 then removed from the apparatus or mill by means of which my method is carried out and be stocked or stored for future operation or completion so that it may be later rolled, or rolled and dished to desired finished form or shape. As a further example; car wheels, disk-wheels or similar articles may be rolled to their proper form or shape and removed from the apparatus or mill and at some future time the article thus rolled 85 may be subjected to treatment according to my methods for dishing the same, and if required they may also be rolled to true form after the dishing operation. These, however, are merely descriptive of certain steps 90 in my method and it will be apparent that any step or operation may be completed to partly roll or form the work-piece and later be operated upon in the performance of any other step or steps, as may be required, but 95 it is to be understood that all the steps of my method herein described are necessary in the manufacture of a complete car wheel 100 or similar article.

Further objects of the invention will hereinafter appear. 110

My invention consists in the novel method or steps, for centering or piercing or penetrating and centering properly heated blanks or work-pieces and completely rolling 115 therefrom with one heat, either dished or undished car wheels or other circular bodies before the same are removed from the apparatus or mill, as hereinafter described and claimed. 120

My invention further consists in the method or steps hereinafter described, by which the wheel or other circular body can be produced with little or no scrap. 125

In the accompanying drawings, in which I illustrate devices or means I prefer to employ in carrying out or practising my invention:

Figures 1, 2, and 3, illustrate parts of one form of a novel apparatus or mill, here- 130

in after described and also fully described in my aforesaid original application and, which I prefer to employ in carrying out the steps in my method herein described, for centering or for piercing or penetrating and centering ingots, blooms, blanks or other work-pieces and rolling or forming therefrom either dished or undished car wheels, or other circular bodies; for rolling, rerolling, reforming or reworking car wheels or other circular bodies; and for utilizing car wheels or other circular objects or reworking the same to form other circular objects therefrom. In these figures is shown, for instance, a flanged and dished car wheel finished in said apparatus or mill according to my method. These figures show respectively different positions of the several parts in said apparatus or mill to the end that my method may be more fully understood; but my invention may be carried out by various forms of apparatus or mill.

Figs. 4 to 15 inclusive, for instance, illustrate somewhat modified forms of the apparatus or mill illustrated in Figs. 1, 2 and 3, hereinafter described and also fully described in my said original application, and which may be employed in carrying out my invention.

Fig. 16 shows one of the oscillating supporting frames for the shaft of one of the web finishing rolls, hereinafter described and also fully described in my aforesaid original application. In this figure is also indicated by the dotted lines, the longitudinal and lateral movements of said web finishing roll.

Figs. 17 to 20 inclusive, show one of the oscillating frames, the manner of supporting, guiding, positioning and shifting or longitudinally moving one of the shafts having an edging and web rolling roll, the gage or indicator for the roll and the driving mechanism for said shaft; in Fig. 17 is also indicated by dotted lines the longitudinal movement of said edging and web rolling roll; in Fig. 18 is also indicated by dotted lines the lateral movement of said edging and web rolling roll; and Figs. 19 and 20 showing three gage rods for each of said edging and web rolling rolls, hereinafter described and also fully described in my aforesaid original application.

Fig. 21 shows a blank or work-piece which, according to certain steps in my method, is shown pierced and centered in the apparatus or mill with piercers or work-supporting centers having for instance the form as shown, and therewith said blank or work-piece being held rotatably in position ready to be rolled. In this figure the hub portion is shown in dotted lines rolled onto the work-piece by the rolls, also shown in dotted lines, which also illustrate my method for forming lateral extensions or hub por-

tion onto a work-piece and for confining the lateral and radial flow of metal in the hub portion during the process of rolling or forming said lateral extensions or hub portion. In this figure are also shown the rolls in the positions they will occupy, either during the time the ingot, bloom, blank or other work-piece is put into the apparatus or mill, or when the work-piece or the finished wheel or other finished article is removed from the apparatus or mill, hereinafter described and also fully described in my aforesaid original application.

Figs. 22, 23 and 24, illustrate certain steps in my novel method for centering or for 80 piercing or penetrating and centering ingots, blooms, blanks or other work-pieces to equal or different depths, hereinafter described and also fully described in my aforesaid original application.

Fig. 25 shows for instance, the flange and tread portion of a car wheel after being rolled, according to my method, with the tread or face rolling roll provided with the rolling surface, as shown and, with the 90 tread or face finishing roll provided with the rolling surface as shown, hereinafter described and also fully described in my aforesaid original application.

Fig. 26 shows for instance, a finished 95 dished disk-wheel or a dished center such as used for tired car wheels, rolled and dished according to my method. In this figure, the rolls and piercers or work-supporting centers are in the positions they occupy at the 100 end of the rolling and dishing process, hereinafter described and also fully described in my aforesaid original application.

Fig. 27 is another illustration of my 105 method for rolling, hereinafter described and also described in my said original application.

Fig. 28, shows for instance, a step in my method for centrally supporting an object or work-piece while the work-piece is rolled 110 or operated on and, which object should not have a large impression or hole; therefore, flat work-supporting centers provided with or without pins as shown are used. In this figure the center portion only of the work-piece is shown, as hereinafter described and 115 also as described in my said original application.

Fig. 29, shows for instance, the center portion only of a blank in position ready to 120 be pierced or centered according to my method, hereinafter described and also described in my said original application.

Fig. 30 shows, for instance, certain steps in my method for centrally supporting a 125 work-piece provided with a large central hole, as for instance shown. In this figure the center portion only of the work-piece is shown, as hereinafter described and also as described in my said original application. 130

Fig. 31 shows the center or hub portion only of the body of an ingot, bloom, or other work-piece having the form or shape for instance, as shown, and in position to be centered or pierced or penetrated and centered according to my invention, hereinafter described and also described in my said original application.

Fig. 32 shows the center or hub portion of a work-piece about to be centered or penetrated and centered, as hereinafter described and also as described in my said original application.

Fig. 33 shows, for instance, an ingot, bloom, car wheel blank, or other work-piece having the form or shape shown or having been rolled to the form or shape shown, and to be rolled according to my method, hereinafter described and also described in my original application.

Fig. 34 shows, for instance, the center portion of a blank or work-piece provided with a conical hole as shown, the blank or work-piece being in position ready to be centered or pierced or penetrated and centered, according to my method, hereinafter described and also described in my said original application.

Fig. 35 shows, for instance, the center portion of a blank or work-piece provided with a cylindrical hole, and in Fig. 36 is shown said blank or work-piece centered or pierced or penetrated and centered according to my method, hereinafter described and also described in my said original application.

In the Figs. 37 and 38 are shown, for instance, two more forms of work-supporting centers for use in carrying out my method, hereinafter described and also illustrated in my said original application.

Figs. 39 to 46 inclusive, illustrate, according to my invention the rolling of the circular forms or shapes for instance shown, from ingots, blooms, blanks or other work-pieces into car wheels or other circular bodies and, also illustrate, according to my invention, rerolled, reformed or reworked car wheels or other circular bodies and, also car wheels or other circular bodies rerolled or reformed to forms of other circular objects. In each of these figures, the sections shown are half or diametral sections; for instance, in Fig. 39 the ingot, car wheel blank or other work-piece is shown rolled to the undished form of the wheel with the inner circumferential faces of the rim portion rolled to rudimentary form and sufficiently inclined as and for the purpose hereinafter described with reference to the Figs. 49, 90 and 91 and, the peripheral face or tread and flange portion of the rim rolled to beaked or rudimentary form, according to my invention. In Fig. 40 said undished wheel is shown rolled and dished to finish according to my invention. These two fig-

ures, for instance, clearly illustrate my method of rolling the object, first into rudimentary undished form shown and then into finished dished form, all of which I prefer to do with one heat and in the same apparatus or mill, as hereinafter described and also as fully described in my said original application; in Fig. 41 is illustrated, for instance, certain steps in my method for reworking or rerolling a car wheel, including the reworking of its hub portion; and in this figure is also shown my method for reducing the diameter of the hub portion, as hereinafter described and also as described in my said original application; in Fig. 42 is shown, for instance, a finished undished car wheel rolled according to my method, hereinafter described and also described in my said original application; in Fig. 43, the ingot, bloom, blank or other work-piece is shown rolled to the undished form of a wheel having the web connecting its hub and rim portions formed at one side of the wheel with the inner circumferential face of the rim portion rolled to rudimentary form and sufficiently inclined as and for the purpose hereinafter described with reference to Figs. 50 and 90 and the peripheral or tread and flange portions of the rim rolled to beaked or rudimentary form, according to my method and, in Fig. 44 is shown the undished wheel illustrated in Fig. 43, rolled and dished to finish according to my invention, hereinafter described and also fully described in my said original application; in Fig. 45 is shown, for instance, certain steps of my invention for rolling disk-wheels, pipe flanges or similar articles from ingots, blooms, blanks or other work-pieces, or for reworking car wheels or other circular objects into disk-wheels, pipe flanges or similar articles, as hereinafter described and also as described in my original application; and in Fig. 46 is shown, for instance, certain steps in my method for forming lateral extensions or hub portion onto a work-piece and for confining or limiting the lateral and radial flow of metal at the central or hub portion during the process of forming said lateral extensions or hub portion, as hereinafter described and also as described in my said original application.

Figs. 47 and 48 illustrate more fully the steps in my invention for rolling or forming the central or hub portion of a car wheel or other circular body, smooth on all its surfaces, to the desired form or shape without leaving a raised circular portion or fin which would have to be removed afterward by turning or other costly means, as herein-after described and also as described in my said original application.

Figs. 49 and 50, illustrate the flow of metal, for instance, in the outer or rim portion of a work-piece during my rolling proc-

ess in accordance with my invention, as hereinafter described and also as described in my said original application. (See also Figs. 90 and 91).

5 Figs. 51, 52 and 53 show the flange and tread portions of car wheels and are diagrammatic views illustrating for instance a few shapes or ways of "beaking," as herein-after described and also as described in my 10 said original application.

Figs. 54 to 61 inclusive, illustrate, according to my invention, certain rolling or forming steps in rolling the finished undished car wheel, for instance shown in the Fig. 42.

15 In said Figs. 54 to 61 are illustrated certain steps for piercing and rolling a heated car wheel blank or work-piece such as shown for instance in the Fig. 54 or 55, into the form of the finished undished car wheel 20 shown in Figs. 60 and 61, all as herein-after described and also as described in my said original application.

Figs. 62 to 68 inclusive, illustrate, according to my invention, certain rolling or forming steps in rolling or forming the finished dished car wheel, for instance, shown in Fig. 40. In said Figs. 62 to 68 are illustrated certain steps for piercing and rolling or forming a heated car wheel blank or work-piece, such as shown for instance in the Fig. 62 or Fig. 63, into the form of the finished dished car wheel shown in the Figs. 67 and 30 68, all as herein-after described and also as described in my said original application.

35 Figs. 69 and 70 illustrate a raising, lowering and retaining device, such as I prefer to employ in carrying out my invention herein-after sufficiently described and also fully described in my said original application.

40 Figs. 71 to 76 inclusive, illustrate more fully the centering or piercing or penetrating and centering, according to my invention, of an ingot, bloom, blank or other work-piece, and the use therein of such raising, lowering and retaining device as I prefer to employ in carrying out my invention, herein-after sufficiently described and also fully described in my said original application.

Figs. 77, 78, 79, 80, 81 and 82, illustrate, 50 for instance, some of the forms of the piercers or work-supporting centers which I prefer to employ in carrying out my invention as herein-after described and also described in said original application.

55 Figs. 83 to 86 inclusive show details and arrangement of the pressure, moving and equalizing devices for the tread or face rolls and, also show details and arrangements of the indicating devices for said rolls for indicating the diameter of the work-piece or wheel during the rolling process and, also illustrate in sectional plan view, portion of said apparatus or mill showing the arrangement of the rolls which I prefer to use in 60 carrying out my invention.

Figs. 87 and 88 illustrate diagrammatically improper flow of metal resulting from improper working of the metal in the rim portion of a car wheel or other object having a web, during the forming of said rim portion, all of which is avoided by my invention, as herein-after described and also described in my said original application. Fig. 89 illustrates, for instance, the proper flow of metal during the forming of a tire 75 having no web, such as used for some tired car wheels, as herein-after described and as referred to in my said original application. Figs. 90 and 91 are diagrammatical illustrations showing more fully the result of the 80 rolling or forming of the rim of a car wheel in accordance with my invention as illustrated in a small scale in the Figs. 39 to 42 and Fig. 49; as herein-after described; and also as fully described in my aforesaid original application.

This invention, as hereinbefore said, is, in accordance with requirements of the Patent Office, a division of my aforesaid original application and, the parts of an apparatus or mill shown in the accompanying drawings are illustrative of parts of my said original application. It is, of course, understood that I do not intend to limit myself to the use of the particular parts shown, as other means may hereafter be devised for carrying out my invention or method in a practicable manner.

Similar characters of reference indicate corresponding parts throughout the several views, and also indicate the same corresponding parts in my said original application.

A⁵ is the foundation box supporting the herein named raising, lowering and retaining device. E, E are the herein named work-supporting axles which are oppositely-arranged in alignment and spaced apart. These axles also serve other purposes, as herein-after fully described; and E¹, E², E³, E⁴, E⁵ and E⁶ show, for instance, different 105 shapes of the herein named piercers or work-supporting centers which are interchangeably or removably secured or attached to the adjacent ends of said work-supporting axles, and as the power or pressure mechanisms operatively connected with said axles are preferably independently movable, said axles are also independently movable and the extent of movement of each controlled separately. There is practically no limit to 110 the shape that said piercers or work-supporting centers may have, and, the work-piece is to be positioned in a plane between said work-supporting centers or between 115 said axles, as and in a manner herein-after described.

F, F¹ and F² represent the work-piece from some of the many various forms or shapes it may have when put into the apparatus or mill to some of the many various 120

forms or shapes which the finished article or product may have. For instance, F represents the ingot, bloom, blank or other work-piece in a few of the many various forms or shapes it may have when put into said apparatus or mill, either solid, as for instance F in Figs. 28, 29, 47, 54, 55, 62, 63 and 74; or previously formed or provided with a hole, as for instance F in Figs. 34, 35 and 71; or having a central hole, as for instance F in Figs. 30, 32, 34, 35 or 71; or as F² in the Figs. 41 or 45; or previously formed into form or shape, as for instance F in Figs. 10, 13, 31, 32 or 33; or previously cast into any suitable form or shape, as for instance F in the Figs. 10, 13, 31, 32 or 33; or it may be a previously formed or rolled car wheel or other previously formed body, to be rerolled or reworked, as for instance the work-piece shown in dotted lines in the Fig. 41, which has been rerolled or reworked to the form or shape F² from the size therein indicated by said dotted lines. Such previously rolled or otherwise formed car wheel or other article to be rerolled, reformed or reworked according to my invention may also have any of the forms or shapes shown, for instance, at F² in the Figs. 26, 40, 41, 42, 44 or 45, or, as at F¹ in the Figs. 39 or 43.

There are many other forms or shapes that the ingot, bloom, blank or other work-piece or previously finished article may have when put into the said apparatus or mill to be operated on according to my invention, as will appear from the matter hereinafter more fully described; as for instance F² which represents the finished article or finished product produced by my invention, either dished or not dished.

G, G¹ are the shafts which have at their one end the herein named web finishing rolls, as shown, for instance, in the Figs. 1, 2 and 3, 10 to 15, 16, 39 to 45 &c., and as will hereinafter be more fully described.

G⁰, G⁰ and G¹, G² and G³, G⁴ and G⁵, G⁶ for instance, are sets of different shapes of the said herein named web finishing rolls. These rolls are interchangeable as described in my said original application. There is practically no limit to the shapes that these rolls may have, as will appear from the matter hereinafter fully described.

H is the herein named tread or face finishing roll which acts against the peripheral face of the work-piece and which, during the rolling process, is moved toward, against or away from the peripheral face of the work-piece and said movements are limited or controlled by adjustable stops provided in the mechanism of said movements, as hereinafter described, whereby the radial distance of said roll from the axis of the supported work-piece is adjusted so as to suit the exact diameter of the wheel when finished. When the wheel has been rolled

to its finished diameter, then said roll acts as a rolling stop against the peripheral face of the work-piece or wheel and maintains said finished diameter of the wheel during any further operation against the wheel.

The peripheral or rolling face of this roll may have many different shapes, as for instance H¹ in the Figs. 1, 7, 10, 13, 21, 25, 27 and 39 to 44; or as H² in the Fig. 26; or as H³ in the Fig. 45; or for instance, as described more fully in my said original application. There is practically no limit to the shapes the peripheral or rolling face of these tread or face finishing rolls may have, as will appear from the matter hereinafter fully described.

J, J¹ are the roll shafts, each of which has at one of its ends one of the herein named edging and web rolling rolls. These rolls are either removably attached to said shafts in such a way that the whole roll may be driven by the shaft, or only part of the roll may be driven by the shaft and the other part be permitted to turn loose; or the whole roll may be permitted to turn loose on a journal removably fastened to said shaft, all as fully described in my said original application.

J⁰, J⁰ and J¹, J² and J³, J⁴ and J⁵, J⁶ and J⁷, J⁸ are, for instance, sets of the herein named edging and web rolling rolls, shown in different shapes. These rolls are also interchangeable as above described and also as fully described in my said original application. There is practically no limit to the shape these rolls may have, as will appear from the matter hereinafter more fully described.

K is the herein named tread or face rolling roll which acts against the peripheral face of the work-piece to roll said face to a beaked or rudimentary form or to partly finished form and which, during the rolling process, is moved toward, against or away from the peripheral face of the work-piece: said movements being limited or controlled by adjustable stops provided in the mechanism for causing said movements, as hereinafter described, whereby the radial distance or distances of said roll from the axis of the supported work-piece may be adjusted so as to suit any requirement and whereby said roll may be stopped and retained at any desired radial distance from the axis of the supported work-piece. Said roll is also supported so as to permit lateral movement of the same. The peripheral or rolling face of this roll may also have various different shapes, as for instance, K¹ in Figs. 1, 4, 7 and 25; or, as for instance K² in Figs. 21, 39, 40, 41, 42 and 46; or, as for instance K³ in Figs. 26 and 45; or, as for instance, a roll having its rolling face to suit the beaked form K⁰ of the peripheral face of a rim portion shown in Fig. 52; or,

as for instance K⁷ in Figs. 43, 44, 54, 56 to 59, 62 and 64 to 66, which is also the proper shape for rolling the peripheral face of a rim portion to the beaked or rudimentary form shown in K⁷ in Fig. 53; or for instance, as described in my said original application. There is practically no limit to the shapes the peripheral or rolling face this tread or face rolling roll may have, as will appear from the matter hereinafter fully described.

Said face rolls H and K may also be moved toward, against or away from the peripheral face of the supported work-piece either together or independently of each other, as and in the manner hereinafter described and also described in my said original application.

20 *Raising, lowering and retaining device.*

Figs. 69 and 70 show, for instance, the herein named raising, lowering and retaining device, such as I prefer to employ in my process for taking the finished article or product out of the apparatus or mill and for putting the properly heated ingot, bloom, blank or other work-piece into the apparatus or mill and retaining the same in such position wherein its outer portion or periphery is central or coaxial, or approximately so, with the piercers or work-supporting centers to permit of its being centered or pierced or penetrated and centered in the center, or approximately in the center, of its outer portion or periphery with said piercers or work-supporting centers; and for lowering the supporting member of said device away from said work-piece, either after said work-piece is so centered or pierced or penetrated and centered or during said centering or piercing process, and for retaining the supporting member of said device in said lowered position away from said work-piece until said work-piece or said finished article or product is to be taken out of the apparatus or mill, as will hereinafter be more fully described. With reference to Figs. 69, 70, 72 and 75, the said device consists mainly of a vertically disposed outer cylinder L¹⁵ supported by said foundation box A⁵ and having a piston on which is the piston-rod L⁸, which piston and piston-rod form a smaller cylinder, itself fitted with a piston having piston-rod L², which is provided at its upper end with the head-piece or supporting member L. Fig. 69 shows the device in its upper position and carrying, for instance, a finished car wheel F² shown in dotted lines to a height above the apparatus or mill, when it is taken away by any suitable means, and another properly heated ingot, bloom, blank or other work-piece F put in its place. The said head-piece or support-

ing member L of said device with the newly placed ingot, bloom, blank or other work-piece F resting thereon is then lowered by means of the said inner piston until it comes against an adjustable stop formed by nut L⁴ and stuffing box extension L⁷ whereby the center line or axis of said work-piece F shown in Fig. 69 in dotted lines and in Fig. 70 in solid lines, will be brought in line, or approximately in line, with the center line or axes of the piercers or work-supporting centers, which centers will then center or pierce or penetrate and center said work-piece and also support the same, then, either after said work-piece is so centered or pierced or penetrated and centered, or during said piercing or penetrating or centering process, said outer piston with its piston-rod L⁸ is then lowered to the position shown in Fig. 70 whereby said head piece or supporting member L is lowered away from said supported work-piece F, the distance for instance indicated by the dotted line y⁴—y⁴ in said Fig. 70 and is retained in said lowered position away from the work-piece until said work-piece or said finished article or product is to be taken out of the apparatus or mill. When said work-piece is so centered or pierced &c., said piercers or work-supporting centers will then remain in said work-piece and will support the same and revolve therewith until the work-piece is rolled to the form or shape of the car wheel or other circular article, either in dished or undished form, as desired, and ready to be removed from the apparatus or mill, then with the inner piston and its piston-rod L² kept at its adjusted lower position, the said outer piston with its piston-rod L⁸ is again raised until it comes to the adjustable stop formed by L¹⁷, L¹⁷ and L¹⁸, L¹⁸, when it is again in the middle position shown by dotted lines in Fig. 69; but this time, instead of said work-piece F, it will receive the finished wheel shown by dotted lines at F² or other article and with it will again be raised to the upper position shown in Fig. 69 when said wheel F² or other article is taken away and another properly heated ingot, bloom, blank or other work-piece put in place of it, and so on; all of which is more fully described in my said original application.

The piercers or work-supporting centers of the preferred apparatus or mill herein shown, are located one at each side of the blank or work-piece, and preferably revolve with the work-piece, and during the piercing or penetrating or centering process are moved longitudinally toward or away from each other or are moved as may be desired; and during the dishing process they are also moved longitudinally with the center or hub portion of the work-piece, wheel or other article, as the case may be.

Piercers or work-supporting centers and work-supporting heads.

With reference, for instance, to Figs. 1 to 5 15, 22, 23 and 24, illustrating the device I prefer for centering or for piercing or penetrating and centering ingots, blooms, blanks or other work-pieces, for supporting the same, and for putting the work-pieces at 10 their hub or center portion while so supported by said work-supporting centers also into clamped condition laterally or axially between said piercers or work-supporting centers and automatically keeping said hub 15 or center portion in said clamped condition by constant pressure during the rolling and dishing or undishing processes, &c., as hereinafter described.

In said figures, M, M are the herein named 20 work-supporting heads; although so named they also serve other purposes, as will be observed from the following:

The axles E, E are carried and rotatably supported by said supporting heads M, M. 25 Each of these axles E, E has one of said piercers or work-supporting centers at one of its ends, as for instance E¹ or E² or E³ or E⁴ or E⁵ or E⁶, &c. These piercers or work-supporting centers are interchangeable. 30 Said heads M, M are moved, with their axles E, E and piercers or work-supporting centers E¹, &c., in line with the axis of the work-piece by means of the pressure cylinders O and N or by any other 35 equivalent means, toward or away from each other, or they may be moved together in either direction, or one of them may be retained in any position while the other is moved toward or away from the one so retained, or are moved as the case may require, and as and in the manner hereinafter 40 fully described. One of said heads M, M is operatively connected with the piston-rod O³ of the piston in cylinder O and is moved 45 by the pressure in said cylinder O, and, the other of said heads M, M, is operatively connected with the piston-rod N³ of the piston in cylinder N and is moved by the pressure in said cylinder N. The ends M⁴⁵, M⁴⁶ 50 of said heads M, M around said axles E, E are formed at an incline with the side of the work-piece, as shown in Figs. 22 and 23, for the purpose hereinafter described.

With reference to Figs. 1, 2 and 3, O is 55 the pressure cylinder for the work-supporting head M located at one side of the work-piece; and, N is the pressure cylinder for the work-supporting head M located at the other side of the work-piece. Cylinder O 60 has a piston with a piston-rod O² and a piston-rod O² passing through the cylinder heads O¹⁵ and O¹⁶ (see Fig. 1) at both ends of cylinder O. The piston-rod O² at its outer end is provided with a long thread O¹¹ 65 over which is fitted a threaded and adjust-

able nut O¹², as shown. This nut O¹² can be adjusted from one end to the other end of said thread O¹¹. At the outer end of said thread is provided a safety stop collar O¹⁴ which indicates the limit of adjustment of 70 said nut O¹² toward the end of the piston-rod and thereby prevents the piston from coming against the cylinder head O¹⁶. The piston-rod O³ is firmly connected at its outer end with said work-supporting head 75 M. From the outer end M²² of said head M the piston-rod O³ is provided with a thread over which is fitted a threaded adjustable nut O⁷ as shown. This nut O⁷ can be adjusted from one end to the other end of said 80 thread, as may be required in adjusting the pull-back stroke of the piston with its rods O², O³; next to said nut O⁷ the piston-rod O³ is also provided with a sleeve or distance piece O⁹ as shown (the purpose of this 85 piece O⁹ being described in my said original application). The details and description of the cylinder N and its connecting parts for the head M at the other side of the work-piece, are similar to those described above, 90 and the characters of reference N to N¹⁸ inclusive indicate the corresponding parts for O to O¹⁸ inclusive. The piercers or work-supporting centers, with their work-supporting heads M, M are operated by the 95 pressures in said cylinders O and N acting against the pistons of said piston-rods N², N³ and O², O³ in the manner hereinafter described.

Centering or piercing or penetrating and centering.

By the words "centering, or piercing or penetrating and centering" used herein, I 105 mean that, the ingot, bloom, blank or other work-piece is centered, or pierced or penetrated and centered by the apparatus or mill, by forcing either one or both said piercers or work-supporting centers against 110 or into said work-piece by their pressure means, when the outer portion or periphery of said work-piece is brought coaxial, or approximately coaxial, with the piercers or work-supporting centers by means of said 115 raising, lowering and retaining device, and this herein means said work-piece is centered, or pierced or penetrated and centered, because said piercing or penetrating at the same time also centers said work-piece, because, at the beginning of said centering or 120 piercing or penetrating and centering process, the outer portion or periphery of said work-piece is then coaxial, or approximately so, with said piercers or work-supporting 125 centers; that is, said piercers or work-supporting centers are then in the center, or approximately in the center of the outer portion or periphery of said work-piece. It is, of course, understood that when a 130

- work-piece has previously been provided with an opening which is somewhat off center, the work-piece is positioned by said raising, lowering and retaining device to bring the peripheral face of said work-piece coaxial, or approximately coaxial, with the piercers or work-supporting centers, regardless of the axis of said opening, and as an illustration of this, reference is had to Figs. 34, 71, 72 and 73, in each of which the hole in the work-piece is made smaller than the piercers or work-supporting centers and has its axis out of line with the axis of said piercers or work-supporting centers. In said figures, and in Figs. 31, 35 and 36, the hub or center portion of the work-piece has been provided with a hole, which in actual practice is purposely smaller, for instance as shown, so that the work-piece can be positioned between said piercers or centers with its outer portion or peripheral face coaxial, or approximately coaxial, with said piercers or centers and in this position said work-piece is centered, or pierced or penetrated and centered, with said piercers or work-supporting centers, regardless of the axis of said hole. In Figs. 71, 72 and 73, which illustrates in a diagrammatical or explanatory manner the operation of centering, or penetrating and centering a work-piece, such for instance as shown in Figs. 34 and 36, and also the use, in said operation, of said raising, lowering and retaining device, I have shown a work-piece having for instance the form as shown and being previously provided with a hole as shown in Fig. 71 and which being then centered or penetrated and centered in the center, or approximately in the center, of its outer portion or periphery with the piercers or work-supporting centers E¹, E¹ having for instance the form as shown; in said figures the axis of the work-piece F, that is, the center line or axis of the outer portion or periphery of the said work-piece F, is represented by the dotted line y¹—y¹ and when the outer portion or periphery of said work-piece is brought coaxial, or approximately coaxial, with said piercers or work-supporting centers by means of said raising, lowering and retaining device, then said center line or axis y¹—y¹ is in line, or approximately in line, with the centers or axes of said piercers or work-supporting centers; Fig. 74, shows a work-piece F having for instance the form as shown; Fig. 75, shows said work-piece F supported and held by the head piece or supporting member L of said raising, lowering and retaining device, and with said device said work-piece F being brought and retained in the position shown, and in which position the outer portion or periphery of said work-piece is coaxial, or approximately coaxial, with said piercers or work-supporting centers E¹, E³ having for instance the form as shown, then said piercers or work-supporting centers are moved toward and against said work-piece F, as shown, by the pressure means operatively connected therewith, then the one work-supporting center E³ having a large supporting member L of said raising, low-

surface at its end as shown, is retained in said position and the said other piercer or work-supporting center E¹ is then forced into the one side of the work-piece F by the 5 pressure means operatively connected therewith; Fig. 76, shows said work-piece F so centered or pierced and centered in the center, or approximately in the center, of its outer portion or periphery at one of its sides 10 only, with one of said piercers or work-supporting centers, as E¹, having for instance the form as shown and its other side supported laterally by the other work-supporting center E² having for instance the form 15 as shown, said work-piece is thus also supported by said piercers or work-supporting centers E¹, E² as shown, and, by said pressure means operatively connected with said piercers or work-supporting centers, the hub 20 or center portion of said work-piece F, if so desired, is also automatically and firmly clamped laterally between said piercers or work-supporting centers E¹, E² for the purpose hereinafter set forth, said head piece 25 or supporting member L of said raising, lowering and retaining device, now being lowered by said device away from the work-piece.

For piercing and centering, for instance, 30 a properly heated blank or work-piece F, having the form shown in Figs. 21, 55 or 63, the blank or work-piece F which, in these illustrations, has a thickness which is for instance the same or somewhat greater than the lateral thickness or width which the marginal or rim portion of the car wheel or other article is to have when finished, is placed on the hereinbefore described head piece or supporting member L of said raising, lowering and retaining device and lowered with said device to the position indicated by the dotted lines in Fig. 69, which brings the outer portion or periphery of said blank F central, or approximately so, 45 with the piercers or work-supporting centers, which will then be moved by the pressures in said cylinders N and O acting on the pistons of the piston-rods N³ and O³ which are operatively connected with said piercers or work-supporting centers, as shown for instance in Fig. 1, to the position shown for instance in either of the Figs. 29, 55 or 63, in which position the outer portion or periphery (not shown in Fig. 29) of the 55 blank or work-piece F is coaxial, or approximately so, with said piercers or work-supporting centers; the total pressure or force will then be delivered to the pistons of said piston-rods N³ and O³, thereby forcing or piercing or penetrating, for instance, the centers E⁶, E⁶ or any other suitably formed piercers or work-supporting centers, as for instance E¹, E¹, &c., into said work-piece F, to the depth or depths as is indicated, for instance by the dotted lines for said centers

E⁶, E⁶ in the Figs. 29, 55 or 63 and shown by solid lines, for instance, in Figs. 21, 22, 23, 36, 46, 77 or 80; or, in case that the blank or work-piece has a thickness which is the same or somewhat greater than the length 70 which the hub of the car wheel or other article is to have when finished, then in such case the shoulders or flanges e²⁰, e²⁰ which are formed with said piercers or work-supporting centers E⁶, E⁶ will come against the 75 sides of the blank or work-piece as for instance shown in the Figs. 1, 39, 40, 48, 50, 56, 64, 78, 79, 81 or 82. In the Fig. 28, is shown a blank or work-piece for an article which should not have a large hole or impression, 80 and therein the blank or work-piece F is held only by the flat ends of the work-supporting centers E³, E³ and their pins e, as shown, or said pins e may be used in one of these centers only or said pins e may be 85 omitted, which pins in this case are pierced or forced into the blank or work-piece, as shown. In case that the work-piece is to be pierced or penetrated or centered at one side only, then one of the centers may have a 90 form similar to E² with or without the pins e, as for instance in said Figs. 75 and 76 (hereinbefore described) and the other center doing the piercing or penetrating or centering may have any suitable form or shape 95 as for instance E¹, E², E¹ or E⁶, &c. In the Fig. 30, the blank or work-piece F has a large central hole and is supported by the centers E⁴, E⁴ as shown. In the Fig. 31, the ingot, bloom or other work-piece F, at its 100 center or hub portion has the form as shown, and when the outer portion or periphery (not shown in Fig. 31) of said work-piece F is brought and retained coaxial, or approximately so, with the piercers or work-supporting centers for instance E¹, E¹ by 105 means of said raising, lowering and retaining device, then said piercers or work-supporting centers are forced by said pressure means operatively connected therewith into 110 said center or hub portion as is indicated by dotted lines, and, in case that said piercers or work-supporting centers would have the form or shape as E⁶, E⁶, then said flanges or shoulders e²⁰, e²⁰ of said centers E⁶, E⁶ 115 would come against the ends e²⁰, e²⁰ of the hub portion of work-piece F, if the thickness between said ends e²⁰, e²⁰ is the same or is somewhat greater as is the length of the hub of the finished article. In each of the 120 Figs. 32 and 33, the hub or center portion of the ingot, bloom, or other work-piece F has for instance the form or shape as shown and the hole or impression shown in these figures may have any form or shape and, the 125 operating process is the same as before described. In Fig. 34, the blank or work-piece has previously been provided with a central conic hole, as shown, and is penetrated or centered by the piercers or supporting cen- 130

ters for instance E^1 , E^1 , as indicated by the dotted lines and, the operating process is the same as before described. In Fig. 36, the blank or work-piece F has previously been provided with a central cylindrical hole as shown in Fig. 35, and being penetrated or centered with the piercers or supporting centers for instance E^6 , E^6 as shown and, the operating process is the same as before described and, said flanges or shoulders e^{30} , e^{30} formed on said centers limit, in this operating process illustrated for instance by Fig. 21, the lateral flow of metal during the process of forming the hub. In the Fig. 41 is shown, for instance, a previously finished or worn car wheel rerolled to the size and form of F^2 , supported by the centers E^2 , E^2 , as shown; these centers, in such case, are forced or are put over the outer diameter of the hub as shown and thereby may also reduce or increase, if so desired, the bore of the wheel or other article, to either smaller or larger diameter. In Fig. 38, I have shown in enlarged section, one of said piercers or work-supporting centers E^2 , E^2 having for instance the form as shown, the center portion e^{38} either centrally enters the hole loosely or will be centrally forced into the hole or bore of the work-piece (as shown in Fig. 41), and the annular flange e^{35} which is separated from said center portion e^{38} by an intervening space, is centrally forced over or put over the outer peripheral part or diameter of the hub of the work-piece, by which process, the central hole or bore of, for instance, either previously formed or worn car wheels may either be reduced or made larger so that the same may be reborred to the diameter of its original bore or to a diameter larger.

I prefer to make the length of these piercers or work-supporting centers to suit the location of the web portion; that is, the metal between the ends of said work-supporting centers, if any, I prefer to be in a plane with that portion of the web which is adjacent the center or hub portion, as for instance shown in Figs. 39, 40, 42, 56, 59, 65 and 66.

In centering or in piercing and centering, for instance, a blank or work-piece F as in the Figs. 22, 23 and 24, it will be possible that one of said piercers or work-supporting centers, during the centering or piercing or penetrating and centering process, penetrates or is forced into the one side of the blank or work-piece F more than is the other forced into the other side of said blank or work-piece F, as is illustrated in the Fig. 22; therein are shown for instance said piercers or work-supporting centers E^6 , E^6 . To prevent such uneven penetration or piercing and to make the said piercers or work-supporting centers penetrate or pierce the blank or work-piece F to the same depth at both

sides, as shown for instance in Fig. 23, or to have purposely one of said piercers or work-supporting centers, for instance E^6 , E^6 , during the centering or piercing or penetrating and centering process, penetrate or pierce the blank or work-piece F more at one side than at the other, as for instance in said Fig. 22, I, as before said, prefer to incline the ends M^{45} , M^{45} of said work-supporting heads M, M around said axles E, E, that is, at an incline with the side of the work-piece, as shown, and provide wedge shaped collars M^{46} , M^{46} which are open at one side so they can be put over said piercers or work-supporting centers, for instance E^6 , E^6 , and with their one flat side fitting to the sides of the blank or work-piece F, and with their other or inclined sides fitting to the said inclined ends M^{45} , M^{45} of said work-supporting heads M, M as shown. The said wedge shaped collars M^{46} , M^{46} are each also provided with the stop pins M^{47} and M^{48} , and with a handle M^{49} as shown. In the operation for centering or for piercing or penetrating and centering, each of said collars M^{46} , M^{46} with its handle M^{49} in an inclined or any other convenient position, such, for instance, as indicated by the dotted lines in the Fig. 24, is put over said piercers or work-supporting centers as is indicated by the dotted lines of said parts M^{46} to M^{49} inclusive, then said collars are turned around said piercers or work-supporting centers until their said stop pins M^{47} and M^{48} come against the sides of said work-supporting heads M, M, then each of said collars M^{46} , M^{46} with its pins M^{47} and M^{48} and handle M^{49} will be held by said pins M^{47} and M^{48} in the position as shown by the solid lines in the said Figs. 23 and 24, and in this said position, the centering or the piercing or penetrating and centering process may be done, and in case that the collar M^{46} at one side of said blank or work-piece is forced by said blank or work-piece F against the said work-supporting head M before the same is done at the other side, then in such case, owing to the additional surface obtained by said collar M^{46} against said blank or work-piece F, the resistance for penetration or piercing on this side of the blank or work-piece may become several times the force required for penetrating or forcing said piercer or work-supporting center into the proper depth of the other side of said blank or work-piece, thereby said piercers or work-supporting centers may be forced to equal depths at both sides of said blank or work-piece F; then the said collars are again turned until their handles M^{49} , M^{49} are again in the position indicated by the dotted lines for said handles and in such position the said collars will be removed, and owing to the wedge-shaped form of said collars and to said inclined ends

M⁴⁵, M⁴⁶ of said supporting heads M, M, said collars may easily be removed by their handles; and in case that said piercers or work-supporting centers should purposely penetrate said blank or work-piece more at the one side than at the other, then in such case, it is only required to give said collars M⁴⁴, M⁴⁶ the required different thicknesses, thereby said piercers or work-supporting centers 5 may be forced more into the one side than into the other side of such blank or work-piece, such as for instance shown in Fig. 22, and, in case that the thickness of the central or hub part of said blank or work-piece is 10 the same or is somewhat greater as is the length of the hub of the finished article, then in such case, said flanges or shoulders e³⁰, e³⁰ of said piercers or work-supporting centers E⁶, E⁶, will serve for the same purpose as the 15 said collars M⁴⁴, M⁴⁶. Thus as above described, the blank or work-piece at its hub or center portion is now automatically and firmly clamped laterally and rotatably supported by said piercers or work-supporting 20 centers, for instance E⁶, E⁶, in such a way that the said centers E⁶, E⁶ with their said axles E, E will, as before described, revolve with the work-piece during the operation 25 against the work-piece, and the head piece or supporting member L of the aforesaid 30 raising, lowering and retaining device has been lowered by said device away from the blank or work-piece the distance for instance indicated by the dotted line y⁴—y⁴ in Fig. 35 to the position shown in the said Fig. 70. The rolls, during the centering or piercing or penetrating and centering process, are either in the positions shown in the Fig. 21 or Fig. 54 wherein are shown, for instance, 40 the piercers or work-supporting centers E⁶, E⁶, or are in the same position when the finished wheel or article is removed from the apparatus or mill, as for instance in Figs. 3, 6, 9, 12 or 15. When the heated 45 work-piece is so supported on said piercers or work-supporting centers, the hub or center portion of said work-piece is also automatically put into clamped condition laterally or axially, as and in the manner before 50 described, and in this clamped condition while so supported said work-piece or its hub or center portion can also be moved axially in either direction as desired, as and for the purpose hereinbefore and hereinafter 55 fully described.

Dishing, undishing and redishing and a few rolling examples.

For instance; with reference to Figs. 1, 2 and 3, the rolling or forming process may begin with the herein named edging and web rolling rolls and tread or face rolling roll and therewith the blank or other work-piece may be rolled to either of the forms or 60 shapes F¹, for instance, such as shown in 65

either of the Figs. 1, 4, 39, 43, 56, 58, 64 or 65 or similar forms, or for instance to the form or shape F² in Fig. 45 or similar form; but in case the finished article should be a dished car wheel having the form or shape 70 shown, for instance, in Fig. 3, the ingot, bloom, blank or other work-piece having been rolled by the herein named edging and web rolling rolls, for instance J¹, J² and the tread or face rolling roll K, to the form or 75 shape F¹ in Fig. 1, and with said rolls in the position shown in said Fig. 1, the herein named web finishing rolls for instance G¹, G² and tread or face finishing roll H, may begin the finishing operation against the work-piece 80 F¹, and during said finishing operation the wheel may also be dished in the following manner:—

With reference to Fig. 1; with the work-piece F¹ supported on the piercers or work-supporting centers for instance E⁶, E⁶ and with its hub or center portion automatically firmly clamped laterally between said piercers or work-supporting centers and before the dishing commences, the piston-rod N³ 85 of the cylinder N with one of the said work-supporting heads M, M with its said axle E and piercer or work-supporting center E⁶ now under constant and continuous pressure from said cylinder N, thereby causing the 90 one piercer or work-supporting center E⁶ to press automatically and continuously toward and against the hub or center portion of this one side of said work-piece F¹, and the piston-rod O³ of the cylinder O with the other 95 work-supporting head M and its axle E and piercer or work-supporting center E⁶ now under constant and continuous pressure from the cylinder O, thereby causing the 100 other piercer or work-supporting center E⁶ 105 to press automatically and continuously toward and against the hub or center portion of said work-piece F¹ at the other side of said work-piece, as shown in Fig. 1, that is, the piston-rods N², N³ will be at the end of 110 their desired forward stroke adjusted by the nut N¹², and said nut N¹² is at rest on the end of the gland extension N¹⁷ forming a stop for this purpose, and the sleeve N⁹ is a certain distance away from the end of the 115 gland extension N¹⁸, but the piston-rods O², O³ are not at the end of either of their adjusted forward or pull-back strokes adjusted by nut O¹² and said sleeve O⁹; said nut O¹² is a certain distance away from the end 120 of the gland extension O¹⁷ and the distance on the piston-rod between said parts O¹² and O¹⁷ equals the proper distance required for 125 dishing the wheel, and the sleeve O⁹ is also a certain distance from the end of the gland extension O¹⁸, then the dishing may take place, while the work-piece is rotating, in the following manner:—While either any or all the driven or all the rolls are in operation, the pressure in said cylinder N is grad- 130

ually somewhat relieved or reduced, retaining therein however, the constant pressure required in said cylinder N to retain the aforesaid automatically clamped condition of the hub or center portion of said work-piece laterally between said piercers or work-supporting centers E¹, E², thereby causing the pressure or force from the cylinder O to overcome the resistance of the piston-rod N² 5 and gradually moving the pistons and their rods O², N² and O³, N³, with their said heads M, M and with the center or hub portion of the car wheel which as aforesaid is firmly held laterally in said automatically clamped condition and revolubly supported by the said 10 piercers or work-supporting centers E¹, E², while the work-piece or wheel is rotating, into the position shown in Fig. 2 in which position the wheel is dished as shown, and 15 in this position, if necessary or desired, the rolls may still be in operation for finishing and truing up the wheel to the form or shape shown at F² in Fig. 2; or, instead of so reducing the constant pressure in said 20 cylinder N, said dishing can also be done, while the work-piece is rotating, in the same manner, by increasing the constant pressure in cylinder O so as to overcome the constant pressure in cylinder N. During the 25 dishing or rolling and dishing operation, the rim of the wheel or other article is supported by the rolls, as shown in Fig. 1 or 2. In the position shown in the Fig. 2, the nut O¹² of the rod O² will now be resting against 30 the end of the gland extension O¹⁷ which forms a stop for this purpose, the sleeve O⁹ will now be farther away from the end of the gland extension O¹⁸, and the nut N¹² of the rod N² will now be a certain distance, 35 that is the proper distance required for dishing, away from the end of the gland extension N¹⁷, the distance between the sleeve N⁹ and end of gland extension N¹⁸ will now be less. After the wheel or other article is 40 completely dished and finished, then the rolls may be pulled back, as shown in Fig. 3 and the outer piston having the piston-rod L⁸ of the before described raising, lowering and retaining device, with the inner piston 45 kept at its lower position, is then again raised from the position shown in the Fig. 70 to the position of said head piece L shown in dotted lines in the Fig. 69; then the said piston-rods O², N² with their said connected parts, are pulled back into the positions shown in the Fig. 3; thereby placing the finished wheel F² or other finished article onto the said head piece L of the said raising, lowering and retaining device, 55 which is then again to be raised by the inner piston having the piston-rod L¹ to the position shown in Fig. 69, when said finished wheel F² is taken away, by any suitable means and another properly heated ingot, 60 bloom, blank or other work-piece put in

place of it and lowered and centered, or pierced or penetrated and centered, &c., as above described. In the positions shown in the Fig. 3, the piston-rods O², O³ and N², N³ are pulled back to their operating limit, that is, the sleeve O⁹ is at rest against the end of gland extension O¹⁸, forming a stop for this purpose, and the sleeve N⁹ is at rest against the end of gland extension N¹⁸, also forming a stop for this purpose. 75

With reference to the Figs. 4 to 15 inclusive, the pressure cylinders O and N with their rods shown in the Figs. 1 to 3 inclusive are not shown in these figures and only parts of the work-supporting heads M, M are shown with their axles E, E and piercers or work-supporting centers, for instance E¹, E², and with different arrangements and forms of rolls. The operations for putting in the ingot, bloom, blank or other work-piece and removing the finished article and for centering or for piercing or penetrating and centering the ingot, bloom, blank or other work-piece and for dishing the wheel or other article, are also similar to those described for and illustrated by said Figs. 1 to 3 inclusive. In case that, the article which may be desired to be rolled and dished by only such rolls as are shown in the said Figs. 4 to 15 inclusive, then in such case, the rolls not shown in these Figs. 4 to 15 inclusive, will not be used in the rolling or rolling and dishing of such article, and therefore may be omitted; or an apparatus or mill for carrying out my invention may be made without them. For instance; a wheel or other article is to be rolled and dished with only the rolls shown in Figs. 4 to 6 inclusive; and the dishing done with the same parts while either any or all the driven rolls or all the rolls shown in said Figs. 4 to 6 are in operation and done, while the work-piece is rotating, in the same manner as before described with reference to Figs. 1 to 3 inclusive, and in this case, Fig. 4 shows for instance, a car wheel ingot, bloom, blank or work-piece centered or pierced or penetrated and centered as before described and rolled on piercers or work-supporting centers, for instance E¹, E², with the herein named edging and web rolling rolls J¹, J² and tread or face rolling roll K to the shape F¹ shown in the Fig. 4. Fig. 5 shows said work-piece F¹ rolled, dished and finished to the form or shape of the car wheel F², as shown. During the dishing or rolling and dishing process, the rim of this wheel or other article, is sufficiently supported by the said rolls J¹, J² and K, as shown, and the dishing process is the same as before described with reference to and illustrated in Figs. 1 to 3 inclusive. Fig. 6 shows the rolls and the piercers or work-supporting centers pulled back and the finished wheel F² ready to be removed, as before described. A 125

wheel or other article may be rolled and dished for instance, with only the rolls shown in Figs. 7 to 9 inclusive, and the dishing done with the same parts while either 5 any or all the driven rolls or all the rolls shown in said Figs. 7 to 9 are in operation and done, while the work-piece is rotating in the same manner as before described with the Figs. 1 to 3 inclusive; in this case, Fig. 10 shows, for instance, a car wheel ingot, bloom, blank or work-piece, centered or pierced or penetrated and centered as before described and rolled on piercers or work-supporting centers E^1 , E^1 , with the herein named edging and web rolling rolls J^1 , J^2 , tread or face rolling roll K and the herein named tread or face finishing roll H ; to the form or shape F^1 shown in the Fig. 7; and Fig. 8 shows said work-piece F^1 rolled, 15 dished and finished to the shape of the car wheel F^2 , as shown. During the dishing or rolling and dishing process, the rim of this wheel or other article is sufficiently supported by the rolls J^1 , J^2 and K , as shown, 20 and the dishing process is the same as before described with reference to and illustrated in Figs. 1 to 3 inclusive; Fig. 9 shows the rolls and the piercers or work-supporting centers pulled back, and the finished 25 wheel F^2 ready to be removed, as before described. A car wheel ingot, bloom, blank or work-piece having the form or shape, for instance, shown at F in the Fig. 10, is to be rolled only at its rim, tread, flange and part 30 of the web next to the rim, and dished with only the use of the rolls shown in the Figs. 10 to 12 inclusive; and the dishing done with the same parts while either any or all the driven rolls or all the rolls shown in 35 said Figs. 10 to 12 are in operation and done, while the work-piece is rotating, in the same manner as before described with reference to Figs. 1 to 3 inclusive. In this case, Fig. 10 shows, for instance, such car wheel blank, 40 ingot, bloom or work-piece having, for instance, the form or shape shown at F , centered or pierced or penetrated and centered as before described and ready to be rolled on piercers or work-supporting centers, for 45 instance E^1 , E^1 , with only the herein named web finishing rolls for instance G^1 , G^2 and tread or face roll H , to the form or shape F^2 before dished in the Fig. 11, and, the Fig. 50 11 shows said car wheel blank, ingot, bloom or work-piece rolled, dished and finished to the form or shape of the car wheel F^2 shown in the Fig. 11. During the dishing or rolling and dishing process, the rim of this wheel or other article is sufficiently supported by the rolls G^1 , G^2 and H as shown, and the dishing process is the same as before described and illustrated by the Figs. 1 to 3 inclusive. Fig. 12 shows the rolls and the 55 piercers or work-supporting centers pulled back, and the finished wheel F^2 ready to be 60 removed, as before described. A car wheel blank, ingot, bloom or work-piece having the form or shape, for instance, as shown at F in the Fig. 13, is to be rolled only at its rim, tread, flange and part of the web next to the rim and dished with only the use of the rolls shown in the Figs. 13 to 15 inclusive, and the dishing done with the same parts while either any or all the driven rolls or all the rolls shown in said Figs. 13 to 15 are in operation and done, while the work-piece is rotating, in the same manner as before described with reference to Figs. 1 to 3 inclusive. In this case, Fig. 13 shows, for instance, such car wheel blank, ingot, bloom or work-piece having the form or shape shown at F , centered or pierced and centered as before described and ready to be rolled on piercers or work-supporting centers, for instance E^1 , E^1 , with only the use of the herein named web finishing rolls for instance G^1 , G^2 , the tread or face finishing roll H and the edging and web rolling rolls J^5 , J^5 having the shape as shown (such rolls as J^5 , J^5 may either be driven by their shafts J , J or turn loose on bearings attached to the ends of said shafts J , J), to the form or shape F^2 before dished in the Fig. 14; and, Fig. 14 shows said car wheel blank F rolled, dished and finished to the form or shape of the car wheel F^2 . During the dishing or rolling and dishing process, the rim of this wheel or other article is sufficiently supported by the rolls G^1 , G^2 and H and J^5 , J^5 , as shown, and the dishing process is the same as before described with reference to and illustrated in Figs. 1 to 3 inclusive; Fig. 15 shows the rolls and the piercers or work-supporting centers pulled back and the finished wheel F^2 ready to be removed as before described. 65

From the foregoing it will now be observed that, the piercers or work-supporting centers revolvably or rotatably support the work-piece and that with the constant pressures in said cylinders N and O being operatively connected with said piercers or work-supporting centers by the means before described, said piercers or work-supporting centers are pressed or forced automatically by constant pressures in said cylinders toward and against the opposite ends of the hub or against the opposite sides of the center portion of the work-piece and thereby the work-piece or wheel at its hub or center portion while so supported by said piercers or work-supporting centers, is also automatically put into clamped condition laterally or axially between said piercers or work-supporting centers, that is, by constant pressures in said cylinders the hub or center portion of the work-piece or wheel is also automatically firmly clamped laterally between said piercers or work-supporting centers, which is absolutely necessary in order to prevent said hub or center portion 120 125 130 135

from being forced out of its true axial or central and desired lateral positions with the work-piece or wheel during the dishing or undishing, or the rolling and dishing or undishing processes, &c, and this said constant clamping force or constant clamping pressure automatically and continually remains during said processes and automatically retains the hub or center portion of 5 said work-piece in its true axial or central position during any desired axial or lateral movement of the work-piece or of the hub or center portion of the work-piece or wheel during either of said processes, and while the 10 work-piece or wheel is so supported by said piercers or work-supporting centers and is also at its hub or center portion so automatically firmly clamped laterally between said piercers or work-supporting centers, 15 said work-piece or its hub or center portion is so automatically moved axially with its said piercers or work-supporting centers during either of said processes, as may be desired; and, to cause said automatical axial 20 movement during the operation while the work-piece or wheel at its hub or center portion in automatically clamped condition is dished, or undished, or rolled and dished or undished, or adjusted between the rolls, &c., 25 30 it will only be required that, either the constant pressure in only one of said cylinders N or O is gradually somewhat reduced so as to cause said automatic axial movement as desired and as before described, or, the constant pressure in only one of said cylinders N or O is gradually somewhat increased so as to overcome the pressure in the other cylinder and thereby cause said automatic axial movement as desired. Or 35 40 This dishing, undishing or redishing operation while the work-piece is rotating may also be effected by retaining said work-supporting axles or work-supporting means in fixed positions while the work-piece 45 is so rotatably supported at its center or hub portion by said work-supporting means and is so laterally clamped between said work-supporting means, as and in the manner before described, and by moving the rolls J¹, J² and K in a lateral direction while the same are positioned for instance as in Fig. 4 or similar thereto and while the same, or at least the rolls J¹, J² 50 are kept in contact with the marginal or rim portion of the work-piece. In thus applying my invention, the marginal or rim portion of the work-piece is moved laterally with respect to its central portion, or, for producing the same effect, both said work-supporting means and said rolls may be moved in opposite directions parallel to the axis of the supported work-piece while said work-piece at its center or hub portion is so supported and is so laterally clamped and while 55 said rolls J¹, J² are so kept in contact with

the marginal or rim portion of the work-piece.

Undishing and redishing may be done in a similar manner as the dishing; in undishing the dished object is placed on said work-supporting centers and while so supported can be moved axially to suit the rolls and then undished while the object revolves. 70

In a dished wheel, the web, that is the part of a wheel between the hub part and the rim part, is in an inclined position, as for instance in a wheel center F² in Fig. 26 or in the wheel F² shown in the Figs. 40, 41, 44 and 67, and in an undished wheel the web is in a straight position, that is, at right angles with the axis of the wheel, or approximately so, as for instance in the undished finished wheel F² shown in the Figs. 42 and 60, and on this account, the said web is longer in the said dished position than in 85 the said undished or straight position, and, the extra length or difference between the length of the web of a dished and undished wheel has to be made up during the dishing process, and for instance, in case that a 90 wheel has been finished by any means to the form or shape, as shown for instance at F² in Fig. 42, and, such wheel is to be dished to the form or shape, as shown for instance at F² in Fig. 40, and, in case such dishing 95 would have to be done, for instance, in the usual manner or through pressure in dies, then in such dishing process, the said web would have to be lengthened by direct extension of the metal in the web in the direction from the hub to the rim-part, or vice-versa, and thereby will be required an immense force to do such dishing, and during such dishing process it will also be possible to twist the finished rim-part with its tread 100 and flange and cause the wheel to be untrue and out of gage. All such difficulties are prevented with my method for dishing or for rolling and dishing, and the force or power required to do the dishing with my 105 process will be very little, as can be easily observed from the following:—With reference to the Figs. 39 and 40 for instance; Fig. 39 illustrates an ingot, bloom, blank or other work-piece rolled with the rolls J¹, J² 110 and K to the undished form or shape F¹ as shown, the roll K having for instance the peripheral or rolling face K²; then with the rolls J¹, J² still in operation, the herein named finishing rolls G¹, G² and H, the roll H having for instance the peripheral or rolling face H¹, commence operating against the wheel, and the dishing may be commenced at the same time and in the manner before described, and when completely rolled 115 and dished, the rolls J¹, J² and G¹, G² and H may still operate against the wheel to its finish, whereby the wheel is made perfectly true and to balance, also to gage or gages, as for instance illustrated in Fig. 40. 120 125 130

The said necessary lengthening of the web during dishing is performed during the dishing process by rolling out with the herein named web finishing rolls, for instance, 5 G¹, G² or G³, G⁴ or G⁵ as shown in the Figs. 40, 41, 42 and 44, the metal f, f near the inner rim-part as indicated by the clearance between the inner rim-part of the wheel and the web reducing roll parts j²⁸, j²⁸ of the said 10 rolls J¹, J² or J³, J⁴ or J⁵ of roll J⁴, which metal was left there by said web reducing roll parts j²⁸, j²⁸ of the herein named edging and web rolling rolls J¹, J² or J³, J⁴ or J⁵, as shown, and thereby adding during the rolling 15 and dishing process by my method of dishing or rolling and dishing, sufficient metal to the web part and providing thereby the required metal for the said extra length to the web part, without producing such above described direct tension in the 20 web. In dishing, for instance, wheels with the rolls shown in the Figs. 4 to 15 inclusive, the said metal for the said extra length of the web may be provided during the dishing 25 process in the following manner; for the dishing or rolling and dishing with the rolls shown in the Figs. 4 to 9 inclusive, the rolls J¹, J² for instance may during the dishing process be sufficiently moved against the inner side or sides of the rim in the direction shown by the arrows f¹, f² in Figs. 5 and 8; and for the dishing or rolling and dishing with the rolls in the Figs. 10 to 15 inclusive, the roll H may, during the dishing process 30 be sufficiently moved against the tread and flange of the wheel in the direction shown by the arrows f³ in the Figs. 11 and 14, or, the rolls G¹, G², may be moved toward the peripheral face of the work-piece.

40 In forming or shaping the hub portion for instance of car wheels or other articles, which hub portion may be formed or shaped either before or after the piercing process or during the piercing process, the ends of the hub may become somewhat uneven, for instance similar to the ends e²⁹, e²⁹ of the hub part of the ingot, bloom or work-piece F shown in the Fig. 31, if rolled on piercers or work-supporting centers formed, for instance as E¹, E¹, and in cases where it is desired to prevent such and also limit the lateral flow of metal in the hub, said piercers or work-supporting centers are each formed, for instance, as E⁶ in Figs. 21, 22, 23, 29, 36, 39, 40, 45, 46, 47, 50, 54, 62, 77, 79, 80, 81 or 82 &c; that is, with the shoulder e³⁰; such shoulders e³⁰, e³⁰ being of proper diameter to suit the hub part, are formed and located on said piercers or work-supporting centers 45 to suit the diameter and length of the hub and the location of the web portion next to the hub of the finished article and also to suit the depth or depths to be pierced or penetrated by said piercers or work-supporting centers, and therewith also limiting the lat- 50

eral flow of the metal in the hub part during the rolling process of forming the hub part, and thereby, said ends of the hub are also formed flat and to the desired gage for the length of the hub, and, said edging and web rolling rolls may come in contact with or against the peripheral faces of said shoulders or flanges during the rolling process of forming the hub as the case may require, as for instance illustrated in the Figs. 1, 21, 39, 45, 46, 47, 48, 50, 54, 56, 57, 62 and 64, and as hereinafter more fully described. Car wheels or other articles after being finished with the apparatus or mill, are bored to suit their axles or shafts, and during such 55 boring, the ends of the hub are generally faced or turned off to gage.

Tread or face rolls.

85 The said tread or face rolls with their movements, &c., hereinbefore and hereinafter fully described, are both pressure rolls and consist of the herein named tread or face rolling roll K and the herein named tread or face finishing roll H, the latter being located between the herein named web-finishing rolls for instance G¹, G² or G³, G⁴ or G⁵, G⁶ or G⁷, or being located as illustrated for instance in Fig. 7. Said face roll H has its axis parallel, or approximately so, with the axes of the said piercers or work-supporting centers; and, said tread or face rolling roll K is located between the herein named edging and web rolling rolls, for instance J¹, J² or J³, J⁴ or J⁵, J⁶ or J⁷, &c.; in the process illustrated for instance in Fig. 13, no face rolling roll K is used, and when in central position between said edging and web rolling rolls, the axis of the tread or face rolling roll K may be parallel, or approximately so, with the axis of said piercers or work-supporting centers, and said tread or face rolling roll may also be used as a tread or face finishing roll, as herein more fully described. Said tread or face rolls K and H with their rolling or working faces, during the rolling or operating process, as and for the purpose hereinbefore fully described, 100 operate against the peripheral face of the work-piece, wheel or other article, either together or independently of each other; and are moved, either together or independently toward, against or away from the work-piece, wheel or other article, by pressure cylinders, one of which is provided for each roll, or by any other suitable means, and said face roll K may also be moved laterally, or, both said face rolls K and H may be arranged for lateral movements, and either one or both rolls may also be retained at any suitable desired radial distance from the axis 105 of the work-piece during the rolling or operating process.

110 115 120 125 130

With reference to Figs. 83, 84, 85 and 86; the face finishing roll H with its supporting or slide head H^5 is located between the said web finishing rolls, for instance G^1 , G^2 , and 5 is moved in the guide or slide bearings H^6 and H^{14} at right angles with the axis of the work-piece, as shown, toward or against or away from the work-piece, such as the case may require, by means of the pressure cylinder H^{27} , or by any other suitable means. To 10 the head H^5 is attached the piston-rod H^{20} of the front end of said cylinder H^{27} . Said cylinder H^{27} is bolted to the bed plate parts B^1 and C^1 by the bolts H^{28} . The said pressure cylinder H^{27} has a piston with a front piston-rod H^{20} and a rear piston-rod passing 15 through the cylinder heads at both ends of cylinder H^{27} ; the front piston-rod H^{20} at its outer end is firmly attached to said head H^5 . The rear piston-rod near its end H^{26} is firmly attached to the cross-head H^{40} and from there the piston-rod is provided with a long thread H^{28} over which is fitted a threaded adjustable nut H^{24} made in 20 halves and firmly held together and to the piston-rod by means of screws; this nut H^{24} can be adjusted from one end to the other end of said thread H^{28} and with the end of the extension H^{32} of the packing box 25 gland forms a stop for the forward stroke of the piston in said cylinder H^{27} , and by adjusting said nut H^{24} forward or backward, as the case may require, the forward stroke of the piston in cylinder H^{27} is regulated and 30 thereby the limit of the forward movement of the tread or face finishing roll H is adjusted. At a suitable distance from the end H^{26} of said rear piston-rod is located an adjusting screw H^{34} which is formed at its end 35 with the enlargement H^{66} forming a stop to limit the movement of the finishing roll H away from the work-piece, and near its outer end said screw H^{34} is provided with a lock nut. Said screw H^{34} is firmly supported by the cross-piece H^{37} which is firmly connected with the cylinder H^{27} by means of the upper and lower distance rods H^{38} , H^{39} and the nuts H^{39} , H^{40} as shown in the Fig. 84. The end H^{38} of said screw H^{34} forms 40 with said end H^{26} of said rear piston-rod a stop for the pull-back stroke of piston in cylinder H^{27} , and by adjusting said screw H^{34} forward or backward, as the case may require, the pull-back stroke of the piston 45 in cylinder H^{27} is regulated and thereby the limit of the return or pull-back movement of the tread or face finishing roll H is adjusted. The said cross-head H^{40} is formed at each 50 of its lower and upper sides with a trunnion H^{41} to which is attached at its end a guide or slide block which is supported and guided in guide bearings of the guide bracket H^{45} , as shown. To said trunnions H^{41} , H^{41} are 55 fitted the pressure blocks H^{43} (see also Fig. 83) which are closely fitted to the forked ends H^{55} of the crank H^{49} and form slide bearings therewith. The said crank H^{49} is firmly fastened to the vertical shaft H^{60} , as shown. To the lower part of said vertical shaft H^{60} is also firmly fastened the crank 60 H^{54} . This crank H^{54} is provided with a journal pin H^{57} , to which is connected one end of the rod H^{62} ; said rod H^{62} with its other end is connected to the one journal pin H^{63} of the loose rocking crank on the vertical shaft H^{67} , as shown. To the other journal pin H^{71} of the said rocking crank on said vertical shaft H^{67} is connected the rod H^{72} , which rod with its other end is 65 connected with the journal pin K^{57} of the crank K^{54} which crank is firmly fastened to the vertical shaft K^{60} , to which shaft is also firmly fastened the crank K^{49} ; said crank K^{49} (see Fig. 83) is connected through 70 the pressure blocks K^{43} , with the trunnions K^{41} , K^{41} of the cross-head K^{40} , in the same manner as is the connection with the crank H^{40} . Said cross-head K^{40} is similar to the cross-head H^{40} and is similarly guided in 75 bearings of the guide bracket K^{45} . The said cross-head K^{40} (see Figs. 83 and 84) is firmly attached to the rear piston-rod end of piston in the pressure cylinder K^{27} for the herein named tread or face rolling roll K . 80

With further reference to Figs. 83, 84, 85 and 86; the said tread or face rolling roll K with the arms K^6 , and supporting or slide head K^{12} , is located between the said edging and web rolling rolls, for instance J^1 , J^2 and their shafts J , J , and is moved in the guide or slide bearing K^{14} at right angles with the axis of the work-piece, as shown, forward or backward, as the case may require, by means of said pressure cylinder K^{27} , or by any other suitable means. To the said supporting or slide head K^{12} is firmly attached the piston-rod K^{20} of said cylinder K^{27} . 90

The said cylinder K^{27} is firmly bolted to the main bed plates. Said pressure cylinder K^{27} has a piston with a front piston-rod K^{20} and a rear piston-rod passing through the cylinder heads at both ends of cylinder K^{27} . The front piston-rod K^{20} at its outer 95 end is firmly connected with said head K^{12} and near the cylinder end is provided as shown in Figs. 83 and 84 with a long thread K^{34} , over which is fitted a threaded adjusting nut K^{36} which is made in halves and 100 firmly held together and to the piston-rod by means of the screws, as shown. The nut K^{36} can be adjusted from one end to the other end of said thread K^{34} , and with the end of the extension K^{38} of the packing box 105 gland forms a stop for the pull-back stroke of the piston in cylinder K^{27} , and by adjusting said nut K^{36} forward or backward, as the case may require, the pull-back stroke 110 of the piston in cylinder K^{27} is regulated and thereby the limit of the return or pull-back movement of the tread or face finishing roll H is adjusted. The said cylinder K^{27} is firmly bolted to the main bed plates. Said pressure cylinder K^{27} has a piston with a front piston-rod K^{20} and a rear piston-rod passing through the cylinder heads at both ends of cylinder K^{27} . The front piston-rod K^{20} at its outer 115 end is firmly connected with said head K^{12} and near the cylinder end is provided as shown in Figs. 83 and 84 with a long thread K^{34} , over which is fitted a threaded adjusting nut K^{36} which is made in halves and 120 firmly held together and to the piston-rod by means of the screws, as shown. The nut K^{36} can be adjusted from one end to the other end of said thread K^{34} , and with the end of the extension K^{38} of the packing box 125 gland forms a stop for the pull-back stroke of the piston in cylinder K^{27} , and by adjusting said nut K^{36} forward or backward, as the case may require, the pull-back stroke 130 of the piston in cylinder K^{27} is regulated

and thereby the limit of the pull-back movement of the tread or face rolling roll K is adjusted. The rear piston-rod near its end is firmly fitted and fastened to the said cross-head K²⁴, and from there, the piston-rod is provided with a long thread K²⁵ over which is fitted a threaded adjustable nut K²⁶ which is made in halves and firmly held together and to the piston-rod by means of screws, as shown. The nut K²⁶ can be adjusted from one end to the other end of said thread K²⁵ and with the end of the extension K²² of the packing box gland forms a stop for the forward stroke of the piston in cylinder K²⁷, and by adjusting said nut K²⁶ forward or backward, as the case may require, the forward stroke of piston in cylinder K²⁷ is regulated and thereby the limit of the forward movement of the tread or face rolling roll K is adjusted.

Said tread or face rolling roll K, through the said sliding head K²⁸, front piston-rod K²⁹, rear piston-rod, cross-head K²⁴ and cranks K²⁰ and K²¹, is connected with the rod H²² loose rocking crank or vertical shaft H²³, rod H²⁴, cranks H²⁵ and H²⁶, cross-head H²⁷, rear piston-rod, front piston-rod H²⁸ and with said sliding head H²⁹ carrying the herein named tread finishing roll H; and thereby equalizing the movements and the pressures of said tread or face rolling roll and said tread or face finishing roll against the work-piece; that is, with the rods H²⁵ and H²⁶ connected as shown, in Fig. 83, said tread or face rolls H and K may be moved toward or away from the work-piece together, that is, each the same distance. For some rolls or articles it is required that, each one of said rolls H and K be moved toward, against or away from the work-piece independently of each other; for one of said rolls H or K may be used only, and in such cases, the said rods H²⁵ and H²⁶ will be disconnected, for instance, the one end of the rod H²⁵ be disconnected from the journal pin H²⁷ of the crank H²⁶ and swung on the journal H²⁷ into the position indicated by the dotted lines for H²⁵ and, the end of the rod H²⁶ be disconnected from the journal pin K²⁵ of the crank K²⁴ and swung on the journal pin H²⁴ into the position indicated by the dotted lines for H²⁶. By this means, said tread or face finishing roll H and said tread or face rolling roll K, may be worked, either together or independently of each other.

Indicating device for peripheral face rolls.

Between said supporting or slide head H²⁹ and said cylinder H²⁷, see Figs. 84, 85 and 86, is attached to the piston-rod H²⁸, the arm H³⁰ which with its upper end is connected to one arm of the bell crank H³¹ by the link H³², and the other arm of said bell crank H³¹ is connected with the crank H³⁰ by the link H³³. Said bell crank H³¹ is supported on journals at H³⁴; said crank H³⁰ which also serves as a balance weight is mounted on the shaft H³⁵ to whose outer end is fastened the pointer H³⁶; said shaft H³⁵ is turned forward and backward, as the case may be, in bearings formed with or attached to the dial piece H³⁷; this dial piece being supported by the upper bed plate part C¹ and fastened thereto as shown. Said dial piece H³⁷ at the face of its upper segmentally formed side is provided with a curved scale which may be graduated to any convenient scale; for instance, from 0 to 16 as shown. The Fig. 85 shows, on an enlarged scale, the upper part of the dial piece H³⁷ with the scale and the indicator parts connected therewith; Fig. 86 shows the same in section. In case the piston with the rod H²⁸ is at its maximum pull-back stroke, then the pointer H³⁶ will be at the beginning point of the graduations; that is, at the line 0, and when said piston with the rod H²⁸ is at its maximum forward stroke, then the pointer H³⁶ will be at the line 16; thus the position of the piston and of the roll H and also the diameter of the wheel or other article can always be seen from the dial during the operation of rolling or at any other time. Near its said upper side the dial face is provided with a T-shaped groove H³⁸ to which is fitted the slide piece H³⁹ and the washer plate H⁴⁰ which is provided with bolt and nut H⁴¹, as shown; said slide piece H³⁹ is also provided with the pointer H⁴², as shown. This slide piece is used in the following manner;—In case the wheel or other article during the rolling process has reached its proper finished diameter, with the tread or face finishing roll H in such position that the pointer H³⁶ is, for instance, in line with the line 11½ on the scale, that is, half way between the lines 11 and 12 of the scale, then the pointer H³⁶ with its slide piece H³⁹ will be moved and set to such position and there fastened to the dial piece by the means of said washer plate H⁴⁰ and bolt H⁴¹, as shown by the dotted lines for said H³⁹, H³⁶ in the said Fig. 86, and, all the wheels or other articles rolled to such diameter, may be rolled with the pointer H³⁶ set in line with said line 11½ on said scale, and, when the tread or face finishing roll H reaches such position, the pointer H³⁶ will be in line with said pointer H⁴², as is shown in the Fig. 84, and, in such position, any further movement of said tread or face finishing roll H, either forward or backward, will be stopped and the roll held in such position, either by the pressure in the cylinder H²⁷ or by the aforesaid adjustable stops H²⁴, H²⁵ or by H²⁶, H²⁷ as the case may be, or by any other suitable means.

At the end of said supporting or slide head K^{12} , which supports the face roll K , see Fig. 84, is attached to the piston-rod K^{20} the arm K^{76} which with its upper end is 5 connected to the lever arm K^{78} provided with the balance piece K^{80} , by the link K^{77} ; said lever arm K^{78} is mounted on the shaft K^{90} to the outer end of which is fastened the pointer K^{81} ; said shaft K^{90} turns for 10 ward or backward as the case may be, in bearings formed with or attached to the dial piece K^{82} . This dial piece is supported by and firmly connected to the bed plate part B^2 by the means as shown in Fig. 84. Said 15 dial piece K^{82} at the face of its upper segmentally formed side is provided with a curved scale graduated to any convenient scale, for instance from 0 to 16 as is shown in said Fig. 84. The T-shaped groove K^{83} 20 and the parts K^{84} , K^{85} , K^{86} and K^{87} , are similar to the like parts in said Figs. 85 and 86 and as described for the indicator for the tread or face finishing roll H . In case that the piston-rod K^{20} is at its maximum 25 pull-back stroke, then the pointer K^{81} will be at the beginning point of the graduations at the line 0 on the scale, and when said piston with the rod K^{20} is at its maximum forward stroke, then the pointer K^{81} will 30 be at the end of the graduations at the line 16 of the scale; thus the position of the piston and of the roll K and also the diameter of the wheel or other article can always be seen from the dial during the rolling 35 progress, or at any other time. The slide piece K^{85} with pointer K^{87} is used and adjusted in the same manner as explained above with reference to the tread or face finishing roll H , that is, in case the work- 40 piece or wheel or other article has reached its desired diameter during the rolling process, with the tread or face rolling roll K in such position that the pointer K^{81} is, for instance, in the position shown in the Fig. 84, 45 then in this case, the pointer K^{87} with its slide piece K^{85} will be moved and set in line with the pointer K^{81} and there fastened to the dial piece K^{82} by the means of said bolt K^{86} , as is shown in Fig. 84; and all the 50 wheels or other articles rolled to such said diameter, may be rolled with the pointer so adjusted, and when the tread or face rolling roll K reaches such position, the pointer K^{81} will be in line with said pointer K^{87} , as in 55 the Fig. 84, and in such said position, any further movement of the tread or face rolling roll K , either forward or backward will be stopped and the roll firmly held in such position, either by the pressure in the cylinder K^{27} , or by the aforesaid adjustable stops K^{24} , K^{25} or by K^{30} , K^{33} , as the case may be, 60 or by any other suitable means.

In rolling for instance car wheels, the lateral thickness or width of said face roll K , 65 is the same as is the lateral thickness or

width which the outer or rim portion of the car wheel is to have when finished, as is shown for instance in the Figs. 39 to 44 inclusive and 56 to 59 inclusive and 64 to 66 inclusive, thereby, with said roll K and with 70 the rolls for instance J^1 , J^2 or J^0 , J^0 or J^8 , J^4 &c., in said Figs. 39 to 44 and 56 to 59 and 64 to 66 inclusive, formed as shown and, with the peripheral rolling or operating face of said face roll K formed as and for 75 the purpose hereinafter described, for instance with reference to Figs. 39, 43, 51, 52, 53, 90 and 91, and with the inner rolling or operating portion of the web reducing roll part J^{88} of the edging and web rolling rolls 80 J^1 , J^2 &c., formed sufficiently conical, as and for the purpose hereinafter fully described for instance with reference to Figs. 39, 43, 49, 50, 90 and 91, and, with all said three rolls situated in a plane passing laterally through the car wheel at one side of its axis and with said rolls moved and operated during the rolling process, as and for the purpose hereinbefore and hereinafter described, the metal in the peripheral face and 90 total rim portion of the work-piece or car wheel is worked continuously during the rolling process upon all its surfaces simultaneously with said three rolls so formed and so moved and operated and so situated 95 as before-said and as shown for instance in said Figs. 39 to 44 and 56 to 59 and 64 to 66 inclusive and diagrammatically illustrated in Figs. 49, 50, 90 and 91 and which to my knowledge, together with the result 100 obtained thereby, was never done or accomplished before in rolling car wheels, whereby the metal in said peripheral face and rim portion is uniformly condensed to its maximum and is also rolled smooth on all its 105 surfaces to the desired form or shapes without leaving a raised circular portion or pin which would have to be removed afterward by turning or other costly-means.

Web finishing rolls.

With reference, for instance, to Figs. 1, 2, 3, 10 to 15, 16, 21, 26, 39 to 45, 56 and 64 &c.; said web finishing rolls G^1 , G^2 or G^0 , G^0 or G^3 , G^4 or G^5 , G^6 or G^5 , G^5 &c., are 110 both positively driven side rolls and are oppositely-arranged and located as shown, one at each side of the work-piece, and their shafts are inclined to the sides of the work-piece, and during the rolling process, may 120 operate against the web and inner rim-part of the work-piece or wheel or other article, either together or independently of each other, and they are also moved either together or independently toward or against 125 or away from the work-piece or wheel or other article, as the case may require, by the pistons of pressure cylinders or pressure mechanism, one for each roll operatively connected therewith, or by any other suit- 130

able means; and if desired, said web finishing rolls are also formed so as to form with the tread or face finishing roll at each side thereof, a stop for their movements against the work-piece or wheel or other article and thereby also assist in turning or driving the tread or face finishing roll H by frictional contact therewith; or, said lateral movements of said web finishing rolls may be limited by adjustable stops provided in said pressure mechanisms which are operatively connected with said rolls.

In most cases, said web finishing rolls are preferably formed for instance, as G¹ and G² in the Figs 39, 40, 41, &c., that is, the part g¹³⁶ of each of said rolls G¹, G² is the herein named web finishing roll part, operating as shown on the web and inner rim-part of the wheel or other article; and, the part g¹¹⁷ of each of said rolls G¹, G² in the process illustrated in said figures is not operating against the work-piece, but in most cases may be permitted to press against the opposite sides of the tread or face finishing roll H as shown, thereby forming aforesaid stop for said web finishing rolls at or near the work-piece in the direction of their lateral movements toward or against the work-piece and thereby also assisting in turning or driving said tread or face finishing roll H by frictional contact therewith; or, such rolls may be formed as for instance G³, G⁴ in Figs. 43 and 44, wherein the roll G³ is moved toward the work-piece from the position shown in Fig. 43 to the position shown in Fig. 44, in which position said roll G³ is retained during its operation against the work-piece until the wheel is dished and finished, and the said roll G⁴ with its said web finishing roll part g¹³⁶, in finishing and dishing this wheel, which has its rim and hub parts extended on the one side of said wheel only, as shown, is operating and is moved against the inner web and rim parts of said wheel, as shown in Fig. 44; or, such rolls may be wholly formed conical, as for instance G⁵, G⁶ in the Fig. 45, wherein the roll G⁵ during its operation against the work-piece, is retained in position against the roll part H³ of said tread or face finishing roll H, as shown, until the article is reformed or finished, while said other roll G⁶ is operating and is moved against the work-piece, and thereby finishing the article to the form or shape F², as shown in said Fig. 45.

Fig. 16 shows in plan view, with its upper part removed, one of the swinging or oscillating frames on which is mounted in bearings G¹⁰ and G¹² one of said shafts G which has one of said web-finishing rolls, for instance G², and also shows the lower part G¹⁶ of said oscillating frame. Said shaft G consists of the two sections G and G⁸ and has said web-finishing roll G² at the outer

end adjacent or near the oscillating or free end of said oscillating frame and at its other or outer end it has the coupling part G³⁰ which is connected to the driving mechanism for said roll, not shown herein. Said shaft section G is interchangeable with other similar shaft sections and is removably fitted into the socket portion G⁹ of said shaft section G⁸. Said roll G² with its said shaft sections is longitudinally movable in said bearings G¹⁰ and G¹² the distances as for instance indicated by the dotted portion of said roll G² for said longitudinal movements, and is also laterally movable during the operating process from the position of said roll G² shown in solid lines to its position next thereto shown in dotted lines. Said roll G² may also be moved laterally from its said position shown in solid lines to its extreme position shown in dotted lines and indicated by its path shown by the curved dotted line x. Each of said oscillating frames swings or oscillates on bearings provided in its hub shaped end for instance G¹¹ and, when said web finishing rolls G¹, G² are moved or oscillated toward or against or away from the work-piece, travel therefore, each in a circular path which has its center at g⁷³, as indicated in Fig. 16, that is, the circular path described by each of said web finishing rolls, is concentric with the axis of the bearing provided in said hub shaped end G¹¹, as for instance illustrated by said circular dotted line x which is drawn from said center g⁷³ in Fig. 16, and thereby the pressure of its roll against the work-piece, will also be in the direction of the path described from the said center g⁷³, and thereby is also produced the proper direction of pressure against the work-piece; that is, the main purpose for locating said center g⁷³ a proper suitable distance away from the axis or extended axis of its said web finishing roll shaft G. In case that the said web finishing rolls would be moved in the direction of a path described, for instance, with the same radius, but from a center located for instance on the axis or extended axis of said shafts G, said roll would be moved in the direction of such path described from such a center located on the axis or extended axis of its shaft as is illustrated, for instance, by the circular dotted line y in said Fig. 16, and thereby would also produce an undesirable direction of pressure of said web finishing rolls against the work-piece, and would also move each of said rolls, when pulled back, into the way of the work-supporting head M. During the rolling or operating process against the work-piece in accordance with my invention, said web finishing rolls, when moved laterally during said rolling process, are moved practically in a line parallel to the axis of the work-piece; that is, parallel to the center line or axes of

said piercers or work-supporting centers. The oscillating frames of said web finishing rolls, of which only one, with for instance the roll G^2 , is illustrated in Fig. 16, are each 5 moved or oscillated laterally by power or pressure means operatively connected therewith to the journal G^{15} thereof shown in Fig. 16.

10 Web finishing rolls; movement and pressure equalizing device, &c.

Said web finishing rolls, for instance, G^1 and G^2 , are connected together by equalizing mechanism which is similar to the equalizing mechanism hereinbefore described for the tread or face rolling rolls, in such manner that said rolls may be connected with or disconnected from said equalizing mechanism, without disconnecting said rolls from the 15 coöperating pressure cylinders operatively connected with said rolls. Said mechanism equalizes the movements and pressures of said web finishing rolls toward or against the work-piece; that is, for instance, with 20 the said rolls so connected together, said rolls, for instance, G^1 and G^2 are moved toward or against or away from the work-piece at both sides thereof, each the same distance as illustrated more fully for instance in the Figs. 31, 54, 56 to 59, 62 and 64 25 to 66. For the rolling process illustrated for instance in Figs. 43 and 44, it is required that each one of the rolls, as for instance G^3 and G^4 shown in said Figs. 43 and 44, be 30 moved laterally toward or against or away from the work-piece independently of each other, and in such case, said rolls G^3 and G^4 are disconnected from said equalizing mechanism without disconnecting said rolls from 35 the coöperating pressure cylinders operatively connected with said rolls. Said rolls will thereby be permitted to be moved laterally by their pressure cylinders operatively connected therewith toward or against or 40 away from the work-piece independently of each other and, either one or both rolls may be retained in any desired position, as for instance shown in said Figs. 43 and 44 and also illustrated in Fig. 45.

45 Said web finishing rolls, as before described, are located one at one side and the other at the other side of the work-piece, as shown, for instance, in Figs. 1, 2, 3, 10 to 15, 21, 26, 39 to 45 inclusive and 54, 56 to 59 inclusive and 62, 64 to 66 inclusive &c., and by the means above described, said web 55 finishing rolls may be moved laterally, either together or independently of each other, or, they may be moved in such manner that, for 60 instance, any one of said web finishing rolls may be retained in any position between the limits of their range of movements and the other may be moved toward or away from the work-piece, such as the case may require, 65 during their operation against the work-

piece. For instance, the web finishing rolls G^1 , G^2 in Figs. 39, 40, 41, 54, 56 to 59, 62, 64 to 66, and the web finishing rolls G^0 , G^0 in Fig. 42 may be moved together, that is, they may be moved toward, against or away from 70 the work-piece at both sides thereof, each the same distance; and, the web finishing rolls G^3 , G^4 in Figs. 43 and 44 and the web finishing rolls G^5 , G^6 in Fig. 45, are moved independently of each other, as for instance 75 in Figs. 43 and 44, wherein one of said rolls, the roll G^3 formed as shown, is moved toward the work-piece F^1 into the position against the one side of the tread or face finishing roll H , as shown in Fig. 44, and 80 in this position, said roll G^3 during its operation against the work-piece is retained or held while the other web finishing roll G^4 is moved as before described by the pressure mechanism operatively connected therewith, toward and against the work-piece at 85 its other side and with its said finishing roll part g^{188} is operating against the inner sides of the web and rim parts, and therewith and with the said tread or face finishing roll H the wheel may be finished during the before described dishing process to the form or shape shown at F^2 in the Fig. 44; or, as 90 for instance in Fig. 45 wherein one of said web finishing rolls, the roll G^5 formed 95 wholly conical as shown, is moved toward the work-piece and into the position against the part H^3 of the tread or face finishing roll H as shown, and in this position said roll G^5 is retained or held during its operation against the work-piece while the other web finishing roll G^6 , which in this case is also formed wholly conical, is moved as before described by its pressure mechanism 100 operatively connected therewith, toward and against the work-piece, and therewith and with said tread or face finishing roll H , the article may be finished to the shape or form F^2 in Fig. 45.

During the final rolling process, for instance as shown in the Figs. 26, 40, 41, 42, 44, 45, 57, 59 or 66, the conically shaped part g^{188} of said web finishing rolls G^1 , G^2 or G^0 , G^0 or G^3 , G^4 or part of the wholly conical rolls G^5 , G^6 , may be permitted, as 110 before said, to come or press against the sides of the said tread or face finishing roll H , thereby forming, at or near the work-piece, a stop to limit the lateral movement of said web finishing rolls against the work-piece and also assist in turning or driving said tread or face finishing roll H . The final rolling process may also be done with the said web finishing rolls in the position, as shown for instance, in Fig. 27, that is, in 115 this position said web finishing rolls do not come against the sides of said face finishing roll H , but said lateral movements of said web finishing rolls are limited by adjustable stops provided in the pressure mechanism 120 125 130

operatively connected with said web finishing rolls, or by any other suitable means.

Edging and web rolling rolls, movement and pressure equalizing device, &c.

5 Said edging and web rolling rolls J^6 , J^9 or J^1 , J^2 &c., are oppositely located positively driven side rolls, one being arranged at each side of the work-piece. When in 10 normal position, their shafts J , J may either be parallel or inclined to the sides of the work-piece, and during the rolling process they may operate against the hub and adjacent web part, or the web part, or the 15 inner rim and adjacent web part, and also upon the edges of the rim of the work-piece or wheel or other article either together or independently of each other; and, with their lateral moving device, may be moved laterally toward or against the work-piece or 20 away from it, or with the same, either together or independently of each other, by the pistons of pressure cylinders, one for each roll operatively connected therewith for its said lateral movements; and with 25 their shifting or longitudinally moving device may be moved longitudinally in either direction, between the center or hub part and the rim-part or periphery of the work-piece or wheel, or other article, forward and 30 backward, such as the case may require, by pressure cylinders, one for each roll for its said shifting device. Each of said edging and web rolling rolls is, either removably 35 attached to its shaft in such a way that the whole roll may be driven by its shaft or that only part of the roll may be driven by its shaft and the other part of the roll be permitted to turn loose; or, the whole roll may 40 not be driven, but instead be permitted to turn loose on a journal which is removably attached to the end of its shaft; and said edging and web rolling rolls are formed so that during the rolling process they come or are 45 against the opposite sides of the tread or face rolling roll and thereby also form with the tread or face rolling roll a stop for their lateral movement against the work-piece, and thereby also assist in turning or driving 50 said tread or face rolling roll K by frictional contact therewith, or, said lateral movements of said edging and web rolling rolls may be limited by adjustable stops provided in said power or pressure mechanism 55 which is operatively connected with said rolls or by any other suitable means.

In most cases, the edging and web rolling rolls are preferably formed, for instance, as J^1 and J^2 , in Figs. 21, 26, 39, 40, 41, 47, 48, 49, 54, 56 to 59, 62, and 64 to 66 inclusive; the part j^{28} of such rolls J^1 , J^2 is the web reducing roll part, which may however have any other desired suitable form or shape than herein shown, operating as shown alternately on the web and hub parts, web

part, and web and rim parts of the work-piece, wheel or other article, that is, said web reducing roll parts j^{28} , j^{28} of said rolls J^1 , J^2 , with their outer rolling or operating portions, are operating on the web and hub 70 parts of the work-piece and form or shape the hub part as and for the purpose herein-after described, for instance with reference to the Figs. 46, 47, 48, 54, 55 or 62 and 64, and with their inner rolling or operating 75 portions are operating on the web part and the inner peripheral face or faces of the rim of the work-piece and roll said faces or inner rim portion sufficiently inclined toward the periphery of the work-piece, as 80 and for the purpose hereinafter fully described for instance with reference to the Figs. 39, 43, 49, 50 and 90. The part j^{29} of each of said rolls J^1 , J^2 is the edging roll part, rolling or operating as shown upon 85 the edges or opposite sides of the marginal or rim-part of the work-piece, wheel or other article, and also limiting the lateral flow of the metal therin between the roll parts j^1 , j^2 of said rolls J^1 , J^2 and the periphery of the work-piece. Said roll parts j^1 , j^2 , during the rolling process come or are against the opposite sides of the tread or face roughing roll K and thereby may also be permitted to press against the sides 90 of said face roll K as shown, thereby also forming a stop at or near the work-piece to limit the lateral movement of said edging and web rolling rolls toward and against the work-piece and also assisting in turning or 100 driving said face roll K ; or such rolls may not have such web reducing part j^{28} , but be wholly formed conical as, for instance, the edging and web rolling rolls J^3 , J^4 in Figs. 13 to 15 inclusive, wherein said rolls J^3 , J^4 105 operate only upon the edges of the rim-part of the wheel shown; and as in Fig. 43 wherein the work-piece F^1 may have its hub part and its rim-part formed with such rolls for instance, as shown, on the one side of the web part only. In said Fig. 43, the one edging and web rolling roll J^3 is formed wholly conical as shown, and the other edging and web rolling roll J^4 is formed similar to said rolls J^1 , J^2 and with its said part j^{28} the 115 said roll J^4 operates alternately on the hub and adjacent web part, web part, inner rim and adjacent web part and with its said part j^{29} operates upon the edge of the rim-part, as shown; and as in Fig. 45, wherein the one edging and web rolling roll J^5 is similar to the said roll J^3 , and the other roll J^6 is similar to said rolls J^1 , J^2 , but the roll part j^{28} of said roll J^6 is operating on the work-piece only, as shown.

The shafts J , J for said edging and web rolling rolls J^1 , J^2 are supported by their journals in bearings located in the guide pieces J^8 , J^9 , one guide piece being provided for each roll, (see Figs. 17 and 18) 130

and in the housings J^{10} and J^{11} of each of the swinging or oscillating frames; and each of said shafts J , J is driven either by bevel gears J^{22} and J^{23} , as shown, or by any other gears. Each of said edging and web rolling rolls J^1 , J^2 , through its pressure cylinder operatively connected to the journal or bearing J^{14} of said guide piece J^8 (see Fig. 18), is moved or swung laterally toward or against or away from the work-piece on its oscillating journal J^{138} , which journal is coaxial with the vertical driving shaft J^{18} (see Figs. 17 and 18). Each of said rolls J^1 , J^2 is also shifted or moved longitudinally with its shaft J , in the bearings located in the said parts J^8 , J^{10} and J^{11} , forward and backward in the direction of the axis of its shaft J by its co-operating pressure cylinder J^{77} , of which there is provided one for each roll, and which is located over the upper side of the swinging or oscillating frame part J^{14} , as shown in Fig. 17.

The rolling with said edging and web rolling rolls may, in most cases, be commenced at or near the center portion of the ingot, bloom, blank or other work-piece, as for instance illustrated by the dotted lines for said edging and web rolling rolls shown in the Figs. 21, 39, 46, 54 and 62. In Fig. 46 for instance, the rolling may commence near the center portion of the blank or work-piece supported on the piercers or centers E^6 , E^6 ; that is, at a suitable distance from the hub which is to be formed onto said work-piece, as for instance indicated by the positions of the edging and web rolling rolls J^1 , J^2 , shown in solid lines and, from these positions said rolls J^1 , J^2 are moved and forced laterally into the opposite sides of said supported work-piece as shown by the dotted lines of said rolls J^1 , J^2 and from there said rolls J^1 , J^2 are shifted or moved longitudinally toward said center portion to form said hub until said rolls are in contact with the peripheral faces of the flanges or shoulders e^{30} , e^{30} of said piercers or centers E^6 , E^6 , as indicated by the dotted end lines of said rolls. During this hub forming process, said shoulders e^{30} , e^{30} are also limiting the lateral flow of metal in said hub portion, which metal during said process had been forced laterally outward against said shoulders e^{30} , e^{30} and radially against said rolls J^1 , J^2 and thus formed the hub portion shown by the dotted lines. From their positions adjacent said shoulders e^{30} , e^{30} , said rolls J^1 , J^2 are shifted or moved longitudinally away from the hub, over their said starting positions, and toward the rim portion until said rolls have reached the position shown for instance in the Figs. 39, 58 and 65, or during this process, said rolls J^1 , J^2 may also be moved forward and backward as often as desired; and, when the rim portion of said work-piece is rolled with the

rolls J^1 , J^2 and K to the form for instance shown in the Fig. 39, then the peripheral face of the work-piece will have been rolled to a beaked or rudimentary form, as and for the purpose hereinafter described, for instance with reference to the Figs. 39, 43, 51, 52, 53 and 90, and the inner peripheral face or faces of the rim portion of the work-piece will have been rolled sufficiently inclined toward the peripheral face of the work-piece, as and for the purpose herein-after fully described, for instance with reference to the Figs. 39, 43, 49, 50 and 90. During the said process, said rolls J^1 , J^2 will in most cases be permitted to come against the sides of the face roll K , as for instance shown or indicated by the dotted lines in Figs. 21, 46, 54 and 62, or by the solid lines in Figs. 26, 39 to 41, 56 to 59 and 64 to 66, or the lateral movement of said rolls may be limited by the aforesaid adjustable stops provided in the power or pressure mechanism operatively connected with said rolls or by any other suitable means.

Figs. 17 to 20 inclusive illustrate one of the oscillating frames for said edging and web rolling rolls; Fig. 18, is a horizontal sectional plan of said oscillating frame through the axis of the roll shaft J , said shaft and parts connected therewith being shown in plan. Fig. 17 is a side elevation of said oscillating frame, illustrating the shifting and driving arrangements for one of said edging and web rolling rolls. The driving mechanism for driving said roll is connected to the shaft J^{18} .

Each of the oscillating frames for said edging and web rolling rolls with the shafts J of the latter, is oscillated or swung forward and backward laterally on its lower trunnion J^{138} and its upper trunnion J^{17} by its co-operating power or pressure cylinder, which is operatively connected to the journal pin J^{104} located in said guide piece J^8 Fig. 18, one cylinder being provided for each roll for its said lateral movements. The lower oscillating frame part J^{15} , see Figs. 17 and 18, is formed or provided with the trunnion part J^{138} as shown. Said lower trunnion J^{138} with its inner sides form a bearing for the vertical shaft J^{18} . The housings J^{10} and J^{11} are adjustably fastened with their lower ends to said lower oscillating frame part J^{15} , and with their upper ends they are adjustably fastened to the upper oscillating frame part J^{14} . Said upper frame trunnion J^{17} is fitted and fastened to the upper frame part J^{14} , as shown, and its axis is in line with the axis or extended axis of said vertical shaft J^{18} .

Each of said shafts J , J , between said housings J^{10} and J^{11} , is provided with feathers, and each of said bevel gears J^{22} , one on each of said shafts J , J , is formed at its inner end with a long hub, as shown,

- which has a sliding fit over its shaft J and over said feathers and by means of said feathers said shaft is driven or rotated by said bevel gear J²². Between the inner sides of said housings J¹⁰ and J¹¹ and the ends of said bevel gear J²² are located ball thrust bearings whereby said bevel gear is kept in its proper position endwise between said housings J¹⁰ and J¹¹ and in proper mesh with said bevel gear J²³. To each of the upper oscillating frame parts J¹⁴, one being provided for each oscillating frame, are fitted and bolted the supporting brackets J²⁸, J²⁹ and J²⁹, J²⁹ for its shifting cylinder J⁷⁷, as shown. Each of said shifting cylinders J⁷⁷, J⁷⁷, of which one is provided for each roll, is firmly but longitudinally and adjustably held by said supporting brackets and supported thereby.
- 20 Each of said edging and web rolling rolls is provided with one of said shifting cylinders J⁷⁷, J⁷⁷ as shown in the Fig. 17, and with reference to the Fig. 17; the piston-rod J⁷⁹ of the shifting cylinder J⁷⁷ by means of the double lever J⁹⁷, J⁹⁷ shifts or moves longitudinally said roll shaft J with its edging and web rolling roll J² endwise alternately forward and backward to the positions indicated for said roll J² for instance by the dotted lines thereof in Fig. 17. Said cylinder J⁷⁷ has a piston with a piston-rod J⁷⁸ and a piston-rod J⁸⁰ passing through the cylinder heads J⁸¹, J⁸¹ at both ends of the cylinder J⁷⁷. The piston-rod J⁸⁰ at its outer end has firmly fastened thereto the collar J¹³⁴ and from there is provided with a long thread J⁸⁴, over which is fitted a threaded adjustable nut J⁸³ which is made in halves and when adjusted is firmly held together and to the piston-rod J⁸⁰. This nut can be adjusted from one end to the other end of said thread J⁸⁴, and with the end of the extension J⁸² of the packing box gland forms a stop for the piston stroke at this end of the cylinder, and by adjusting said nut J⁸³ forward or backward, such as the case may require, the forward stroke of the piston is regulated and thereby the desired limit of the shifting movement of the said edging and web rolling roll away from the center part and toward the rim-part or periphery of the work-piece, wheel or other article is regulated or adjusted. To the outer end of the piston-rod J⁷⁹, the cross-head J⁸⁹ is fastened with a key, or other suitable means, and from there said piston-rod is provided with a long thread J⁸⁷ over which is fitted the threaded adjustable nut J⁸⁶ which is made in halves and when adjusted is firmly held together and to the piston-rod. This nut J⁸⁶ can be adjusted from one end to the other of said thread J⁸⁷, and with the end of the extension J⁸⁵ of the packing box gland forms a stop for the piston stroke at this end of the cylinder, and by adjusting
- 5 said nut J⁸⁶ forward or backward such as the case may require, the return stroke of the piston is regulated and thereby the desired limit of the shifting movement of the said edging and web rolling roll toward the center or hub part of the work-piece, wheel or other article is regulated or adjusted. Said cross-head J⁸⁹, at both its outer sides is formed or provided with trunnions J⁹¹; links J⁹⁰ are connected with one of their ends to said trunnions J⁹¹, and with their other ends with the journal pin J⁹² as shown, said links being located at the upper ends of said double lever J⁹⁷, J⁹⁷ and connecting the upper ends of said double lever J⁹⁷, J⁹⁷ with the cross-head J⁸⁹ as shown. Lugs J⁹⁰ are formed with said lower oscillating frame part J¹⁵ at one end thereof, as shown, and are provided with bearings for the one journal pin J⁹⁶ of the link J⁹⁵, at its other end said link J⁹⁵ is provided with a bearing for its other journal pin J⁹⁴. At each of the outer sides of said link J⁹⁵, the end parts of said journal pin J⁹⁴ are fitted or fastened to the lower ends of said double lever J⁹⁷, J⁹⁷, as shown; said double lever consisting of the like parts or levers J⁹⁷, J⁹⁷ as shown in the Fig. 18. The said roll shaft J at its outer end is provided with a thread over which is fitted the threaded adjustable nut J¹⁰² which is made in halves and when adjusted is firmly held together and to the shaft J. On said shaft J and between said nut J¹⁰² and a shoulder provided on the shaft J, are fitted to said shaft J the cross-head J⁹⁸ and thrust bearings located at each end of said cross-head J⁹⁸. Said cross-head J⁹⁸ is formed at two of its opposite sides with the journals or trunnions J⁹³, J⁹³, whereby said cross-head J⁹⁸ is connected with the double lever J⁹⁷, J⁹⁷, as shown. Said cross-head does not revolve with shaft J and any end play or wear is taken out or adjusted by said nut J¹⁰². Said roll shaft J is as before said, supported in the bearing of said guide piece J⁸ and in the bearings of said housings J¹⁰ and J¹¹, and is shifted or moved longitudinally with said double lever, J⁹⁷, J⁹⁷ by said shifting cylinder J⁷⁷ in the bearings of said parts J⁸, J¹⁰ and J¹¹ and in said bevel gear J²², forward and backward, such as the case may require.
- 10 Each of said guide pieces J⁸, one for each roll, see Figs. 17 and 18, is formed at its upper side with a lug to which is lengthwise adjustably attached the gage rod J⁹, as shown, or two or more such gage rods may each be so adjustably attached to such lug or lugs as shown for instance in Figs. 19 and 20 in which figures for instance three such gage rods are shown and in which figures the Fig. 20 is a sectional end view through line 20—20 Fig. 19, looking in direction of the arrows. At its one end, said
- 15 70 75 80 85 90 95 100 105 110 115 120 125 130

gage rod J^9 is formed with a long thread which is provided with the nuts as shown, and its other pointed end is bent down, as shown. Each of said shafts J , J is provided with a circumferential mark or shoulder J^{152} as shown. In the Fig. 17, the roll J^2 is shown in position with the said adjustable nut J^{83} against the end J^{82} of said extension of said packing box at the one end of cylinder J^{77} , and the dotted lines of the total roll J^2 show said roll when moved into the position with the said adjustable nut J^{86} against the end J^{85} of the extension of said packing box at the other or lever end of cylinder J^{77} , as is shown by the dotted lines for said nut J^{84} , and therein, the position of said double lever J^{97} , J^{97} is also shown by the dotted lines. When the gage rod J^9 is adjusted, for instance, to its commencement position shown in Fig. 17, then in such case, the roll J^2 is shifted until said mark or shoulder J^{152} on said shaft J has reached the point of said gage J^9 , as illustrated by the dotted line for J^{152} , and in said position, the roll J^2 will be, for instance, in the position indicated by the dotted lines for part of said roll J^2 , and in which position the operation of the said roll J^2 against the work-piece may commence. Said gage rod or rods J^9 can also be adjusted to any desired position or positions between said shifting limits from the center of the work-piece, at which the shifting operation of said roll against the work-piece may be retained or may be stopped, and which position of said roll or rolls will be indicated by the said means with said adjustable gage rod or gage rods J^9 , or J^9 , J^9 , one or more for each roll; and, in case it should be so desired that each one of such positions of said roll or rolls, that is the position for starting and for stopping the shifting operation of said roll or rolls against the work-piece should each be indicated, then in such case, another adjustable gage rod or rods similar to J^9 will be attached next to said rod J^9 to each of said guide pieces J^8 , in a similar manner as is rod J^9 attached thereto, as for instance shown in said Figs. 19 and 20; and thereby, two or more gage rods, each similar to rod J^9 , will be provided for each one of said edging and web rolling rolls. For instance, with reference to Fig. 46, in which the operation of the said rolls J^1 , J^2 against the blank or work-piece commenced with the said rolls J^1 , J^2 in the position shown and as before described, the rolls J^1 , J^2 in this case have been set to the position shown by the points of said gages J^9 , J^9 and said mark J^{152} on each of said shafts J , J . Said nuts on said gage rods J^9 , J^9 , &c., can be adjusted to the ends of the thread forward or backward, such as the case may require, thereby, the points of said gage rods J^9 , J^9

&c., can be adjusted to any desired position of said edging and web rolling rolls between their shifting limits.

Said edging and web rolling rolls may be shifted or longitudinally moved also independently of each other; for instance in such a way that, any one of said rolls may be retained in any position between their shifting limits and the other of said rolls, while operating on the work-piece, may be shifted forward and backward, such as the case may require, as for instance illustrated in Figs. 43, 44, 45 and 50. In Fig. 43, one of said rolls, the roll J^3 formed wholly conical, is retained in the position shown, and therein, the work-piece during the rolling process is pressed against said roll J^3 with practically the same pressure with which the other roll J^4 may be pressed or held laterally against the work-piece, and under this pressure, the roll J^3 is operating against the whole side, from the center or hub part to the periphery of the work-piece, as shown; and the other roll J^4 during the rolling process, is also shifted or moved longitudinally by its cylinder J^{77} , as before described, and with its said web reducing part j^{28} operates as before described on the web, hub and inner rim parts, and with its said edging roll part j^{29} operates as before described upon the edge or side of the rim-part of the work-piece F^1 . When the roll J^4 has reached the position, as for instance shown in Fig. 43, then said roll J^3 is shifted or longitudinally moved by its said coöperating pressure cylinder J^{77} and is laterally moved by its other coöperating pressure cylinder (operatively connected therewith to the journal pin J^{104} located in said guide piece J^8) somewhat toward the work-piece, until said roll J^3 has reached the position shown in said Fig. 44, when the dishing and finishing of the finished wheel F^2 shown in said Fig. 44 will commence and be done as and in the manner before described; and, in Fig. 45, the one roll J^6 , which is formed wholly conical, is retained in the position shown and therein the work-piece during the rolling process, is pressed against said roll J^6 with practically the same pressure with which the other roll J^6 may be pressed or held laterally against the work-piece and under this said pressure, the said roll J^6 is operating against the whole side, from the center or hub part to the periphery of the work-piece as shown, and the other roll J^6 during the rolling process is also shifted by its said cylinder J^{77} , as before described, and is operating only with its said web reducing roll part j^{28} against the work-piece as shown; and, the total pressure, during the rolling process against such rolls as J^3 or J^6 , which are retained in such position, as shown in Fig. 43 or 45, is practically the same pressure with which said rolls J^4 or J^6

may be pressed or held laterally against the work-piece, and not more.

From the above it will be seen that, with the herein named edging and web rolling 5 rolls formed as herein shown and, with the inner rolling or operating portions of the web reducing roll parts j^{28} , j^{28} of said edging and web rolling rolls J^1 , J^2 , &c., formed sufficiently conical, as and for the purpose 10 herein fully described with reference to the Figs. 39, 43, 49, 50 and 90, an efficient rolling action is obtained, which during the formation of the web part toward the rim part, causes the metal to flow in the proper 15 directions; that is to say, toward the rim part, within the latter, and peripheral thereto. The lateral flow of the metal is limited by the roll parts j^{29} , j^{29} of the edging and web rolling rolls, and when this 20 lateral flow of the metal is thus arrested, the continued flow thereof will be peripheral to the rim. It will be observed that the radial flow of the metal is limited by the rolling surface of the tread or face rolling roll K, 25 and when the radial flow is thus arrested, the continued flow of the metal will be peripheral to the rim, as for instance partly illustrated in Figs. 39, 49, 50 and 90. From this and from the matter described below 30 with reference to the Figs. 39, 49, 50, 90 and 91, and with reference to other figures herein shown, it is to be observed that the metal, when being rolled from the blank or other work-piece into a wheel or other article, is, 35 especially in the tread and flange or rim portion, not expanded radially and therefore does not produce incipient cracks in the tread and flange portions of the rim, but is truly rolled and increases in density with increased working, thus giving to the metal both its due maximum strength and maximum resistance to wear. In other words, 40 this method of rolling produces the same effect in the metal of the rim portion as if the web portion of the wheel were not in existence and the rim portion rolled its total width on its inner peripheral surface or surfaces as is done on its outer peripheral surface consisting of the tread and flange. 45 In Fig. 49 are shown such edging and web rolling rolls, for instance, J^1 , J^2 rolling or forming the web and rim parts of the work-piece F^1 central with the hub part, as shown and therein with the inner rolling or operating 50 portions of the web reducing roll parts j^{28} , j^{28} of the edging and web rolling rolls J^1 , J^2 formed sufficiently conical as for instance shown and as and for the purpose hereinafter more fully described, the centers 55 of the pressures caused by the so conically formed inner rolling or operating portions of said web reducing roll parts j^{28} , j^{28} of said rolls J^1 , J^2 are illustrated as acting at the centers of the lengths of said conically 60 formed inner rolling or operating portions and at right angles thereto against the work-piece, as is indicated by the arrows p and p^1 of said pressures, and the resultant pressure r from said pressures p and p^1 is there- 65 in indicated in the direction shown by the arrow for said resultant pressure r , and the actual flow of the metal will be in a lateral, radial and peripheral direction, that is, toward the rolls J^1 , J^2 and peripheral to the rim and in a radial and peripheral direction, 70 that is toward the periphery of the work-piece in the direction of the arrow r against the face rolling roll K (which roll K is not shown in said Fig. 49) and from there the metal will flow peripheral to the rim, and 75 said lateral flow of metal is limited by said edging roll parts j^{29} , j^{29} of said rolls J^1 , J^2 from where the metal will flow peripheral to the rim, and the said radial flow of metal is limited by the rolling surface of the said 80 tread or face rolling roll K (which roll K is not shown in said Fig. 49), from where the metal will flow peripheral to the rim; and in Fig. 50 are shown such edging and web rolling rolls for instance J^3 and J^4 , 85 forming the web and rim parts of the partly shown work-piece F^1 which is to have its hub and rim parts formed at one side as shown and as before described with reference to Fig. 43. With the inner rolling or 90 operating portion of the web reducing roll part j^{28} of the edging and web rolling roll J^4 formed sufficiently conical as for instance shown in said Fig. 50 and as and for the purpose hereinafter more fully described, the total pressure p^2 , caused by the so sufficiently 95 conically formed inner rolling or operating portion of said web reducing roll parts j^{28} of said roll J^4 acting the total length of said 100 conically formed inner rolling or operating portion and at right angles thereto against the work-piece, as is indicated by the arrows p^2 for said total pressure, thereby causes or forces the metal to flow against the face of said roll J^3 in the direction indicated by said arrows p^2 , and as the metal in the work-piece cannot flow in said direction beyond the face of said roll J^3 , it will practically flow in a lateral, radial, and in a peripheral direction; that is, in a lateral direction against the roll part j^{29} of said roll J^4 and in a radial direction in the direction of the arrow r^2 against the face rolling roll K (which roll K is not shown in said 110 Fig. 50), from where it will flow peripheral to the rim; that is toward and against the roll J^3 and toward and against the roll part j^{29} of the roll J^4 from where it will flow peripheral to the rim; and said radial flow of metal is limited by the rolling surface of the tread or face rolling roll K (which roll K is not shown in said Fig. 50), and from 115 there the metal will flow peripheral to the rim. 120

Figs. 87 to 91 inclusive are sections of 130

the rim portion of car wheels illustrating diagrammatically the flow of metal caused by various forms of rolls, and therein the pressures caused by the rolls against the surfaces of the metal in contact with the rolls are assumed to be uniformly distributed at said surfaces, as indicated by the arrows pointing against said surfaces and the direction of the flow of metal from 5 said arrows toward the inner region of the rim portion is indicated by the pressure lines of said arrows. The flow of metal illustrated by pressure lines parallel to each other indicate a uniform compression 10 of metal. The flow of metal illustrated by diverging pressure lines indicate that said uniformly distributed pressures at said surfaces in contact with the rolls are becoming less toward the inner region and 15 peripheral face of the rim portion, and therefore the metal in those portions of the rim having diverging lines is not condensed to the same degree as is the metal in the portions having parallel pres- 20 sure lines and which degree of condensing becomes less and less as the distances between said diverging lines become greater; and if the rim is not rolled at its outer peripheral face simultaneously with 25 the rolling of its inner peripheral faces, the metal will be extended instead of being compressed and thereby producing incipient cracks in the tread or outer peripheral face of the rim. The finished peripheral face of 30 the car wheel is indicated by f^{12} and the outline of each of said sections is shown in heavy lines. In the Figs. 87, 88 and 89 the center line of the rim and adjacent web portion is indicated by y , and said inner face 35 or faces of the rim portion in contact with the rolls are indicated by f^{13} . In Fig. 87, the portions of the rim in which the metal is not properly condensed is indicated by the distances d^1 , d^2 occupied by said di- 40 verging lines. In Fig. 88, the portions of the rim in which the metal is not properly condensed is indicated by the distances d^3 , d^4 occupied by said diverging lines. The 45 rolling of the rim portion as and in the manner described with reference to Figs. 50 87 and 88 does not properly work the metal in the rim and therefore forms a rim, which during the rolling process has already been weakened where its strength is needed and 55 of which the tread will wear out quickly and shorten the life of such wheel, all of which may be observed on present wheels in actual use. In Fig. 89 is illustrated a section of a tire having for instance no web, 60 such as used for some tired car wheels. From this figure it can easily be observed that the metal in such objects having a straight inner face without a web as shown, can be rolled to practically uniform density 65 as indicated by the parallel pressure lines

for the total pressure P ; and, the metal in the rim portion of car wheels and similar objects having each a web formed integral with the rim, can be rolled in accordance with my invention to practically uniform 70 and maximum density, as can be done with rims having no web portion.

Therefore and in order to produce said effects or results in the metal of the rim portion of the work-piece or car wheel as 75 hereinbefore described with reference to Figs. 49 and 50, and to entirely avoid the improper working of the metal described with reference to Figs. 87 and 88, I form the inner rolling or operating portion of 80 the web reducing part j^{28} of each of said edging and web rolling rolls for instance J^1 , J^2 , sufficiently conical, so that the face of said conically formed portion is suffi- 85 ciently inclined from its lateral apex toward the inner end of its roll; that is to say, so that when for instance, the web reducing parts j^{28} , j^{28} of said rolls J^1 , J^2 are against the finished web, then said face of said coni- 90 cally formed portion of each of said parts j^{28} , j^{28} is sufficiently inclined from the side of the web outwardly in the direction away from the axis of the work-piece, as for instance in Figs. 39, 43, 49, 50, 58, 65 and 90 95 Said inclination of each of said web reducing parts j^{28} , j^{28} I therefore form suffi- 100 ciently large enough so as to roll the inner peripheral faces of the rim portion suffi- 105 ciently inclined outwardly toward the peripher- 110 al face of the work-piece so that during the rolling or forming of the rim portion for instance to the rudimentary form shown in the Figs. 39, 43, 58, 65 and 90 the metal is caused to flow in the proper direc- 115 tions to assure compression of the metal in 100 said rim portion to uniform or to prac- 120 tically uniform density, as is distinctly shown and diagrammatically illustrated in Fig. 90. In Figs. 90 and 91 is diagrammatically illus- 125 trated and distinctly shown the result of the 110 rolling or forming of the rim of a car wheel in accordance with my invention hereinbefore described with reference to Figs. 39 to 42 and to Figs. 49 and 50, &c. Fig. 90 dis- 130 tinctly shows what is meant by the herein 115 used words "sufficiently conical" or "suffi- 120 ciently inclined" and therein is shown said rim portion rolled for instance to the rudi- 125 mentary form shown in the Figs. 39, 58 and 65, and therein is also shown in dotted 130 lines said rim portion rolled to finished form, and the pressures p , p^1 are the same described with reference to Fig. 49; the pressure lines for each of said pressures p , p^1 being parallel to each other in the di- 135 rections of the arrows and at right angles to said inclined faces of said roll parts j^{28} , j^{28} . The said pressures p , p^1 from said sufficiently inclined faces of said roll parts j^{28} , j^{28} thus applied during the rolling or 140

forming of said inner rim portion have rolled said inner faces f^{18} , f^{19} of the so rudimentarily formed rim portion sufficiently inclined, as distinctly shown by the pressure lines for each of said pressures p , p^1 , which caused the metal during said rolling or forming of the rim portion to flow in the proper directions to be compressed to uniform density, as distinctly illustrated by 5 said parallel pressure lines for each of said pressures p , p^1 , while at the same time the pressures p^5 , p^6 against the lateral sides of the rim from the edging roll parts j^{29} , j^{28} of said rolls J^1 , J^2 have caused the metal to 10 flow into the inner region of the rim in the direction of the arrows of the pressure lines for said pressures p^5 , p^6 and have rolled the rim to desired lateral thickness and while at the same time the pressure p^7 against the 15 peripheral face of the rim portion from the face beaking or face roughing roll K having its rolling face K^7 formed as shown, has caused the metal to flow also into the inner region of the rim in the directions 20 of the arrows of the pressure lines for said pressure p^7 and has rolled said peripheral face to the beaked or rudimentary form K^7 as shown, thereby having rolled said metal in the rim and adjacent web portion simultaneously on all its surfaces by rolls situated 25 in a plane passing laterally through said rim and adjacent web portion and therewith having compressed said metal simultaneously on all its surfaces to uniform and maximum density, or practically so, while 30 at the same time the rim portion has been rolled to said rudimentary form shown for instance in the Figs. 39, 58, 65 and 90. The so rudimentarily formed rim is then rolled, 35 as hereinbefore described, with rolls situated at another point of the rim portion to finished form whereby its metal is still further condensed as and in the manner hereinbefore described for instance with reference to the Figs. 40, 42, 51, 52 and 53, and 40 diagrammatically illustrated in the Fig. 91. In Fig. 91, said so rudimentarily formed rim portion, rolled in accordance with my invention, is shown in dotted lines, and the finished rim and adjacent web portion 45 shown rolled in accordance with my invention during the finishing rolling process to finished form, is shown in heavy lines, and during the finishing rolling process with the 50 rolls G^1 , G^2 and H operating against the rim portion at another point thereof, the web finishing rolls G^1 , G^2 with their web finishing roll parts g^{136} , g^{136} roll said inclined faces f^{18} , f^{19} to the finished forms 55 f^{20} , f^{20} , while the peripheral face finishing roll H rolls said beaked or rudimentarily formed peripheral face K^7 to the finished form f^{12} and while the edging roll parts j^{29} , j^{28} of said rolls J^1 , J^2 (each of which 60 rolls has now been moved somewhat toward the axis of the work-piece as hereinbefore described or as for instance indicated by the distance f^{24} in said Figs. 90 and 91) are still operating in contact with the sides f^{22} , f^{23} of the rim at another point thereof and are 65 limiting the lateral flow of metal and maintaining the lateral thickness in the rim to which the same has been rolled during the rolling described with reference to Fig. 90; the combined action of said rolls J^1 , J^2 , G^1 , G^2 and H during said finishing rolling process roll or form the rim and adjacent web portion to the finished form shown in Fig. 91. Said Figs. 90 and 91 distinctly show and diagrammatically illustrate that the 70 metal in the whole rim portion, rolled in accordance with my invention, is rolled or worked to uniform and maximum density, or practically so, especially in the tread, flange and root of the flange where the 75 strength and resistance to wear is mostly needed. It is, of course, to be understood that in order to produce said results, the rim portion must be rolled first for instance to the rudimentary form as and in the manner described with reference to Fig. 90 before the same is rolled to the finished form shown in the Fig. 91, and that the rolling of the said inclined faces f^{18} , f^{19} and the 80 rolling of said beaked peripheral face K^7 to their finished forms during the finishing rolling process will not disturb the density of the metal to which it has been compressed during the process described with reference to Fig. 90, but will still more compress the 85 metal, especially so in the tread, flange and root of the flange where the strength and resistance to wear is mostly needed, as can 90 easily be seen from said Fig. 91.

From the foregoing it will now be observed that, in rolling for instance car wheels with the edging and web rolling rolls formed as herein shown and as and for the purpose described with reference to Figs. 39, 43, 49, 50, and diagrammatically illustrated in Figs. 90 and 91, and with the lateral thickness or width of said tread or face rolling roll K being the same as the lateral thickness or width which the rim portion of the car wheel is to have when finished, as 95 is for instance shown in the Figs. 39, 43, 56 to 59 and 64 to 66 and diagrammatically illustrated in Fig. 90, thereby, and with said roll K formed as shown and as and for the purpose herein described with reference to Figs. 39, 43, 51, 52, 53 and diagrammatically illustrated in Figs. 90 and 91 and with the rolls J^1 , J^2 in said Figs. 39, 56 to 59, 64 to 66 and in Fig. 90, formed as shown and as and for the purpose above described 100 to Figs. 39, 43, 51, 52, 53 and diagrammatically illustrated in Figs. 90 and 91 and with the rolls J^1 , J^2 in said Figs. 39, 56 to 59, 64 to 66 and in Fig. 90, formed as shown and as and for the purpose above described 105 to the Figs. 39, 49, 50, 90 and 91, or with the rolls J^3 , J^4 in said Fig. 43 formed as shown and as and for the purpose above described, and with all said three rolls for instance J^1 , J^2 and K situated in 110 115 120 125 130

a plane passing laterally through the work-piece at one side of its axis, the metal in the peripheral face and the whole rim portion of the work-piece or car wheel is worked 5 continually, during the rolling or forming of the rim to rudimentary form, upon all its surfaces simultaneously with said three rolls so formed and so situated as before said and as shown for instance in said Figs. 10 39, 43, 56 to 59, 64 to 66 and Fig. 90, and in then rolling the so rudimentarily formed rim to finish form as and for the purpose for instance described with reference to Figs. 49, 50, 90 and 91 and, which to my knowledge, 15 together with the result obtained thereby as for instance above described with reference to the Figs. 39, 43, 49, 50, 51, 52, 53, 20 90 and 91, was never done or accomplished before in rolling car wheels, whereby the metal in said peripheral face and the whole rim portion is uniformly condensed to its maximum, or practically so, thereby giving the metal in said peripheral face and in the whole rim portion its due maximum and 25 uniform strength and its due maximum and uniform resistance to wear; and, as any surplus of metal in the work-piece can be worked during the rolling process for instance into the inner rim and adjacent web 30 portion, the said peripheral face and the whole rim portion of the car wheel can also be rolled, by my rolling process, smooth on all its surfaces to the desired form without leaving a raised circular portion or fin, 35 which would have to be removed afterward by turning or other costly means.

At a suitable distance from the inner ends of said edging and web rolling rolls, the said shafts J, J are supported and guided 40 by adjustable bearings located in the aforesaid guide pieces J⁸, one for each roll, as shown in said Figs. 17 and 18. Each of said guide pieces J⁸, is formed at its lower side with a circular segmentally shaped guide 45 block which is formed concentric with the said vertical shaft J¹⁸, as shown, and which is supported and guided by its circular segmentally shaped guide bearing (not shown herein) and which is also formed 50 concentric with said vertical shaft J¹⁸. Each of said guide pieces J⁸, with the end part of its shaft J supported therein, as shown, is moved forward and backward in a circular path described from the center of said 55 vertical shaft J¹⁸, and thereby, by the other end part of its said shaft J, the aforesaid oscillating frame by its said housings J¹⁰ and J¹¹ which are supporting said other end part of said shaft J, as shown, is also swung 60 forward or backward, such as the case may be, on its trunnions J¹³⁸ and J¹¹ which are central or coaxial with the said vertical shaft J¹⁸; therefore, said edging and web rolling rolls, when moved laterally, as for 65 instance indicated by the dotted line of roll J² in Fig. 18, toward or against or away from the work-piece, each move in a circular path described from the center of said vertical shaft J¹⁸ and the line thus described by said path is practically parallel 70 to the axis of the work-piece during the operating process.

Said edging and web rolling rolls, for instance, J¹ and J², for their lateral movements, are connected together by equalizing 75 mechanism, which is similar to the equalizing mechanism hereinbefore described for the tread or face rolling rolls, in such manner that said rolls may be connected with or be disconnected from said equalizing 80 mechanism, without disconnecting said rolls from the coöperating pressure cylinders operatively connected with said rolls. Said mechanism equalizes the movements and pressures of said edging and web rolling 85 rolls toward or against the work-piece, that is, for instance; with said rolls so connected together, said rolls, for instance, J¹ and J² are moved toward or against or away from the work-piece at both sides thereof, each 90 the same distance, as illustrated more fully for instance, in the Figs. 21, 47, 54, 56 to 59, 62 and 64 to 66. For the rolling process illustrated for instance in Figs. 43 and 44, it is required that each one of the rolls, as 95 for instance J² and J⁴ shown in said Figs. 43 and 44 be moved toward or against or away from the work-piece independently of each other, and in such case, said rolls J² and J⁴ are disconnected from said equalizing 100 mechanism without disconnecting said rolls from the coöperating pressure cylinders operatively connected with said rolls. Said rolls will thereby be permitted to be moved laterally by their pressure cylinders operatively connected with said rolls, toward or against or away from the work-piece independently of each other, and, either one or both rolls may be retained in desired position, as for instance shown in said Figs. 43 110 and 44 and also illustrated in Fig. 45.

Said edging and web rolling rolls, with their said shifting or longitudinally moving device may be moved during the rolling process longitudinally in either direction between their shifting limits and between the center or hub part and the rim-part or periphery of the work-piece, or may be moved during the rolling process forward and backward to their shifting limits as often as may 115 be desired, or may be moved to any position between their shifting limits; or may be retained at any desired position between their shifting limits, or may be operated in such a manner that any one of said edging and web 120 rolling rolls may be retained in any position between the shifting limits, and the other while operating on the work-piece may be shifted to any point or to any distance between the shifting limits forward or backward 125 130

or forward and backward as often as may be desired, such as the case may require, or the distance for shifting forward and backward can be adjusted in both said shifting directions from the shifting limit to any point between said shifting limits, and the operation of said edging and web rolling roll or rolls against the work-piece may be commenced or may be stopped at any one end 5 of said adjusted shifting distance, or at any point between said adjusted shifting distance; and, between said adjustable shifting distance, by means of adjustable indicating device, said edging and web rolling roll or 10 rolls, during their operation against the work-piece, can be set to any desired radius from the center of the work-piece at which their operation against the work-piece should be commenced; or, any desired position 15 of said roll or rolls between said shifting distance, from the center of the work-piece, at which position the shifting operation of said roll or rolls against the work-piece may be retained or may be stopped, 20 will be indicated by means of said adjustable indicating device. Said shifting or longitudinal movements and said lateral movements of each one or of both said edging and web rolling rolls may either be done 25 at the same time or at different times.

The arrangement for driving said web finishing rolls and said edging and web rolling rolls is such that; said web finishing roll may be either connected to or may be disconnected from the main driving shaft 30 of the apparatus or mill, or, may be made to run in either direction; and that, while retaining said main driving shaft at one speed, said edging and web rolling rolls may 35 be made to run at various speeds; and that said edging and web rolling rolls may also be connected to or may be disconnected from said main driving shaft, and also that said edging and web rolling rolls may be run 40 in either direction, such as may be desired, all of which is clearly illustrated and described in my said original application.

A car wheel, or other article, may also be rolled, as for instance described in the following:—The properly heated blank or work-piece F, for instance of the form shown in Fig. 21, having been pierced and centered as before described or the piercing may be done either before or after the hub 50 is formed or may be done during the process of forming or shaping the hub portion, is ready to be rolled and dished, for instance, into a car wheel having the form or shape shown at F² in Fig. 40 or 67. The said 55 web reducing roll parts j²⁸, j²⁸ of both the edging and web rolling rolls J¹, J² may commence operating against both sides of the work-piece F, first forming the hub part in the following manner with the said tread 60 or face finishing roll H against the work- 65 piece F; both the rolls J¹, J² with their said web reducing roll parts j²⁸, j²⁸ commence operating against each side of the work-piece F and on the point f⁶ thereon (see Fig. 21), and from there are operating against 70 the work-piece at each side thereof in the direction of the dotted line f⁶—f⁶, and thereon are moving at each side of the work-piece from f⁶ to f⁶ until the said rolls J¹, J² are in the positions indicated by the dotted 75 lines, and during the time that said rolls J¹, J² move with their said web reducing roll parts at each side of the work-piece from f⁶ to f⁶, the said web reducing roll part j²⁸ of each roll, with its side which is next to the 80 hub, is operating against the work-piece and force the metal therein to flow toward the hub and laterally against the shoulders or flanges e⁸⁰, e⁸⁰ of the piercers or work-supporting centers E⁶, E⁶ and to flow radially 85 against said rolls J¹, J² and, thus form the hub part as shown by the dotted lines, and with their other sides which are toward the periphery of the work-piece, both said web reducing roll parts j²⁸, j²⁸ of both rolls J¹, 90 J² are not pressing against the work-piece F in this described process or manner of operation, and therefore, all the metal which during said operation is removed from 95 around the hub part and which is sectionally indicated by the dotted lines at both sides of the work-piece for part of said web reducing roll parts j²⁸, j²⁸, is practically wholly used in forming said hub; and with the shoulders of flanges e⁸⁰, e⁸⁰ of said 100 piercers or work-supporting centers E⁶, E⁶ limiting the lateral flow of said metal in the hub part during the operation of forming the hub part and with the end parts of said rolls J¹, J² limiting the radial flow of 105 said metal and coming against the peripheral faces of said shoulders or flanges e⁸⁰, e⁸⁰, the ends of the hub part may be formed flat and to the desired gage for the length of the hub, and the hub rolled or formed 110 smooth on all its surfaces as illustrated, for instance, in the Figs. 21, 46, 48, 54, 55, 56, 62, 63 and 64, all without leaving a raised circular portion or fin which would have 115 to be removed afterward by turning or other costly means. Then when the hub part is so finished, the said edging and web rolling rolls J¹, J² are moved as and by the means hereinbefore described, from the hub part toward the rim-part, or are moved forward and backward as often as desired, and thus make the metal flow in the proper direction and, rolling or forming the web part to its desired thickness and when said rolls J¹, J² are in the positions shown for 120 instance in the Fig. 39 the inner face or faces of the rim portion have been rolled or formed to said rudimentary form, as and for the purpose hereinbefore described with 125 reference to the Figs. 49, 50, 90 and 91, and 130

during this operation any lateral flow of the metal is limited by said edging roll parts j^{29} , j^{30} , and also during this operation, the tread or face rolling roll K with its 5 rolling surface K^2 having the shape as shown in said Fig. 39, or as K^7 in Fig. 65 is limiting the radial flow of metal and is operating against the peripheral face of the work-piece to beak the same, as and for the 10 purpose herein described for instance with reference to the Figs. 51, 52, 53, 90 and 91, and in conjunction with said rolls J^1 , J^2 roll the peripheral face of said work-piece to the beaked shape shown at F^1 for instance in 15 said Fig. 39, 65 or 90; and, then with the said rolls J^1 , J^2 still operating with their roll parts j^{29} , j^{30} in contact with the work-piece in the positions shown for instance in Fig. 39, 65 or 90, or with said rolls moved 20 somewhat toward the axis of the work-piece as before described or as for instance indicated by the distances f^{11} , f^{24} in Figs. 90 and 91 and with the said roll K in the same position shown in Fig. 39, 65 or 90, or said 25 roll K may be pulled back somewhat, the herein named web finishing rolls G^1 , G^2 and tread or face finishing roll II commence operation against the work-piece F^1 and the dishing process may be commenced at the 30 same time as and in the manner before described and roll and dish the work-piece to the form or shape of the dished car wheel at F^2 shown for instance in the Fig. 40 or 66; and, when so completely rolled and 35 dished, the said rolls J^1 , J^2 and G^1 , G^2 and II may still continue to operate in contact with or against the wheel as desired, whereby the wheel is made perfectly true and to 40 balance and to gauge or gages and its tread and flange surfaces made harder and smoother and more durable and, any surplus of metal may be forced to flow toward the dished rim and adjacent web portions into the space f^{12} in Fig. 66, whereby the 45 rim portion is rolled smooth on all its surfaces without leaving a raised circular portion or fin which would have to be removed afterward by turning or other costly means; then, all the rolls and piercers or work- 50 supporting centers are pulled back, whereby said work-supporting centers are entirely removed from the so finished car wheel as and by the means before described, and the wheel removed and replaced with a new 55 properly heated blank or work-piece, and then the above described operation repeated, all as and by the means before described.

In rolling for instance the peripheral face of car wheels or similar articles first to a 60 beaked or rudimentary shape simultaneously with the rolling or forming the rim portion to the rudimentary form shown for instance in Figs. 39 and 90 and as and for the purpose hereinbefore described with refer- 65 ence to the Figs. 39, 49, 50, 90 and 91, and

then to the finished form; the tread or face rolling roll K with its peripheral face formed for instance as shown in Fig. 39, 43, 64 or 90, &c., or a similar face, serves to beak the peripheral face of the car wheel 70 before rolling the same to finished form, that is, to roll the peripheral face of the car wheel to beaked or rudimentary shape, for instance, to such form as shown at K^2 , K^6 or K^7 &c., in the Figs. 51, 52 or 53, &c., 75 such preliminary action being herein termed "beaking." During such beaking and rolling or forming process the metal in the whole rim portion of the work-piece or wheel is worked continually and simultaneously upon all its surfaces which gives the metal forming the tread, flange, and the whole rim portion of the wheel the required uniform strength and density absolutely necessary for maximum and uniform resist- 80 ance to wear. After this beaking action is completed, the finishing roll or rolls are brought into action and roll out of said beaked or rudimentary formed peripheral face the finished form of the tread and flange 85 of the wheel and roll the same to its desired finished diameter as, for instance, shown by the dotted lines f^{12} for said finished peripheral face in Figs. 51, 52 and 53, and diagrammatically illustrated in the 90 Figs. 90 and 91, whereby the metal in the tread and flange and the whole rim portion is still further condensed, and any surplus of metal in the rim portion is forced into the inner rim and adjacent web portion 95 100 into the spaces f^{15} , f^{16} in Fig. 66. The wheel thus rolled or formed in accordance with my invention has its metal uniformly condensed to its maximum where it is subjected to greatest strain and wear, and at 105 the point heretofore considered the weakest, and is rolled smooth on all its surfaces without leaving a raised circular portion or fin anywhere on the so finished wheel.

Said blank or work-piece, when put into 110 the apparatus or mill to be rolled or formed according to my invention, may have a proper volume or weight, which on account of scale will be somewhat more than the volume or weight in the completely finished 115 rolled wheel or other article finished according to my invention, but for like wheels or like articles, the ingot, bloom, blank or other work-piece will each have practically the same volume or weight; and, in forming or finishing the hub part from the central or hub part of an ingot, bloom, blank or other work-piece having a thickness which for instance is less than the length of the hub of the finished wheel or other 120 article is to be, the location of said point f^8 in Fig. 21 from the center of the blank or work-piece, may be determined from the thickness of the said central or hub part of such blank or work-piece and from the de- 125 130

sired amount of metal in the hub part, or as practice may require, for instance;—for blanks or work-pieces of such description, the distance from the center of the blank 5 or work-piece to said point f^5 may be greater and the operation for forming the hub part in such case, may be done as hereinbefore described and shown for instance in Fig. 46; or, the thickness of the blank or work- 10 piece necessary for so forming or finishing the hub part may be determined from the desired amount of metal in the hub part, and during the rolling process, the diameter of the blank or work-piece, may either be 15 increased, decreased, or may remain about the same, for instance;—if a blank or work-piece F , such as shown, for instance, in Figs. 21, 47, 54, 55, 62 or 63, is of a thickness and diameter necessary to make up the 20 proper volume or weight in the finished article, but its diameter is less than the diameter of the finished wheel or other article is to be, then in such case, the said diameter of such blank or work-piece will be 25 increased during the rolling process; or for instance,—if a blank or work-piece is of a thickness and diameter necessary to make up the proper volume or weight in the finished article, but its diameter is greater 30 than the diameter of the finished wheel or other article is to be, then in that case, said diameter of said blank or work-piece will be decreased during the rolling process; or for instance, if a blank or work-piece is of 35 the thickness and diameter necessary to make up the proper volume or weight in the finished article, but its diameter is the same or approximately the same as the diameter of the finished wheel or other article is to 40 be, then in that case, the said diameter of the blank or work-piece will remain about the same during the rolling process.

In rolling, for instance, the peripheral face of a car wheel, blank or work-piece with the 45 herein named tread or face rolling roll K , having a rolling face, for instance as K^2 , the said roll K and the said tread or face finishing roll H may be moved toward or against or away from the work-piece or 50 wheel, independently of each other, as hereinbefore described; and in rolling, for instance, said peripheral face with said tread or face rolling roll K having a rolling face for instance as K^1 in Figs. 1 to 9 inclusive 55 and Fig. 25, or for instance as K^7 in Figs. 44, 57, 59 or 66, the said rolls K and H may be moved toward or against or away from the work-piece, either together or independently of each other.

60 When rolling for instance the peripheral face of a car wheel or work-piece with the herein named tread or face rolling roll K , having its rolling face for instance as shown at K^2 in Fig. 39 or K^7 in Fig. 43, 58, 65 or 66, simultaneously with the rolling with said

edging and web rolling rolls J^1 , J^2 , &c., as and in the manner hereinbefore described, the work-piece is first rolled to the form or shape shown by F^1 , wherein the inner peripheral face or faces of its rim have been 70 rolled to rudimentary form, as and for the purpose hereinbefore described with reference to the Figs. 49, 50, 90 and 91, and its outer peripheral face rolled to beaked or to partly conical form, as and for the purpose 75 hereinbefore described with reference to the Figs. 51, 52, 53, 90 and 91; and then rolling said inner peripheral faces of the rim with adjacent web portion and said beaked peripheral face of the work-piece or wheel to 80 finished forms with the herein named web finishing rolls for instance G^1 , G^2 or G^3 , G^4 and tread or face finishing roll H , as for instance shown in the Figs. 40, 42, 44, 57, 59, 66 or 91, thereby the metal in the 85 flange, tread and the whole rim, where the strength of the wheel is most needed, will be worked to practically uniform and maximum density, thereby giving to these parts by so rolling them the greatest possible 90 strength and most efficient wearing surface, which result heretofore has not been accomplished to my knowledge by any other known process for rolling car wheels.

In Fig. 26, for instance, a wheel center F^2 , 95 such as used for instance in tired car wheels, is shown rolled and dished according to my method to the form or shape shown in a similar manner as before described; therein is illustrated also the herein named tread or 100 face rolling roll K having the rolling face K^3 as shown and, the herein named tread or face finishing roll H having the rolling face H^2 as shown. In this case, all the rolls, that is the rolls in each set, may be moved either 105 together or independently of each other.

In Fig. 41 is shown, for instance, a previously finished or worn car wheel supported by said piercers or work-supporting centers E^2 , E^2 as before described, and thereon, the 110 said previously finished or worn wheel, of which the tread, flange, rim and web parts are indicated by the dotted lines, is shown rolled for instance larger in diameter to the size and form or shape of the finished re- 115 rolled or reworked wheel indicated by F^2 . The center portion e^{2a} (see Fig. 38) of each of said piercers or work-supporting centers E^2 , E^2 is in this case for instance being forced into the bore of the hub of said car 120 wheel to make said bore larger, while at the same time said annular flange e^{2b} (see Fig. 38) of each of said piercers or work-supporting centers is put over the outer peripheral portion or diameter of said hub, as shown in 125 said Fig. 41. Such previously finished or worn wheel, if desired, may also be rerolled or reworked to a smaller diameter, or be rolled true to its original diameter or to any larger diameter, such larger diameter of 130

course being limited by the metal in such previously finished or worn wheel. In the Figs. 42, 57, 59 or 60 is shown for instance, an undished wheel F^2 rolled to the form or 5 shape F^2 in a similar manner as before described, but without the dishing, as shown.

In the Figs. 43 and 44, is shown for instance a work-piece or wheel having its web part formed wholly at one side thereof; in 10 Fig. 43 is shown the first rolling of the ingot, bloom, wheel blank or other work-piece to the form or shape, indicated by F^1 , and therein, the one edging and web rolling roll J^3 formed wholly conical as shown, is moved 15 to the position shown and therein retained, while the other roll J^4 , as before described, is forming or is finishing the hub part and the web part and together with the tread or 20 face rolling roll K having for instance the rolling face K' is rolling the work-piece to the form or shape indicated by F^1 wherein the inner peripheral face of its rim has been rolled to rudimentary form, as and for the purpose hereinbefore described with reference to the Figs. 49, 50 and 90, and its outer peripheral face rolled to beaked or 25 rudimentary form, as and for the purpose hereinbefore described with reference to the Figs. 51, 52, 53, 90 and 91. The roll J^3 is 30 then moved to the position shown in Fig. 44, and the web finishing roll G^3 formed as shown is moved toward the work-piece F^1 into position against the side of the tread or face finishing roll H , as shown, and said roll 35 G^3 is retained in this position during its operation against the work-piece while the other web finishing roll G^4 formed as shown is moved as before described toward and against the work-piece F^1 and operating 40 against the inner rim and adjacent web parts and at the same time with the tread or face finishing roll H , and with the edging and web rolling rolls J^3 , J^4 in the position shown in Fig. 44, the wheel is rolled and is dished, 45 as and in the manner before described, to the finished form or shape F^2 shown in said Fig. 44.

In Fig. 45 is shown, for instance, a work-piece or article formed with a hole, as shown, 50 by means of which it is supported on the piercers or work-supporting centers E^6 , E^6 , as shown, which centers are, for instance, formed with the hereinbefore described flanges or shoulders e^{30} , e^{30} for limiting the 55 lateral flow of the metal in the hub part during the operation in forming or finishing said hub part. Said work-piece during the rolling process is reformed or is rolled into a pipe flange or into any other article having the shape F^2 , or similar shape, as shown in said figure and therein, the one edging and web rolling roll J^5 and the one web 60 finishing roll G^6 , both formed wholly conical as shown, are moved to the positions shown

and therein retained while the other edging 65 and web rolling roll J^6 , formed as shown, is as before described finishing the hub part and then only the web or flange part as shown, and the other web finishing roll G^6 , also formed wholly conical, is moved as before described toward and against the work-piece and operating against its side, as shown, and at the same time with the rolling surface H^6 of the tread or face finishing roll H , the said pipe flange or other like 70 shaped article is rolled to the finished form or shape F^2 shown in Fig. 45. During the process of forming the hub, both said rolls J^5 and J^6 are in contact with the peripheral 75 faces of the flanges e^{30} , e^{30} of said work- 80 supporting centers E^6 , E^6 as shown and, thereby prevent the formation of any undesired circular portion or fin which would have to be removed afterward by turning or other costly means and, when during the 85 rolling process, said roll J^6 approaches the position shown in said Fig. 45, then the said tread or face rolling roll K is pulled back into the position shown and therein is not operating against the work-piece, but may 90 be used if so desired, as a stop to limit the lateral movement of the roll J^6 against the work-piece, as hereinbefore described. The pressure caused by the roll part j^{22} of said roll J^6 during its operation against the work- 95 piece from the hub toward the periphery of the work-piece, is resisted by the peripheral face of the flange e^{30} of the one center E^6 being against or in contact with the end-part of said roll J^6 as shown. 100

In the Figs. 47 and 48, I have for instance, illustrated in brief, piercing and rolling process or steps according to my invention such as I prefer to employ for piercing or centering and for rolling or forming the center 105 or hub portion of a car wheel or other circular body as hereinbefore described with reference to Figs. 21, 29, 36, 39 or 46 and also described in my aforesaid original application. In Fig. 47 a work-piece F is shown 110 having a thickness which is the same or is somewhat greater than the length which the hub of the wheel or other body is to have when finished. The work-piece F has been brought into the position shown by the 115 aforesaid raising, lowering and retaining device and in which position the outer portion or periphery of the work-piece is coaxial, or approximately so, with the piercers or work-supporting centers E^6 , E^6 and is being pierced or centered with said piercers or work-supporting centers E^6 , E^6 and, operated on with the rolls J^1 , J^2 which, while rotating the work-piece, are forced or rolled against and into the opposite 120 sides of the work-piece for rolling or forming the hub and, during this process of forming the hub, the ends of said rolls J^1 , J^2 are 125

either in contact with the peripheral faces of the flanges e^{30} , e^{30} of said centers E^6 , E^6 , as for instance shown in Figs. 47 and 48, or come against said flanges e^{30} , e^{30} during the hub forming process as hereinbefore described with reference to Figs. 21, 39 or 46 and also described in my aforesaid original application, and thus the hub is finished to the form shown for instance in Fig. 48 including the piercing or centering of the work-piece and the hub formed smooth on all its surfaces and to desired form or shape without leaving a raised circular portion or fin which would have to be removed afterward by turning or other costly means. In Fig. 48, the work-piece F shown in Fig. 47, is shown pierced by said piercers or centers E^6 , E^6 and rolled with said rolls J^1 , J^2 to the form F^1 as shown while the work-piece is supported by both said work-supporting centers E^6 , E^6 , as shown. Said piercing or centering may be done either before or during the process of rolling the hub portion; and said raising, lowering and retaining device, as before described is moved away from the work-piece either after or during the piercing or centering process.

In the Figs. 54 and 61 inclusive, I have for instance, illustrated in brief, rolling or forming process or steps according to my invention, such as I prefer to employ for completely rolling the undished car wheel as hereinbefore described and also described in my aforesaid original application and shown at F^2 in Fig. 42, or a car wheel similar thereto, including the piercing or centering of the properly heated work-piece. In Fig. 54, the properly heated blank or work-piece F has a thickness which is the same or is somewhat greater than the length which the hub of the car wheel is to have when finished, and in Fig. 55, the properly heated blank or work-piece F has a thickness which is, for instance, the same or is somewhat greater than the lateral thickness or width which the marginal or rim portion of the car wheel is to have when finished. Fig. 54 shows said work-piece F brought into position by said raising, lowering and retaining device so that the outer portion or periphery of the same is coaxial, or approximately so, with the piercers or work-supporting centers E^6 , E^6 , which piercers or centers in this case are made of unequal lengths to suit the location which the web portion of the wheel is to have with reference to the ends of the hub; that is, the web portion of the car wheel in this case will not be formed in the center of the length of the hub and said centers E^6 , E^6 will have different lengths which may reach to the center of the thickness of the finished web next the hub portion of the wheel as shown. During the process of piercing and of rolling a car wheel of this type the centers

E^6 , E^6 are moved against the opposite sides 65 of the work-piece and together with the work-piece are moved into the position shown in Fig. 54. In this position the piercing or centering and the rolling or forming of the work-piece, including the rolling or 70 forming of its center or hub portion, to the form of the work-piece shown at F in dotted lines, will begin and be performed in the following manner:—During the piercing or centering process, the short piercer or center E^6 is moved axially from its position shown in solid lines into the position thereof shown in dotted lines, in which position the axial movement of said short piercer or center E^6 is automatically stopped and is rotatably 75 retained in said position during the rolling or operating process illustrated in Fig. 54, and during said piercing or centering process said short piercer or center E^6 is also forced axially into one side of the work-piece 80 until its flange or shoulder e^{30} is against said side, as shown by said dotted lines. The other or long piercer or center E^6 is forced axially into the work-piece during said piercing or centering process, it 85 being moved from its position shown in solid lines to the position thereof shown by the dotted lines, and in this latter position the shoulder or flange e^{30} of said long piercer or center E^6 is against the other side of the 90 work-piece as shown by said dotted lines, and thus the work-piece is rotatably supported at its center or hub portion by both said piercers or centers E^6 , E^6 , and while so supported the work-piece may also be automatically and firmly clamped between said piercers or centers E^6 , E^6 as and for the purpose hereinbefore described and be so retained in said clamped condition during the 95 entire rolling or operating process until the 100 finished rolled wheel is ready to be removed. The oppositely-arranged rolls J^1 and J^2 shown at one side of the axis of the work-piece are both simultaneously moved laterally equal distances from their positions 105 shown in solid lines to the positions thereof shown in dotted lines, thereby rolling the work-piece to the form shown thereof in the dotted lines, and in these latter positions the outer ends of said rolls J^1 , J^2 are still in 110 contact with or against the peripheral faces of the shoulders or flanges e^{30} , e^{30} of said centers E^6 , E^6 , and, the edging roll portions j^{28} , j^{28} of said rolls J^1 , J^2 are then in contact 115 or against the opposite sides of the face roll K, as shown, and are limiting the lateral flow of metal in the work-piece between the roll parts j^{28} , j^{28} of said rolls J^1 , J^2 and the periphery of the work-piece during the further rolling or operating process against the 120 work-piece. During the first part of these lateral movements of said rolls J^1 , J^2 , the roll J^1 only, is operating upon one side of 125

the work-piece at one side of its axis as shown until the other roll J^2 comes against the other side of the work-piece when both rolls J^1, J^2 will operate against both sides of 5 the work-piece and roll the same to the form shown in said dotted lines, while simultaneously during this operating process of said rolls J^1, J^2 the face beaking or face roughing roll K may begin to act or be acting against 10 the peripheral face of the work-piece as shown and the rolls G^1 and G^2 at the other side of the axis of the work-piece are both simultaneously moved laterally equal distances from their positions shown in solid 15 lines to the positions thereof shown in dotted lines and, during these lateral movements of said rolls G^1, G^2 , the roll G^1 only is operating upon one side of the work-piece, as shown, until said rolls G^1 and G^2 reach the 20 positions shown thereof in dotted lines and thus, the pressures applied against one side of the work-piece at each side of its axis, caused by said rolls J^1 and G^1 operating and 25 pressing simultaneously against the work-piece during their lateral movements, is equalized, and the pressures of said rolls J^1, G^1 against said one side of the work-piece is resisted by said short piercer or center 30 E^6 , which, as before said, is retained in the position shown thereof in the dotted lines, and in which position said short piercer or center E^6 centrally supports the work-piece at its other side against the lateral pressures exerted by said rolls J^1, G^1 against said one 35 side of the work-piece as indicated in Fig. 54; and thus the work-piece F is rolled, including the piercing and the rolling or forming of its hub portion, from the form in Fig. 54 shown in solid lines to the form in 40 said figure shown in dotted lines. It is to be understood that the piercing or centering of the work-piece may be done either before or during the rolling process above described and illustrated in Fig. 54; and that said raising, lowering and retaining device, as before 45 described, may be moved away from the work-piece either after or during the piercing or centering process. Fig. 56 shows said work-piece F so pierced or centered and 50 rotatably supported and so rolled to the form shown, in which the hub is completely formed. In Fig. 56 both rolls J^1, J^2 are in contact with or against the peripheral faces of the shoulders or flanges e^{30}, e^{30} of said 55 piercers or centers E^6, E^6 ; and with the rolls J^1, J^2 thus positioned, the web portion of said work-piece F may be reduced or rolled to its desired thickness in either of the following manner forming part of said rolling or forming process or steps; for instance, 60 said rolls J^1, J^2 may either be moved longitudinally during the rolling or forming process from their positions adjacent the hub portion, as shown in Fig. 56, to the positions adjacent the rim portion, shown in

Fig. 58 and, during said longitudinal movements of said rolls J^1, J^2 , the web reducing roll portions j^{28}, j^{28} thereof are rolling or reducing the web portion of the work-piece to its desired thickness and rolling the inner 70 peripheral faces of the rim of the work-piece to the rudimentary form shown and, as and for the purpose hereinbefore described with reference to Figs. 49, 50, 90 and 91, and, the edging roll portions j^{29}, j^{29} of said rolls J^1, J^2 are in contact with or against the opposite sides of the face rolling roll K and are rolling or limiting the lateral flow of metal in the work-piece between said face roll K and the web reducing roll portions j^{28}, j^{28} of 80 said rolls J^1, J^2 , while simultaneously with the longitudinal movements of said rolls J^1, J^2 , said face rolling roll K is also operating against the peripheral face of the work-piece and rolls the same to the beaked or 85 rudimentary form as for instance shown in Fig. 58 and, as and for the purpose hereinbefore described with reference to the Figs. 51, 52, 53, 90 and 91; or, instead of said longitudinal movement of said rolls J^1, J^2 from 90 their positions adjacent the hub portion to the positions adjacent the rim portion, said rolls J^1, J^2 may be moved longitudinally forward and backward as often as desired while simultaneously with said longitudinal movements of said rolls J^1, J^2 , said face roll K is 95 against or is operating against the peripheral face of the work-piece and rolls the same to the said beaked or rudimentary form as shown in Fig. 58; then while the roll 100 parts j^{29}, j^{29} of said rolls J^1, J^2 are still operating in contact with the lateral sides of the rim portion both said finishing rolls G^1, G^2 shown at the other side of the axis of the work-piece, are then moved laterally and 105 simultaneously from their positions shown in Fig. 58 to the positions thereof shown in Fig. 59 and, during their said lateral movements, said rolls G^1, G^2 are rolling the so 110 rudimentarily rolled inner peripheral faces of the rim of the work-piece to the finished form, while simultaneously with the operations of said rolls G^1, G^2 against the work-piece the face finishing roll H begins operating against the so beaked or rudimentarily 115 formed peripheral face of the work-piece and rolls the same to the finished form shown at F^2 in Fig. 59 while the edging roll parts j^{29}, j^{29} of said rolls J^1, J^2 are maintaining the lateral thickness of the rim to which 120 the same has been rolled during the process; thus finishing the wheel to the form F^2 shown in Figs. 59 or 60. Or, if desired, said rolls J^1, J^2 may, for instance, be retained in their positions adjacent the hub portion of 125 the work-piece F shown in Fig. 56 and the web, the inner faces of the rim and the so beaked or rudimentarily formed peripheral face of said rim portion of the work-piece may be rolled with the rolls G^1, G^2 and H , 130

by moving the rolls G^1 , G^2 simultaneously laterally from their positions shown in Fig. 56 to the positions thereof shown in Fig. 57 and, during said lateral movements said 5 rolls G^1 , G^2 are reducing or rolling the unfinished web of the work-piece to its desired thickness and the inner faces of the rim of the work-piece to the finished form shown, while simultaneously with the operation of 10 said rolls G^1 , G^2 against the work-piece, said face finishing roll H may be in contact with or begin operating against the so beaked or rudimentarily formed peripheral face of the work-piece and roll the same to the finished 15 form shown at F^2 in Fig. 57 while the edging roll parts j^{29} , j^{29} of said rolls J^1 , J^2 are maintaining the lateral thickness of the rim to which the same has been rolled during the process, thus finishing the wheel to the 20 form F^2 shown in Fig. 57 or 60 and, in this form the wheel is rolled perfectly true and smooth, to balance, and to gage or gages. Any surplus of metal in the work-piece or car wheel may be forced, during the rolling 25 process, to flow either into the inner rim and adjacent web portion, that is to say, into the spaces indicated by f^{15} , f^{15} in Fig. 59, or it may be forced into an other portion or portions of the work-piece, wheel or other object, without leaving a raised circular portion or fin anywhere on the finished rolled wheel.

In Fig. 55, the long piercer or center E^a is moved or forced the proper distance or 30 depth into one side of the blank or work-piece during said piercing or centering process, as indicated by the dotted lines for said long piercer or center E^a and in this position the shoulder or flange e^{30} of said long piercer 35 or center is spaced from said side of the blank or work-piece the proper distance, or somewhat more than the proper distance required to make up the length which the hub of the car wheel is to have when finished, as 40 and in the manner before described with reference to Figs. 22, 23 and 24 or in any other manner producing the same result. The rolling or forming of the hub of the car 45 wheel may also be effected in a manner similar to that before described with reference to Figs. 21, 46 or 47 and 48. When the wheel is so completely rolled as described or 50 rolled by any of the steps or combination or succession of steps described, then all the 55 rolls may be pulled back to the positions shown for instance in Fig. 3 and, said raising, lowering and retaining device is then again raised until it is in contact with the so finished wheel, after which said piercers 60 or centers E^a , E^b are pulled back into the positions shown for instance in Fig. 3, thereby placing said finished wheel onto said raising, lowering and retaining device and therewith removing the same from the apparatus or mill, &c., as and in the manner hereinbefore described.

By such piercing or centering and rolling or forming process or steps according to my invention, as for instance above described and illustrated in Figs. 54 to 61 inclusive, 70 for completely rolling car wheels or other circular bodies, including said piercing or centering of the work-piece, with my said preferred apparatus or mill or with any other mill producing the same result, the 75 blank or work-piece F , shown in solid lines in either of the Figs. 54 or 55, is pierced or centered and is completely rolled with one heat in the same apparatus or mill to the completely rolled or finished car wheel F^2 80 shown in the Figs. 60 and 61, of which figures, Fig. 61 shows in plan view the so finished rolled wheel F^2 and, Fig. 60 is a diametral section thereof taken on dotted line 60—60 Fig. 61, looking in direction of the 85 arrows.

In the Figs. 62 to 68 inclusive, I have for instance, illustrated in brief, rolling or forming process or steps according to my invention, such as I prefer to employ for completely rolling or forming and dishing the dished car wheel as hereinbefore described and also described in my aforesaid original application and shown, for instance, at F^2 in Fig. 40, or a dished car wheel similar 90 to including the piercing or centering of the properly heated work-piece. In Fig. 62, the properly heated blank or work-piece F has a thickness which is the same or is somewhat greater than the length which the hub 100 of the car wheel is to have when finished and, in Fig. 63, the properly heated blank or work-piece F has a thickness which is, for instance, the same or is somewhat greater than the lateral thickness or width which the marginal or rim portion of the car wheel 105 is to have when finished. Fig. 62 shows said work-piece F brought into position by said raising, lowering and retaining device so that the outer portion or periphery of the 110 same is coaxial, or approximately coaxial, with the piercers or work-supporting centers E^a , E^b . In this case the piercers or centers have their lengths to suit the location of the web portion of the wheel as shown; that is, the web portion of the car wheel in this case will be formed in the center of the length of the hub of the car wheel and said centers E^a , E^b will both have the same length, which 115 may reach to the center of the thickness of the finished web adjacent the hub portion of the wheel as shown. In this position of the work-piece, said piercers or centers E^a , E^b are moved against the opposite sides of the work-piece and the piercing or centering and the rolling or forming the work-piece, including the rolling or forming of its hub portion, to the form of the work-piece shown 120 125

at F in dotted lines, will begin and be performed in the following manner:—During the piercing or centering process one work-supporting center E^o is moved axially from 5 its position shown in solid lines into the position thereof shown by the dotted lines, in which latter position the axial movement of said one piercer or center E^o is automatically stopped and is rotatably retained in said 10 position during the rolling or operating process illustrated in Fig. 62, and during said piercing or centering process this one piercer or center E^o is also forced axially into one side of the work-piece until its 15 shoulder or flange e³⁰ is against this one side, as shown thereof by the dotted lines, and during said piercing or centering process the other piercer or center E^o is also forced axially into the other side of the 20 work-piece from its position shown in solid lines to the position thereof shown by the dotted lines wherein the shoulder or flange e³⁰ of said other piercer or center E^o is against the other side of the work-piece as 25 shown by the dotted lines, and thus the work-piece is rotatably supported at its center or hub portion by both said piercers or centers E^o, E^o, and while so supported the work-piece may also be automatically and 30 firmly clamped between said piercers or centers E^o, E^o as and for the purpose hereinbefore described and be so retained in said clamped condition during the entire rolling or operating and dishing processes until the 35 work-piece is rolled and dished to finished form and ready to be removed. The oppositely-arranged rolls J¹ and J² shown at one side of the axle of the work-piece are both simultaneously moved equal distances during 40 the hub forming process and are so moved either from their positions shown in solid lines to the positions thereof shown by the dotted lines, or are moved during the hub forming process as hereinbefore described with reference for instance to Figs. 45 21, 39 or 46 and also described in my aforesaid original application while the face beaking or face roughing roll K may begin to act against the peripheral face of the work-piece as shown, thereby rolling the work-piece for instance to the form shown thereof in the dotted lines, and in these latter positions said rolls J¹, J² are in contact with the peripheral faces of the shoulders or flanges 50 e³⁰, e³⁰ of said piercers or centers E^o, E^o, and, the edging roll portions j²⁹, j²⁹ of said rolls J¹, J² are then in contact with or against the opposite sides of the face roll K, as shown, and are limiting the lateral flow of metal in 55 the work-piece between the roll parts j²⁹, j²⁹ of said rolls J¹, J² and the periphery of the work-piece during the further rolling or operating process against the work-piece and thus the work-piece F is rolled, including 60 65 the piercing and the rolling or forming of

its hub portion, from the form in Fig. 62 shown in solid lines to the form in said figure shown in dotted lines. It is to be understood that said piercing or centering of the work-piece may be done either before or during the rolling process above described and illustrated with Fig. 62, and that said raising, lowering and retaining device, as before described, may be moved away from the work-piece either after or during the piercing or centering process. Fig. 64 shows said work-piece F so pierced or centered and rotatably supported and so rolled to the form shown with its hub completely formed and with both said rolls J¹, J² in contact with or against the peripheral faces of the shoulders or flanges e³⁰, e³⁰ of said piercers or centers E^o, E^o; and with the rolls J¹, J² thus positioned, the web portion of the work-piece may be reduced or rolled to its desired thickness in the following manner, forming part of said rolling or forming process or steps;—said rolls J¹, J² may be moved during the rolling or forming process longitudinally from their positions adjacent the hub portion, shown in Fig. 64, to the positions adjacent the rim portion shown in Fig. 65, and during said longitudinal movements of said rolls J¹, J², the web reducing roll portions j²⁹, j²⁹ of said rolls J¹, J² are also rolling or reducing the thickness of the web portion of the work-piece to its desired thickness and rolling the inner peripheral faces of the rim of the work-piece to the rudimentary form shown and as and for the purpose hereinbefore described with reference to the Figs. 49, 50, 90 and 91 and, while simultaneously with said longitudinal movements of said rolls J¹, J² said face roll K is operating against the peripheral face of the work-piece and rolls the same to the beaked or rudimentary form, as for instance shown in Fig. 65 and as and for the purpose hereinbefore described with reference to the Figs. 51, 52, 53, 90 and 91; or said rolls J¹, J² when rolling said web portion to its desired thickness, may be moved longitudinally forward and backward as often as desired while simultaneously with said longitudinal movements of said rolls J¹, J², said face roll K is 105 against or is operating against the peripheral face of the work-piece and rolls the same to the said beaked or rudimentary form as shown for instance in Fig. 65 or 90; then while the roll parts j²⁹, j²⁹ of said rolls J¹, J² are still operating in contact with the lateral sides of the rim portion said finishing rolls G¹, G² and H shown at the other side of the axis of the work-piece begin operating against the so rudimentarily formed rim portion and roll with said rolls G¹, G² the so rudimentarily rolled inner peripheral faces of the rim of the work-piece to the finished form and roll with said roll H the so beaked or rudimentarily formed peripheral face of 110 115 120 125 130

the work-piece to the finished form shown at F² in Fig. 66, while the edging roll parts J¹, J² of said rolls G¹, G² and H against the work-piece the dishing may be done and dish the work-piece or wheel while the same is rotating to the form F² shown in Fig. 66; which dishing may be done in the same manner as before described, for instance with reference to Figs. 1 to 3, or in a manner similar thereto, or in any manner producing the same result. By such rolling or forming process in accordance with my invention, as for instance above described with reference to Figs. 62 to 68, the car wheel is pierced and is rolled and dished to the form F² shown in Fig. 66 and, any surplus of metal in the work-piece or wheel may be forced during the rolling or operating process, to flow either into the inner rim and adjacent web portions; that is, into the spaces indicated by f¹⁵, f¹⁶ in Fig. 66; or, said surplus of metal may be forced into any other portion or portions of the work-piece or wheel without leaving a raised circular portion or fin anywhere on the so finished: rolled wheel; and, when so completely rolled and dished, said rolls J¹, J² and G¹, G² and H may still be operating against the so rolled and dished car wheel, whereby said dished car wheel is rolled perfectly true and smooth, to balance, and to gage or gages; and its tread and flange surface made harder and smoother and more durable.

In Fig. 63, said piercers or centers E⁶, E⁷, during said piercing or centering process are moved or forced the proper equal distances or depths into both sides of the blank or work-piece, as indicated by the dotted lines for the same and in these positions the shoulders or flanges e³⁰, e³¹ of said centers E⁶, E⁷ are spaced from the sides of the blank or work-piece the proper distances, or somewhat more than the proper distances required to make up the length which the hub of the car wheel is to have when finished, as and in the manner before described with reference to Figs. 22, 23 and 24, or in any other manner which produces the same result. The rolling or forming of the hub of the car wheel may also be done in a similar manner, as for instance hereinbefore described with reference to Figs. 21, 46, or 47 and 48, and, when the wheel is so completely rolled and dished, then all the rolls may be pulled back into the positions shown for instance in Fig. 3 and, said raising, lowering and retaining device is then again raised until it is in contact with the so finished dished car wheel, after which said centers E⁶, E⁷ are pulled back into the positions shown, for instance, in Fig. 3, thereby placing said finished dished wheel onto said raising, lowering and retaining device and therewith removing the same from said apparatus or mill, &c., as and in the manner hereinbefore described.

By such piercing or centering and rolling or forming processes or steps according to my invention, as for instance above described with reference to Figs. 62 to 68 inclusive, for completely rolling and dishing car wheels or other circular bodies including said piercing or centering of the work-piece with my said preferred apparatus or mill, or with any other mill producing the same result, the blank or work-piece F, shown in solid lines in either of the Figs. 62 or 63, is pierced or centered and completely rolled in the same apparatus or mill with one heat to the completely rolled and dished finished car wheel F² shown in the Figs. 67 and 68, of which figures, Fig. 68 shows in plan view the so finished rolled and dished car wheel F² and, Fig. 67 is a diametral section thereof taken on dotted line 67-67 Fig. 68, looking in direction of the arrows.

In the centering or piercing or penetrating and centering and rolling or forming and dishing processes or steps according to my invention, the properly heated ingot, bloom, blank or other work-piece, by means of said raising, lowering and retaining device, is brought, held and retained in a position wherein its outer portion or periphery is central or coaxial, or approximately so, with the piercers or work-supporting centers and therewith centered or pierced or penetrated and centered, and during or after this process, said raising, lowering and retaining device is lowered out of the way as shown in Fig. 70, after which the said ingot, bloom, blank or other work-piece may be completely rolled and, while the same revolves may be dished or not, as may be desired, to the form or shape of a car wheel, disk wheel, pipe flange or to the form or shape of any other suitable desired article such for instance as herein disclosed or similar thereto, and when so completely rolled and dished or not dished, all the rolls and piercers or work-supporting centers are pulled back, whereby said piercers or work-supporting centers are entirely removed from the so completely rolled car wheel or other article, leaving nothing but the so completed car wheel or other completely finished article on the raising, lowering and retaining device, which has again been raised to its proper position to receive said completely rolled car wheel or other article and therewith it will then be raised to the position indicated for instance by the dotted lines for F² in Fig. 69, after which said car wheel or other article is removed from the apparatus or mill and is exchanged for another properly heated ingot, bloom, blank or other

work-piece, after which the above described operation is repeated.

The advantages of my invention are many and will be appreciated by those skilled in the art. Some of said advantages are for instance;—instead of it being necessary in making, for instance, a car wheel out of a properly heated blank or other work-piece of proper diameter and thickness, such as shown for instance in Figs. 21, 29, 54, 55, 62 and 63; first by piercing and centering and by roughing out the hub and part of the web with a special apparatus; and second, by forming roughly the web, rim, flange and tread part with another special apparatus; and third, by forming to the finish the hub, web, rim, flange and tread without dishing with still another special apparatus; and fourth, by dishing with still another special apparatus; and fifth, by removing the work-supporting center part with still another special apparatus; said piercing and centering and rolling or forming the whole car wheel complete, including the dishing and the removing of the work-supporting centers, may all be done in accordance with my invention with one heat and with the same apparatus or mill. In removing the blank or other work-piece or wheel during each of said five operations from one apparatus or die and placing the same into another, much time is required and it also requires that the blank, work-piece or wheel be reheated several times, which is very expensive. For instance, if a blank or work-piece is removed from one apparatus or die into another, it loses much of its heat during such time and if such forming or shaping is partly or wholly done, for instance, with dies or with any other tools having large surfaces which are comparatively cold to the properly heated work-piece or wheel coming in contact therewith and during such forming or shaping process, the work-piece or wheel will lose still more of its heat, and therefore, after about only two such removals and processes, the work-piece or wheel may have to be reheated. With my invention, the car wheels or other articles may be completely rolled and be dished from properly heated ingots, blooms, blanks or other work-pieces which may also be centered or pierced or penetrated and centered and, all the centering or the piercing or penetrating and centering and the rolling and the dishing and the removing of the piercers or work-supporting centers may all be performed in accordance with my invention in the same apparatus or mill with one heat and therewith, in rolling for instance, such articles as car wheels, the metal therein, in the flange, tread and whole rim portion, where the strength of the wheel is mostly needed, may be worked to uniform and to its maximum density and thereby give to said parts the greatest possible strength

and most efficient wearing surface; whereby is also reduced enormously the cost of operation in the manufacture or in the making of car wheels or other articles, the product is cheapened and the output increased; or for instance, any previously formed blank or work-piece formed by any method or means into any suitable desired form or shape such for instance as herein disclosed or similar thereto and being properly heated and having the proper volume or weight for the desired finished article, may, in accordance with my invention, be rolled and dished or not dished, as may be desired, and finished to the desired form or shape of any of the bodies or articles as herein described or to the form or shape of any other suitable desired article such for instance as herein disclosed or similar thereto and being properly heated and having the proper volume or weight for the desired finished body or article, may according to my invention be rolled and dished or not dished and finished to the desired form or shape of any of the bodies or articles as herein described or to the form or shape of any other suitable desired article such for instance as herein disclosed or similar thereto; or for instance, the rolling, forming or shaping a hub portion as and in the manner hereinbefore described for instance with reference to Figs. 21, 46, 47, 48, 54, 55, or 62 and 63, whereby a hub can be rolled, formed or shaped and can be formed smooth on all its surfaces to its desired form or shape without leaving a raised portion or fin which would have to be removed afterward by turning or other costly means; or for instance, the rolling or forming the inner peripheral face or faces of the marginal or rim portion of a work-piece or wheel sufficiently conical, or sufficiently inclined as and for the purpose hereinbefore described, for instance with reference to Figs. 49, 50, 90 and 91, and then rolling the metal, or part of the metal forming the so sufficiently conically rolled face or faces into another portion of the work-piece or wheel, as and for the purpose hereinbefore described and diagrammatically illustrated with the Figs. 90 and 91; or for instance, the rolling of the total peripheral face of the work-piece or wheel first to beaked or rudimentary form, as and for the purpose hereinbefore described with reference to Figs. 39, 51, 52, 53, 90 and 91 and then rolling the so beaked or rudimentarily formed peripheral face to desired finished form, as and for the purpose hereinbefore described, for instance with reference to Figs. 51, 52 and 53 and diagrammatically illustrated with the Figs. 90 and 130

91; or for instance, such bodies or articles as herein described or any other similar desired articles which were previously finished by any process, but which were not dished; 5 may according to my invention while such article revolves be dished to any desired dish, and if so required, may also be rolled true after the dishing is done; or, such bodies or articles as herein described or any other 10 similar desired articles which were previously finished by any process and which were either dished or not dished and which were either bored and fitted or forced to their axles or shafts or which were not 15 bored, may according to my invention be rolled true or rolled to a different form or size and while such article revolves may also be dished to any desired dish or be not dished, and if bored, such bore may also be 20 made smaller in diameter so it may again be bored to its original diameter and be again fitted to the same place on its axle or shaft; or, ingots, blooms, blanks or other work-pieces which may have been previously centered or pierced and centered and which may 25 also have or not have the hub portion formed by any process or which may also have or not have been formed into any of the aforesaid forms or shapes by any process, may according to my invention be rolled and be 30 dished or not dished, as may be desired, to their desired form or shape; or for instance; the piercers or work-supporting centers, by constant and continuous pressure means de- 35 scribed, also automatically clamp the hub or center portion of the work-piece firmly between them and revolve with the blank or other work-piece while the same at its hub or center portion is so automatically firmly 40 clamped laterally, and during the centering or piercing and centering process and also during the dishing, or rolling and dishing or undishing processes, said piercers or work-supporting centers with the hub or 45 center portion of the work-piece so automatically and firmly clamped laterally between them, are moved in the direction of their axes forward or backward, such as the case may require, whereby, car wheels or 50 other circular bodies will be rolled and dished, or undished and rolled, and thereby and with the aid of indicating devices or with the aid of adjustable stops, car wheels or other circular bodies will be rolled and 55 dished &c, perfectly true, smooth and to balance and to the desired gage or gages, and when the tread and flange or peripheral face of the car wheel or other circular body being rolled reaches its desired finished diameter, 60 then said finished diameter will automatically be retained during any further rolling of the car wheel or other body, or during any further operation against said car wheel or other body; or for instance; by the means 65 of said raising, lowering or retaining device, whereby the ingot, bloom, blank or other work-piece is brought into and retained in such position wherein its outer portion or periphery is central or coaxial, or approximately so, with the piercers or work-supporting centers to thereby permit of its being centered or pierced or penetrated and centered in the center, or approximately in the center, of its outer portion or periphery, and after said work-piece is so centered or 70 pierced or penetrated and centered or during said centering or piercing or penetrating and centering process, said device is lowered away from the work-piece and is retained in said lowered position away from the work-piece until said work-piece or finished article is to be removed from the apparatus or mill, when said device is again raised to receive said work-piece or finished article and to remove the same from the apparatus or 75 mill; or for instance, with the face roll K having its peripheral or rolling face formed as and for the purpose hereinbefore described with reference to the Figs. 51, 52, 53, 90 and 91 and having its lateral thickness or width the same as is the lateral thickness or width which the outer or rim portion of the car wheel or other article which is to be rolled from the work-piece is to have when finished and, with the edging and 80 web rolling rolls J¹, J² &c, being formed as and for the purpose hereinbefore described, for instance with reference to the Figs. 49, 50, 90 and 91 and as for instance shown in the Figs. 39 and 43, &c, thereby, with said roll K and with said 85 edging and web rolling rolls J¹, J² in said Fig. 39 formed as shown and as and for the purpose hereinbefore described or, with said roll K and with said 90 edging and web rolling rolls J³, J⁴ in said 100 Fig. 43 formed as shown and as and for the purpose hereinbefore described, the metal in the peripheral face and the whole rim portion of a car wheel or other article is also rolled or worked continually during the 105 rolling process upon all its surfaces simultaneously with said three rolls formed for instance as shown in said Figs. 39 and 43, and thereby, the metal in the peripheral face and the whole rim portion of a car wheel 110 or other article is also condensed uniformly to its maximum whereby is given to said metal in said peripheral face and rim portion its due maximum and uniform strength and its due maximum and uniform resistance to wear and thereby when the work-piece or wheel is finished by my finishing rolling and dishing processes to its finished form or shape as for instance shown at F² 115 in the Figs. 40 or 44, or by my finishing rolling process to its finished form or shape as for instance shown at F² in Fig. 42 &c, said peripheral face and the whole rim portion is also rolled smooth on all its surfaces to the desired forms or shapes without leav- 120

ing a raised circular portion or fin which would have to be removed afterward by turning, or other costly means; or for instance, during the rolling according to my 5 invention, any surplus of metal in the heated work-piece may be forced during the rolling process to flow either into the inner peripheral portion of the rim or into the web portion adjacent the rim, or into both; 10 or to flow into any other portion or portions of the wheel or other object, without leaving a raised circular portion or fin anywhere on the finished rolled wheel or other finished rolled object which would have to be removed afterward by turning or other costly 15 means.

Where in the specification and claims the word "coaxial" or "coaxially" is used with reference to the centering, or piercing or 20 penetrating and centering, and to the positioning of a work-piece &c, it is intended to mean "coaxial," or "approximately coaxial," &c.

Where in the specification and claims the 25 words "ingot, bloom or blank" are used, it is intended to mean the work-piece to be operated upon, and the word "work-piece" is used herein in a broad sense and is intended to include an ingot, bloom, blank, car wheel 30 or any other unfinished or completely finished circular, or approximately circular, object adapted to be rolled, rerolled, reworked or reformed either to entirely change its shape, or only partly change its 35 shape or outline, or to change its dimensions in whole, or part as desired. In other words "work-piece" means any circular, or approximately circular, object to be operated upon.

Where in the specification and claims the 40 words "sufficiently conical" or "sufficiently inclined" are used with reference to the said inner rolling or operating portions of the web reducing roll parts j^{28} , j^{28} of said edging and web rolling rolls for instance J^1 , J^2 , 45 or with reference to the inner peripheral face or faces of the marginal or rim portion of a work-piece or wheel or other object, it is intended to mean, the inclination of said inner rolling or operating portions of said 50 web reducing roll parts j^{28} , j^{28} being or to be formed &c, so as to cause the metal, during the rolling or forming of said rim portion, to flow in the proper directions to assure compression of the metal in said rim 55 portion to uniform or to practically uniform density, as distinctly illustrated in Fig. 90 and as hereinbefore fully described with reference to said Fig. 90.

The foregoing description clearly sets 60 forth various piercing or penetrating or centering and rolling or forming processes or steps and operations, according to my invention, I prefer to employ for carrying out my invention for centering or for piercing or penetrating and centering and com-

pletely rolling and dishing according to my invention, properly heated blanks or work-pieces into completely finished rolled wheels, in the same apparatus with the said one heat, and while the means illustrated and described are designed to practically carry out the various steps of my method, I do not wish to limit myself to the use of such means, as modifications thereof may be employed and my invention practised thereby 75 without departing from my invention or sacrificing any of the advantages thereof.

The foregoing description and accompanying drawings further fully set forth my invention together with portions of an apparatus or mill for carrying out the invention and also illustrate modifications in the arrangement and construction of said portions of said apparatus or mill, which modifications may be employed for carrying out 85 my invention, all embodying my invention. It is to be understood, however, that many modifications and changes in the steps, operation and in the construction and arrangement of parts may still be made without departing from my invention, as defined in the claims.

The features of my invention herein described are not all claimed herein, but such features not herein claimed are covered by 95 claims within applications filed by me and having the hereinbefore said serial numbers and filing dates.

I claim as my invention:—

1. The method of rolling or forming car 100 wheels from heated ingots, blooms, blanks or other work-pieces, which consists in subjecting the work-piece to the action of piercing or penetrating and rolling processes which pierce or penetrate the work-piece at its opposite sides forming thereby a rudimentary bore, or a part or parts thereof, and completely roll and shape the work-piece to the form or shape of the car wheel.

2. The method of rolling or forming car 110 wheels or other circular bodies, in an apparatus or mill, from heated ingots, blooms, blanks or other work-pieces with one heat and before the finished wheel or other finished body is removed from said apparatus 115 or mill, which consists in subjecting the work-piece to the action of piercing or penetrating and rolling processes which pierce or penetrate the work-piece at its opposite sides forming a rudimentary bore, or a part 120 or parts thereof, and completely roll or form the work-piece to the desired form or shape of the car wheel or other body.

3. The method of rolling or forming car 125 wheels or other circular bodies, in an apparatus or mill, from heated ingots, blooms, blanks or other work-pieces with one heat and before the finished wheel or other finished body is removed from said apparatus or mill, which consists in subjecting the 130

work-piece to the action of piercing or penetrating and rolling processes which centrally pierce or penetrate the work-piece at its opposite sides to desired depth or depths 5 forming a rudimentary bore, or a part or parts thereof, and roll or shape the work-piece, wheel or other body as and where desired.

4. The method of rolling or forming car 10 wheels or other similar circular bodies, in an apparatus or mill, from heated ingots, blooms, blanks or other work-pieces, which consists in subjecting the work-piece to the action of piercing or penetrating and rolling 15 and dishing processes which centrally pierce or penetrate the work-piece at its opposite sides to desired depth or depths and completely roll or shape the work-piece and dish the same to the desired form or shape 20 of the dished wheel or other dished body.

5. The method of rolling or forming car 25 wheels or other similar circular bodies, in an apparatus or mill, from heated ingots, blooms, blanks or other work-pieces, which 30 consists in subjecting the work-piece to the action of piercing or penetrating and rolling and dishing processes which centrally pierce or penetrate the work-piece at its opposite sides to desired depth or depths 35 and roll or shape the work-piece as and where desired and dish the same to the desired form or shape of the dished wheel or other dished body.

6. The method of rolling or forming car 40 wheels or other similar circular bodies from 35 heated ingots, blooms, blanks or other work-pieces, while the work-piece is supported in an apparatus or mill, which consists in subjecting the supported work-piece to the action of rolling and dishing processes which 45 completely roll or shape the work-piece and dish the same to the desired form or shape of the finished dished wheel or other dished body.

45 7. The method of rolling or forming car 50 wheels or other similar circular bodies from 45 heated ingots, blooms, blanks or other work-pieces, while the work-piece is supported in an apparatus or mill, which consists in subjecting the supported work-piece to the action of rolling and dishing processes which 55 roll or shape the work-piece as and where desired and dish the same to the desired form or shape of the dished wheel or other dished body.

8. The method of rolling, rerolling, reworking or reforming new or worn heated car 60 wheels or other similar circular bodies or work-pieces, in an apparatus or mill, which consists in subjecting the work-piece to the action of forming and supporting, and 65 rolling processes which diametrically compress the central or hub portion of the work-piece and also rotatably support the same on said hub portion and roll, reroll, rework, or

reform the work-piece as and where desired to desired new form or shape of the new wheel or other new body.

9. The method of rolling, rerolling, reworking or reforming new or worn heated car 70 wheels or other similar circular bodies or work-pieces, in an apparatus or mill, which consists in subjecting the work-piece to the action of forming and supporting, and rolling processes which diametrically compress the hub of the work-piece and also support the same on said hub and completely roll, reroll, rework, or reform the work-piece, wheel or other body to the desired new form and shape of the new wheel 75 or other new body.

10. The method of rolling, rerolling, reworking or reforming new or worn heated car 80 wheels or other similar circular bodies or work-pieces, in an apparatus or mill, which consists in subjecting the work-piece to the action of forming and supporting, undishing, rolling, and redishing processes which diametrically compress the hub of the work-piece and also support the same, and undish and roll, or roll and undish the work-piece to desired diameter or form and shape, and redish or dish the same to the desired new form or shape of the new dished wheel 85 or other dished body.

11. The method of rolling or forming car 90 wheels or other circular bodies from heated ingots, blooms, blanks or other work-pieces, which consists in subjecting the work-piece to the action of piercing or penetrating, 100 supporting, clamping, and rolling processes which centrally pierce or penetrate the work-piece at its opposite sides and rotatably support the work-piece and while so supported also axially clamp the work-piece at 105 opposite sides at its center or hub portion and completely roll or shape the work-piece to the desired form or shape of the car wheel or other body.

12. The method of rolling or forming car 110 wheels or other circular bodies, in an apparatus or mill, from heated ingots, blooms, blanks or other work-pieces with one heat and before the finished wheel or other finished body is removed from said apparatus 115 or mill, which consists in subjecting the work-piece to the action of piercing or penetrating, supporting clamping, and rolling processes which centrally pierce or penetrate the work-piece from opposite sides and 120 rotatably support the work-piece and while so supported also axially clamp the work-piece at opposite sides at its center or hub part and completely roll or shape the work-piece to the desired form or shape of the 125 car wheel or other body.

13. The method of rolling or forming car 130 wheels or similar circular bodies, in an apparatus or mill, from heated ingots, blooms, blanks or other work-pieces with one heat

- and before the finished wheel or other finished body is removed from said apparatus or mill, which consists in subjecting the work-piece to the action of piercing or penetrating, supporting, clamping, and rolling processes which centrally pierce or penetrate the work-piece from opposite sides to desired depth or depths and rotatably support the work-piece and while so supported also 5 axially clamp the work-piece at its center or hub part and roll or shape the work-piece, wheel or other body as and where desired.
14. The method of rolling or forming car wheels or similar circular bodies, in an apparatus or mill, from heated ingots, blooms, blanks or other work-pieces, which consists in subjecting the work-piece to the action of piercing or penetrating, supporting, clamping, rolling, and dishing processes 10 which centrally pierce or penetrate the work-piece at its opposite sides to desired depth or depths forming a rudimentary bore, or a part or parts thereof, and rotatably support the work-piece and while so supported also 15 axially clamp the work-piece at its center or hub part and completely roll or shape the work-piece and dish the same to the desired form or shape of the dished car wheel or other dished body.
16. The method of rolling or forming car wheels or similar objects, in an apparatus or mill, from heated ingots, blooms, blanks or other work-pieces, which consists in subjecting the work-piece to the action of piercing or penetrating, supporting, clamping, rolling, and dishing processes which centrally pierce or penetrate the work-piece at its opposite sides to desired depth or depths and rotatably support the work-piece and 20 while so supported also axially clamp the work-piece at opposite sides at its center or hub part and roll or shape the work-piece as and where desired and dish the same to the desired form or shape of the dished car wheel or other dished body.
17. The method of piercing or penetrating and supporting heated work-pieces to be rolled or operated on, while the work-piece is so supported, which consists in subjecting the work-piece to the action of piercing or penetrating, supported and clamping processes which centrally pierce or penetrate the work-piece from opposite sides to desired depth 25 or depths and rotatably support and axially clamp the work piece at opposite sides at its hub or center portion during the operating process.
18. The method of piercing or penetrating and supporting heated work-pieces to be rolled or operated on, while the work-piece is so supported, which consists in subjecting the work-piece to the action of piercing or penetrating, supporting and clamping processes which centrally pierce or penetrate the work-piece from opposite sides and rotatably support and axially clamp the work-piece at its hub or center portion during the operating process. 76
19. The herein described method of supporting heated work-pieces to be rolled or operated on, while the work-piece is so supported, which consists in subjecting the work-piece to the action of supporting and clamping processes which centrally and rotatably support the work-piece and while so supported automatically clamp the work-piece laterally or axially at opposite sides at its hub or center portion during the operating process. 80
20. The method of rolling or forming car wheels or similar circular bodies from heated ingots, blooms, blanks or other work-pieces, while the work-piece is centrally supported in an apparatus or mill, which consists in subjecting the supported work-piece to the action of clamping, rolling, and dishing processes which axially clamp the supported work-piece at its center or hub part between its supporting means and completely roll or shape the work-piece and dish the same to the desired form or shape 90 of the finished dished car wheel or other dished body. 95
21. The method of rolling or forming car wheels or similar circular bodies from heated ingots, blooms, blanks or other work-pieces, while the work-piece is supported in an apparatus or mill, which consists in subjecting the supported work-piece to the action of clamping, rolling, and dishing processes which axially clamp the supported work-piece at its center or hub part between its supporting means, and roll or shape the work-piece as and where desired and dish the same to the desired form or shape of the finished dished car wheel or other dished body. 100
22. The method of rolling, rerolling, reworking or reforming new or worn heated car wheels or similar circular bodies or work-pieces, in an apparatus or mill, which consists in subjecting the work-piece to the action of forming and supporting, clamping, and rolling processes which diametrically compress the center or hub part of the work-piece and support the same on said 110 115 120 125 120

- hub part and while so supported also axially clamp the work-piece at its center or hub part and roll, reroll, rework or reform the work-piece, wheel or other body as and where desired to desired new diameter or new form and shape of the new car wheel or other new body.
23. The method of rolling, rerolling, reworking or reforming new or worn heated car wheels or similar circular bodies or work-pieces, in an apparatus or mill, which consists in subjecting the work-piece to the action of forming and supporting, clamping, and rolling processes which diametrically compress or size the center or hub part of the work-piece and support the same on said hub part and while so supported also axially clamp the work-piece at its center or hub part between its supporting means and completely roll, reroll, rework or reform the work-piece, wheel or other body to the desired new form or shape of the new car wheel or other new body.
24. The method of rolling, rerolling, reworking or reforming new or worn heated car wheels or similar circular bodies or work-pieces, in an apparatus or mill, which consists in subjecting the work-piece to the action of forming and supporting, clamping, rolling, undishing, rolling and redishing processes which diametrically compress or size the center or hub part of the work-piece and support the same on said hub part and while so supported also axially clamp the work-piece at its center or hub part between its supporting means and roll and undish, or undish and roll, the work-piece to desired diameter or form and shape and redish or dish the same to the desired new form or shape of the new dished car wheel or other dished body.
25. The method of supporting heated work-pieces to be rolled or operated on, while the work-piece is so supported, which consists in subjecting the work-piece at opposite sides of its center portion to the action of supporting and constant axially clamping process or processes which centrally support the work-piece from opposite sides and also continuously clamp the work-piece axially between its supporting means during the operating process and which so act against at least one of the side faces of the centrally clamped portion of the work-piece within a circle equaling about the size of the central hole or impression or not larger than the smallest diameter which the hub or extension of said center portion is to have.
26. The method of supporting, and rolling or forming a central hub or hub portion onto heated work-pieces to be further rolled or operated on, while the work-piece is so supported, which consists in subjecting the work-piece at opposite sides of its center portion to the action of supporting and
- clamping process or processes which centrally and rotatably support the work-piece from opposite sides and while so supported also clamp the work-piece axially between its supporting means during the operating process and which so act against at least one of the side faces of the centrally clamped portion of the work-piece within a circle equaling about the size of the central hole or impression or not larger than the smallest diameter which the hub or extension of said center portion is to have, and in subjecting the object or work-piece while so supported and so

clamped to the action of rotating and dishing process or processes which rotate the object or work-piece and dish the same while rotating.

- 5 30. The method of centrally and axially supporting, and dishing heated objects or work-pieces, which consists in subjecting the work-piece at its center or hub part to the action of supporting and clamping process or processes which centrally support and axially clamp the work-piece from opposite sides between its supporting means, and in subjecting the work-piece while so supported and so clamped to the action of rotating and dishing process or processes which rotate the object or work-piece and dish the same while rotating.

31. In the art of rolling car wheels or other circular bodies, the method of centrally and axially supporting, and dishing heated objects or work-pieces, which consists in subjecting the work-piece at its center or hub part to the action of supporting and clamping means which centrally support and axially clamp the work-piece from opposite sides, and in subjecting the work-piece to the action of rotating and dishing process or processes which rotate the object or work-piece and dish the same while rotating.

32. In the art of rolling car wheels or other circular bodies, the method of supporting heated ingots, blooms, blanks or other work-pieces to be rolled or operated on, while the work-piece is so supported, which consists in subjecting the work-piece at opposite sides of its center portion to the action of supporting and clamping process or processes which centrally and rotatably support the work-piece from opposite sides and while so supported also put the work-piece into axially clamped condition between its supporting means by means of constant power or pressure applied during the operating process and which so act against at least one of the side faces of the centrally clamped portion of the work-piece within a circle equaling about the size of the central hole or impression or not larger than the smallest diameter which the hub or extension of said center portion is to have.

33. In the art of rolling car wheels or other circular bodies, the method of supporting heated ingots, blooms, blanks or other work-pieces to be rolled or operated on, while the work-piece is so supported, which consists in subjecting the work-piece at opposite sides of its center portion to the action of supporting and clamping process or processes which centrally and rotatably support the work-piece from opposite sides and also put the work-piece automatically into axially clamped condition during the operating process and which so act against

at least one of the side faces of the centrally clamped portion of the work-piece within a circle equaling about the size of the central hole or impression or not larger than the smallest diameter which the hub or extension of said center portion is to have.

34. The method of centrally and axially supporting heated ingots, blooms, blanks or other work-pieces so that each work-piece can be rolled upon all its surfaces from its hub portion out and may be dished or not dished, while the work-piece is so supported, which consists in subjecting the work-piece at opposite sides of its center portion to the action of supporting and automatic clamping process or processes which centrally support the work-piece from opposite sides and also put the work-piece automatically into axially clamped condition at its center portion during the operating process and which so act against at least one of the side faces of the centrally clamped portion of the work-piece within a circle equaling about the size of the central hole or impression or not larger than the smallest diameter which the hub or extension of said center portion is to have.

35. The method of supporting heated ingots, blooms, blanks or other work-pieces to be rolled or operated on, while the work-piece is so supported, which consists in subjecting the work-piece at its center or hub part to the action of supporting and constant clamping process or processes which centrally and rotatably support the work-piece from opposite sides and also put the work-piece into axially clamped condition during the operating process.

36. The method of supporting heated ingots, blooms, blanks or other work-pieces to be rolled or operated on, while the work-piece is so supported, which consists in subjecting the work-piece at its center or hub part to the action of supporting and automatic clamping process or processes which centrally and rotatably support the work-piece from opposite sides and while so supported also put the work-piece automatically into axially clamped condition between its supporting means during the operating process.

37. The method of centrally and axially supporting heated ingots, blooms, blanks or other work-pieces so that each work-piece can be rolled upon all its surfaces from its hub portion out and may be dished or not dished, while the work-piece is so supported, which consists in subjecting the work-piece at its center portion to the action of supporting and clamping process or processes which centrally and rotatably support the work-piece from opposite sides and while so supported also put the work-piece into axially clamped condition between its sup-

porting means by means of constant power or pressure applied during the operating process.

38. The method of centrally and axially supporting heated ingots, blooms, blanks or other work-pieces so that each work-piece can be rolled upon all its surfaces from its hub portion out and may be dished or not dished, while the work-piece is so supported, which consists in subjecting the work-piece at its center or hub part to the action of supporting, and automatic clamping process or processes which centrally support the work-piece from opposite sides and while so supported also put the work-piece automatically into axially clamped condition between its supporting means during the operating process.

39. The method of supporting, axially clamping, and axially moving heated ingots, blooms, blanks or other work-pieces to be rolled or operated on, while the work-piece is so supported and so axially clamped, which consists in subjecting the work-piece at its center portion to the action of axially moving, supporting and clamping means which centrally and rotatably support the work-piece from opposite sides and while so supported also axially clamp the work-piece and while so rotatably supported and so axially clamped also move the work-piece or its center or hub portion axially into any position which may be desired during the operating process.

35 40. The method of supporting, axially clamping, and axially moving heated ingots, blooms, blanks or other work-pieces to be rolled or operated on, while the work-piece is so supported and so axially clamped, which consists in subjecting the work-piece at opposite sides of its center portion to the action of axially moving, supporting and clamping process or processes which centrally and rotatably support the work-piece from opposite sides and also put the work-piece into axially clamped condition during the operating process and which so act against at least one of the side faces of the centrally clamped portion of the work-piece within a circle equaling about the size of the central hole or impression or not larger than the smallest diameter which the hub or extension of said center portion is to have, and while the work-piece is so rotatably supported and so axially clamped also move the work-piece or its center or hub portion axially into any position which may be desired during the operating process.

41. The method of piercing or penetrating, supporting, axially clamping and axially moving heated ingots, blooms, blanks or other work-pieces to be rolled or operated on, while the work-piece is supported and axially clamped, which consists in subjecting the work-piece at its center or hub por-

tion to the action of axially moving, piercing or penetrating, supporting and clamping processes which centrally pierce or penetrate and also centrally and rotatably support the work-piece from opposite sides and while so supported also put the work-piece into axially clamped condition between its supporting means and while so rotatably supported and so axially clamped also move the work-piece or its center or hub portion axially into any position which may be desired during the operating process.

42. The herein described method of centering or piercing or penetrating the central portion of heated blanks, blooms or other work-pieces to any suitable size and shape and supporting and rolling the same, which consists in moving or forcing a pair of alined, oppositely-arranged axially and independently movable work-supporting devices into the work-piece at opposite sides to any predetermined depth or depths and thus also supporting the work-piece, and in subjecting the so supported work-piece to the action of rolls and rolling the same as and where desired.

43. The method of piercing or centering or penetrating the central portion of heated blanks, blooms or other work-pieces and supporting and rolling the same, which consists in applying alined and oppositely-arranged work-supporting devices to opposite sides of the work-piece and exerting piercing or penetrating pressure against the work-piece by means of either or both of said devices and pierce or penetrate and also support the work-piece, and in subjecting the so supported work-piece to the action of rolls and rolling the same as and where desired.

44. The method of piercing or centering or penetrating heated ingots, blooms, blanks or other work-pieces and supporting and rolling the same, which consists in applying a pair of alined and oppositely-arranged work-supporting devices to opposite sides of the work-piece and then exerting piercing or penetrating pressure with said devices to pierce or penetrate or center the work-piece and also support the same, and in subjecting the so supported work-piece to the action of rolls and rolling the same as and where desired.

45. The method of centering or piercing or penetrating heated work-pieces at opposite sides to any desired depth or depths and supporting the same to permit of the work-piece being rolled or formed into desired form or shape, which consists in moving or forcing independently a pair of alined and oppositely-arranged piercers or work-supporting centers into opposite sides of the work-piece to any predetermined depth or depths and also supporting the work-piece, and in then subjecting the so supported work-piece to the action of rolls.

46. The herein described method of centering or piercing or penetrating heated work-pieces to any desired depth or depths and supporting and rolling the same, which consists in applying axial pressure against the work-piece with alined and axially movable piercing or work-supporting means, in regulating or controlling the extent of axial movement of said supporting means so as to limit the extent of entrance of said supporting means into the work-piece and thus also supporting the same, and in then subjecting the so supported work-piece to the action of rolls to roll the work-piece as and where desired.
47. The method of piercing or centering or penetrating heated work-pieces to be rolled to desired shape or form, which consists in moving or forcing independently a pair of rotatably mounted piercers or work-supporting centers by the use of independent power or pressure means against the work-piece at opposite sides thereof, and forcibly entering one or both said piercers or centers into the work-piece and rotatably and centrally supporting the same, and in then subjecting the so supported work-piece to the action of rolls to roll the work-piece while so supported as and where desired.
48. The method of laterally piercing or penetrating and centrally supporting heated work-pieces in a vertical plane to permit of the work-piece being rolled to desired shape or form, which consists in moving a pair of rotatably mounted work-supporting means against the work-piece at opposite sides thereof and forcing said work-supporting means into the work-piece by the use of independently moving power or pressure means so as to rotatably support the work-piece, and in then subjecting the so supported work-piece to the action of rolling means.
49. The method of piercing or penetrating or centering heated work-pieces and at the same time rotating the same, which consists in moving or forcing under pressures a pair of alined and rotatably-mounted piercers or work-supporting centers against opposite sides of the work-piece, in applying rolls against the work-piece, in rotating the work-piece with at least one of said rolls, and in forcing either or both of said piercers or work-supporting centers into either or both sides of the work-piece during the rotation of the latter.
50. The herein described method of centering or piercing or penetrating heated work-pieces to any desired depth or depths and supporting and rolling the same, which consists in placing the work-piece between a pair of alined work-supporting heads having piercers or work supporting centers at adjacent ends, in applying piercing or penetrating or centering pressure against said heads and forcing said piercers or centers into the work-piece, in preventing at a point between the work-piece and one of the work-supporting heads the penetration of one of said piercers or work-supporting centers into the work-piece beyond a certain limit and also supporting the work-piece, and in then subjecting the so supported work-piece to the action of rolls and rolling the same as and where desired.
51. The method of centering or piercing or penetrating heated work-pieces to any predetermined depth or depths, which consists in placing the work-piece between a pair of alined work-supporting heads having piercers or work-supporting centers at adjacent ends, in applying piercing or penetrating pressure against said heads and forcing said piercers or centers into the work-piece, and in preventing at points between the work-piece and work-supporting heads the penetration of said piercers or work-supporting centers into the work-piece beyond a certain limit or limits.
52. The method of centering or piercing or penetrating heated work-pieces to any desired depth or depths, which consists in placing the work-piece between a pair of alined and oppositely-arranged work-supporting heads having piercers or work-supporting centers at adjacent ends, in applying piercing or penetrating or centering pressure against each of said heads and forcing said piercers or centers into the work-piece, and in preventing at a point between one side of the work-piece and one of said work-supporting heads, or at points between each side of the work-piece and each of said work-supporting heads the penetration of said piercers or work-supporting centers into the work-piece beyond a certain depth or depths.
53. The method of centering or piercing or penetrating heated work-pieces, which consists in placing the work-piece between a pair of alined work-supporting heads having piercers or work-supporting centers at adjacent ends, in applying pressure against one of said heads and moving its piercer or center against one side of the work-piece and in this position retaining the same against this one side of the work-piece while applying piercing or penetrating pressure against the other one of said heads and forcing its piercer or center into the other side of the work-piece, and in preventing at a point between the work-piece and said last-mentioned head the penetration of the last-mentioned piercer or center into said other side of the work-piece beyond a certain limit.
54. The herein described method of piercing or penetrating or centering to any suitable size and shape the central portion of heated circular or approximately circular ingots, blooms, blanks or other work-pieces

- at one side and supporting and rolling the same, which consists in moving or forcing one of a pair of suitable work-supporting centers into the work-piece to any predetermined depth while retaining the other of said supporting centers against the other side of the work-piece and thus also supporting the same, and in subjecting the so supported work-piece to the action of rolls and rolling the same as and where desired. 5
55. The method of centering or piercing or penetrating heated work-pieces at one side and supporting and rolling the same, which consists in temporarily supporting the work-piece, in moving and retaining one of a pair of suitable work-supporting devices axially against one side of the work-piece, in moving or forcing the other of said pair of work-supporting devices axially against the other side of the work-piece, in then applying piercing or centering or penetrating pressure with said last-mentioned device against the work-piece to cause said device to center or pierce or penetrate the work-piece and also support the same, and in then subjecting the so supported work-piece to the action of rolls. 10
56. The method of piercing or penetrating or centering heated work-pieces and supporting and rolling the same, which consists in temporarily supporting the work-piece, in moving or forcing a pair of work-supporting centers axially against opposite sides of the work-piece, in then applying piercing or penetrating or centering pressure against each of said centers to cause them to pierce or penetrate and also support the work-piece and cause the metal displaced at the center by said piercing or penetrating process to flow into another part or parts of the work-piece, and in then subjecting the so supported work-piece to the action of rolls and rolling the work-piece as and where desired. 15
57. The method of centering or piercing or penetrating heated work-pieces to any desired depth or depths and supporting and rolling the same, which consists in temporarily supporting the work-piece in a vertical plane, in moving or forcing by the use of power or pressure means a pair of aligned piercers or work-supporting centers against opposite sides of the work-piece and then applying piercing pressure against said piercers or work-supporting centers to cause them to pierce or penetrate the work-piece to desired depth or depths and to cause the metal thereof displaced by said piercers or centers to flow into another part or parts of the work-piece and thus also support the work-piece on said piercers or centers, and in then subjecting the so supported work-piece to the action of rolls and rolling the work-piece as and where desired. 20
58. The method of piercing or centering

- and supporting and axially positioning heated work-pieces and rolling the same, which consists in centering or piercing or penetrating the work-piece by applying axially movable piercing or supporting means to opposite sides of the work-piece and subjecting said means to the action of pressure so as to pierce or penetrate and support the work-piece, in then moving or positioning the work-piece axially by moving said supporting means together into any desired position, and in then subjecting the so supported work-piece to the action of rolls and rolling the work-piece as and where desired. 25
59. The method of centering or piercing or penetrating and axially positioning heated work-pieces to be rolled to desired shape or form, which consists in moving or forcing a pair of rotatably mounted work-supporting centers by the means of independent power or pressure against the work-piece at opposite sides thereof and then forcibly entering or penetrating said centers into the work-piece to rotatably support the same, in moving the work-piece axially into any desired position while so supported by axially moving said centers, and in subjecting the so supported work-piece to the action of rolls to roll the work-piece to desired shape or form. 30
60. The method of centering or piercing or penetrating, and while so centering or piercing or penetrating also axially positioning heated work-pieces, and of rolling the work-piece to desired form or shape, which consists in moving or forcing a pair of rotatably mounted and axially movable work-supporting devices with power or pressure against the work-piece at opposite sides thereof, in forcibly entering said supporting devices into the work-piece to rotatably support the same and axially moving or positioning the work-piece while so centering or piercing or penetrating the same, and in subjecting the so supported work-piece to the action of rolls to roll the work-piece to desired form or shape. 35
61. The method of centrally piercing or penetrating or centering and centrally supporting heated work-pieces and rolling the same, which consists in placing the work-piece on a supporting member of a raising, lowering and retaining mechanism and therewith raising or lowering the work-piece into proper position and retaining the work-piece to permit of its being centrally pierced or penetrated or centered in the direction of its axis, in moving said supporting member of said raising, lowering and retaining mechanism away from the work-piece either during or after said piercing or centering process, in moving and forcing by means of power or pressure a pair of aligned piercers or work-supporting centers against opposite sides of the work-piece and then applying

- piercing pressure against said piercing or work-supporting centers to cause them to centrally pierce or penetrate the work-piece in the direction of its axis and also support the work-piece, and in then subjecting the so supported work-piece to the action of rolls and rolling the work-piece as and where desired.
62. The method of centrally piercing or penetrating or centering and centrally supporting heated work-pieces and rolling the same, which consists in placing the work-piece on a supporting member of a raising, lowering and retaining mechanism and therewith raising or lowering the work-piece into proper position and retaining the work-piece to permit of its being centrally, or approximately centrally, pierced or penetrated or centered in the direction of its axis, in moving the work-supporting member of said raising, lowering and retaining mechanism away from the work-piece either during or after said piercing or centering process, in moving and forcing by means of power or pressure a pair of alined piercers or work-supporting centers against opposite sides of the work-piece and then applying piercing pressure against one of said piercing or work-supporting centers to centrally pierce or penetrate the work-piece in the direction of its axis and also support the work-piece, and in then subjecting the so supported work-piece to the action of rolls to roll the work-piece.
63. The method of rolling or forming the center portion, or hub and adjacent web portion of car wheels or other similar objects having each a web portion formed integral with its said hub, during the rolling or forming of the car wheels or other objects from heated ingots, blooms, blanks or other work-pieces having each a thickness which is the same or somewhat greater than the length of the finished hub, which consists in subjecting the work-piece to the piercing or penetrating action of a pair of alined oppositely-arranged piercers or work-supporting centers, provided with flanges or shoulders, to centrally pierce or penetrate or center the work-piece at its opposite sides and support the same and so that when so pierced or penetrated or centered and supported said flanges or shoulders are against the sides of the work-piece, in subjecting the work-piece at its opposite sides, either after or during said piercing or penetrating process, to the action of oppositely-arranged rotating edging and web rolling rolls which with their web rolling portions roll and reduce the thickness of the metal in the web portion of the work-piece adjacent its central or hub portion to desired thickness of the web and force metal to make up the length of the hub to flow from the rolled region adjacent the hub portion outward between said piercers or centers and said rolling rolls and which outward flow of metal is limited by the shoulders of said piercers or centers and thus form said hub and adjacent web portion.
64. The method of rolling or forming the center portion, or hub and adjacent web portion of car wheels or other similar objects having each a web portion formed integral with its said hub, during the rolling or forming of the car wheels or other objects from heated ingots, blooms, blanks or other work-pieces having each a thickness which is less than the length which the hub of the wheel or other object is to have when finished, which consists in subjecting the work-piece to the piercing or penetrating action of a pair of alined oppositely-arranged piercers or work-supporting centers, provided with flanges or shoulders, to centrally pierce or penetrate or center the work-piece at its opposite sides to desired depth or depths and support the same and so that when so pierced or penetrated or centered and supported said flanges or shoulders are spaced from the sides of the work-piece the proper distances or somewhat more than the proper distances required to make up the length which the hub of the wheel or other object is to have when finished, in subjecting the work-piece at its opposite sides, either after or during said piercing or penetrating process, to the action of oppositely-arranged rotating edging and web rolling rolls which with their web rolling portions roll and reduce the thickness of the metal in the web portion of the work-piece adjacent its central or hub portion to desired thickness of the web and force metal to make up the length of the hub to flow from the rolled region adjacent the hub portion outward between said piercers or centers and said rolling rolls and which outward flow of metal is limited by the shoulders of said piercers or centers and thus form said hub and adjacent web portion.
65. The method of rolling or forming the center portion, or hub and adjacent web portion of car wheels or other similar objects having each a web portion formed integral with its said hub, during the rolling or forming of the car wheels or other objects from heated ingots, blooms, blanks or other work-pieces having each a thickness which is less than the length which the hub of the wheel or other object is to have when finished, which consists in subjecting the work-piece to the piercing or penetrating action of a pair of alined oppositely-arranged piercers or work-supporting centers, provided with flanges or shoulders, to centrally pierce or penetrate or center the work-piece at its opposite sides to desired depth or depths and support the same and so that when so pierced or penetrated or centered and supported the flange or

shoulder of one of said piercers or centers is against one side of the work-piece and the flange or shoulder of the other piercer or center is spaced from the other side of the 5 work-piece the proper distance or somewhat more than the proper distance required to make up the length which the hub of the wheel or other object is to have when finished, in subjecting the work-piece at its 10 opposite sides, either after or during said piercing or penetrating process, to the action of oppositely-arranged rotating edging and web rolling rolls which with their web rolling portions roll and reduce the thickness 15 of the metal in the web portion of the work-piece adjacent its central or hub portion to desired thickness of the web and force metal to make up the length of the hub to flow from the rolled region adjacent the hub 20 portion outward between said last-mentioned piercer or center and one of said rolling rolls and which outward flow of metal is limited by the shoulders of said piercers or centers and thus form said hub and adjacent web portion. 25

66. The method of rolling or forming the center portion, or hub and adjacent web portion of car wheels or other similar objects having each a web portion formed integral with its said hub, during the rolling or forming of the car wheels or other objects from heated ingots, blooms, blanks or other work-pieces having each a thickness which is less than the length which the hub 30 of the wheel or other object is to have when finished, which consists in subjecting the work-piece to the action of a pair of alined and oppositely-arranged and axially independently movable piercing or work-supporting 35 members, in moving one of said members against one side of the work-piece and thereat retaining the same while the other member, provided with a flange or shoulder, centrally pierces or penetrates or centers the work-piece at its other side to desired depth and supporting the work-piece and so that when so pierced or penetrated or centered and supported said flange or shoulder of 40 said last-mentioned piercer is spaced from said other side of the work-piece the proper distance or somewhat more than the proper distance required to make up the length which the hub of the wheel or other object is to have when finished, in subjecting the work-piece at its opposite sides, either after or during said piercing or penetrating process, to the action of oppositely-arranged 45 rotating side rolls and which with at least one of said rolls roll and reduce the thickness of the metal in the web portion of the work-piece adjacent its central or hub portion to desired thickness of the web and force metal to make up the length of the hub to flow from the rolled region adjacent the hub portion outward between said one 50

flanged member and said last-mentioned side roll and which outward flow of metal is limited by the flange or shoulder of said flanged member and thus form said hub and adjacent web portion. 70

67. The method of sizing or shaping or centering the outer or peripheral hub portion of heated blanks or other work-pieces and supporting the work-piece on the hub portion during the rolling or operating process, which consists in moving and forcing a pair of alined and oppositely-arranged work-supporting devices over the outer peripheral face or faces of the hub portion and thereby compressing the metal of said 80 hub portion and also supporting the work-piece upon said devices, and, in subjecting the so supported work-piece to the action of rolls. 85

68. The method of sizing or suitably shaping or centering the outer or peripheral hub portion of heated work-pieces having each a central hub whereon it is adapted to be supported and while supported also be operated on, which consists in moving and 90 centrally forcing a pair of alined and oppositely-arranged dished forming devices over the outer peripheral faces of the hub at opposite sides of the work-piece and supporting the same, and in subjecting the so 95 supported work-piece to the action of rolls to operate upon the work-piece. 100

69. The method of rotatably supporting heated work-pieces to be operated upon, which consists in independently moving and 105 forcing each of a pair of alined and oppositely-arranged rotatable forming and work-supporting devices into, over or against the central portion of the work-piece and supporting the work-piece thereon, in retaining 110 said rotatable forming and supporting devices against opposite sides of the central portion of the work-piece by continuous pressure, and in subjecting the so supported work-piece to the action of rolls to operate upon the work-piece. 115

70. The method of decreasing the diameter of the central hole of heated work-pieces having each a central hub and supporting and rolling the work-pieces, which consists 120 in moving and forcing a pair of alined and oppositely-arranged forming devices over the peripheral face of said hub at opposite sides of the work-piece and thereby compressing the diametral portion of the hub 125 and decreasing the diameter of said central hole at opposite ends thereof and also supporting the work-piece, and in subjecting the so supported work-piece to the action of rolls to operate upon the work-piece and roll the same as and where desired. 130

71. The method of reducing the size of the hub in heated car wheels or the like and supporting and rolling the same, which consists in entering into the bore from opposite

- sides of the work-piece trunnions of smaller diameter than said bore, in applying pressure to the outer circumferential surface of said hub to compress the metal against said 65
 5 trunnions and also support the car wheel, and in subjecting the so supported car wheel to the action of rolls to operate upon the car wheel and roll the same as and where desired.
- 10 72. The method of reducing the size of the hub in heated car wheels or the like and supporting and rolling the same, which consists in entering into the bore from opposite sides of the work-piece trunnions of smaller 70
 15 diameter than said bore, in applying wedging pressure to the outer circumferential surface of the hub by movement of said trunnions in the direction of the length of said bore and thus also supporting the work-
 20 piece, and in subjecting the so supported car wheel to the action of rolls to roll the car wheel as and where desired.
73. The method of reducing the diameter of the central bore of heated car wheels and 75
 25 of supporting each of the car wheels at its hub portion during the operation of rolling or reworking the same, which consists in moving and forcing a pair of alined and oppositely-arranged forming and supporting
 30 elements over the peripheral face of the hub portion at opposite sides of the car wheel and compressing the diametral portion of the hub or part thereof and thereby decreasing the diameter of its bore, and thus 80
 35 also supporting the car wheel at its hub portion by said forming and supporting elements while the car wheel is rolled or operated on.
74. The method of reducing the diameter 85
 40 of the central bore of heated car wheels or other work-pieces and of supporting the car wheel or other work-piece at its hub portion during the operation of rolling or reworking the same, which consists in making the bore, 90
 45 or part of the bore of the hub portion of the car wheel or other work-piece smaller in diameter by radially compressing the walls of said bore and thus also supporting the car wheel or other work-piece on its hub
 50 portion while compressing said walls, and while so supported the car wheel is rolled or operated on.
75. The method of supporting heated car 95
 55 wheels during the operation of reworking the same, which consists in moving and forcing a pair of alined and oppositely and rotatably arranged forming and supporting elements over the hub portion at opposite sides of the car wheel and thereon also sup- 100
 60 porting the car wheel while the same is rolled or operated on.
76. The method of centrally and rotatably supporting heated car wheels during the operation of reworking the same, which con- 105
 65 sists in applying alined rotatable and inde- 110
 70 pendent axially-movable forming and work-supporting dies to the central or hub portion of the car wheel and supporting the same while it is being rolled or operated on.
77. The method of piercing or penetrat- 115
 75 ing or centering and supporting and rolling heated work-pieces, which consists in applying pressure against opposite sides of the work-piece with suitable piercing or penetrat- 120
 80 ing elements to displace metal at the center of the work-piece and force the so displaced metal to flow into another part or parts of the work-piece and also supporting the work-piece on said elements, and in then subjecting the so supported work-piece to 125
 85 the action of rolls which roll or form a hub on the work-piece simultaneously with said piercing or penetrating process.
78. The method of rolling heated work- 130
 90 pieces having each a central or hub portion and piercing or penetrating the same while rolls rotate the work-piece and act against its central or hub portion, which consists in moving or forcing under pressure a pair of alined, rotatably mounted and suitably formed work-supporting devices against opposite sides of the work-piece and centrally supporting the same, in applying rolls against the work-piece and therewith rotating the same and rolling or forming the outer peripheral face or faces of said central or hub portion, and in piercing the work-piece with either or both of said work-supporting devices while or before rolling or forming said central or hub portion. 135
 95
79. The method of causing metal from the central portion of heated objects or work-pieces to flow outward laterally in forming a hub portion on both sides of the work-piece, which consists in moving or forcing a 140
 100 pair of alined and rotatably mounted piercers or work-supporting centers against the work-piece at opposite sides thereof, in applying rolls against opposite side of the work-piece to roll and rotate the same and forcing or rolling said rolls into the sides of the work-piece and moving said rolls radially toward the axis of the work-piece while at the same time applying piercing pressure to said piercers or work-supporting centers and therewith piercing or penetrating the work-piece and supporting the same while rotating, said rolling and piercing causing metal in the central or hub portion of the work-piece to flow outward laterally between said work-supporting centers and said rolls in forming a hub portion on both sides of the work-piece. 145
 105
80. The method of forming a hub on heated work-pieces, while the work-piece is 150
 110 subjected to the action of rolls, which consists in rotating the work-piece, in applying rolling pressure to one or both sides of the 155

work-piece, and in crowding metal at one or both sides inwardly toward axis of the work-piece while rotating the latter.

81. The method of rolling or forming a hub on heated work-pieces, which consists in centrally and rotatably supporting the work-piece, in applying rolling pressure against opposite sides of the work-piece and also toward the axis or center portion of the work-piece.

82. The method of rolling or forming a hub on heated work-pieces, which consists in shouldered means for centrally and rotatably supporting the work-piece, in applying rolling pressure against the metal at opposite sides of the work-piece, in forcing metal inwardly toward the axis of the work-piece and laterally against the shoulders on said work-supporting means, and in confining the metal of the hub portion between said supporting means and said rolls.

83. The method of rolling or forming a hub on heated work-pieces, which consists in centrally and rotatably supporting the work-piece, in applying radial and lateral rolling pressures against one side of the work-piece and forcing metal to flow outwardly against the supporting means and said rolling means while forming an extension or hub portion onto one side of the work-piece.

84. The method of rolling or forming a lateral extension or hub portion on heated work-pieces, which consists in centrally engaging a pair of devices having circumferential flanges against the work-piece at opposite sides thereof, and in applying radial and lateral rolling pressures against opposite sides of the work-piece and causing metal to flow against said circumferential flanges while forming said lateral extension or hub portion.

85. The method of rolling or forming a central extension or hub portion on the central portion of heated objects or work-pieces, which consists in centrally and rotatably supporting the object on work-supporting means having circumferential flanges or shoulders spaced from the sides of the supported object, in subjecting the so supported object to rolling pressures or rolling means which rotate and roll the object and cause metal displaced thereby to flow against said flanges or shoulders and into the space adjacent the web portion formed by said work-supporting means and said rolling means.

86. The method of rolling or reducing the thickness of the web portion and rolling or forming a lateral extension or hub portion at opposite sides of and onto the central portion of heated objects or other work-pieces, which consists in supporting the work-piece on a pair of aligned rotatably mounted and axial independently-movable supporting members provided with circumferential

flanges spaced from the sides of the supported object, in applying radial and lateral rolling pressures against opposite sides and also toward the central or hub portion of the work-piece and thereby causing or forcing metal of the work-piece to flow against said circumferential flanges and confining the metal between said supporting members and said rolling means and forming said lateral extension or hub portion on opposite sides of the central portion of the work-piece without leaving an undesirable raised portion or fin on the hub portion thus formed.

87. The method of rolling or forming a hub or hub portion on heated and supported work-pieces, which consists in centrally and rotatably supporting the work-piece, in applying rolling pressures at opposite sides of the supported work-piece laterally against the sides and radially toward the axis of the work-piece, and in limiting the lateral and radial flow of metal in said hub portion while forming the latter.

88. The method of rolling or forming a lateral extension or hub portion onto opposite sides of the central portion of heated objects or work-pieces, which consists in applying rotatable supporting means against opposite sides of the work-piece, in applying radial and lateral rolling pressures against opposite sides of the supported work-piece and forcing metal to flow outwardly against said supporting means and said rolling means while forming said lateral extension or hub portion.

89. The method of rolling or shaping a hub onto heated objects or work-pieces, which consists in rotatably supporting the object on rotatable centers or supporting means in a fixed central position and by means of oppositely-arranged rolls acting against opposite sides of the object reducing the thickness thereof, in causing metal to flow toward the central portion of the object, and in confining the metal in its lateral flow at said central portion.

90. The method of rolling heated objects having each a hub portion, which consists in centrally and rotatably supporting the object, in applying rotating rolls laterally to the sides of the object to force metal to flow toward its center and in confining the flow of metal laterally at the center or hub portion of the object.

91. The method of piercing or penetrating or centering and rolling or forming a hub portion on heated work-pieces, which consists in moving or forcing under pressure a pair of aligned and rotatably mounted piercers or work-supporting centers against the work-piece at opposite sides thereof, in applying rolls against opposite sides of the work-piece at a suitable radial distance or distances from the axis of the work-piece,

in rotating the work-piece with at least one of said rolls, in forcing or rolling said rolls into the sides of the work-piece until a web portion or a part thereof has been rolled or 5 reduced to desired thickness, and in forcing said piercers or work-supporting centers into the sides of the work-piece while rolling or reducing said web portion, said rolling and piercing operation causing metal of 10 the work-piece to flow outward laterally to form the hub.

92. The method to cause metal of the central portion of heated circular work-pieces to flow outward laterally, which consists in 15 moving or forcing a pair of alined and rotatably mounted piercers or work-supporting centers against the work-piece at opposite sides thereof, in applying rolls against opposite sides of the work-piece at a proper 20 radial distance or distances from the axis of the same, in rotating the work-piece with at least one of said rolls, in forcing or rolling said rolls into the sides of the work-piece while rotating the work-piece and in 25 applying piercing or centering pressure to said piercers or work-supporting centers to therewith pierce or penetrate the work-piece while rotating, said rolling and piercing causing metal in the central or hub portion 30 of the work-piece to flow outward laterally between and against said work-supporting centers and said rolls.

93. The method of piercing or penetrating or centering and rolling or forming a hub portion on both sides of heated work-pieces, which consists in moving or forcing a pair of alined piercers or work-supporting centers against opposite sides of the work-piece, in applying rolls against opposite sides of 40 the work-piece at a suitable radial distance or distances from the axis of the work-piece, in rotating the work-piece with at least one of said rolls, in forcing or rolling said rolls into the sides of the work-piece and applying 45 piercing or penetrating pressure to said piercers or work-supporting centers to pierce or penetrate the work-piece while rotating the latter, and in confining the lateral outward flow of metal of the hub portion, said 50 rolling and piercing causing metal in the central or hub portion of the work-piece to flow outward laterally within a confined region between said work-supporting centers and said rolls to form a hub portion on 55 both sides of the work-piece.

94. The method of forming a hub on heated work-pieces, which consists in centrally and axially supporting the work-piece, in applying rolls to the so supported work-piece to rotate the same, in applying rolling pressure with one of said rolls to one side of the work-piece at a suitable radial distance from the axis thereof and forcing metal inwardly toward the axis of the work-piece to cause a central lateral extension to

be formed on the work-piece, and in confining the lateral flow of metal to govern the length of said extension.

95. The method of forming a hub on heated work-pieces, which consists in centrally 70 piercing or penetrating the work-piece at opposite sides, in applying rolling pressures to the work-piece at opposite sides and at suitable radial distances from the axis of the work-piece, in forcing metal toward the axis of the work-piece from the points of applying said pressures to cause said metal at opposite sides of the work-piece to flow toward the axis of the latter and outward laterally to form a hub on said work-piece. 75

96. The method of forming a hub on heated work-pieces, while the work-piece is subjected to the action of rolls, which consists in centrally piercing or penetrating the work-piece at opposite sides and rotatably 80 supporting the same, in applying rolling pressures to opposite sides of the work-piece at a suitable radial distance or distances from the axis of the work-piece, and in forcing metal at opposite sides of the work-piece toward the pierced or penetrated points thereof, thereby reducing the thickness of the work-piece at the operated region and forming a hub extending from opposite sides of the work-piece. 90

95. 96. 97. The method of forming a hub on heated work-pieces, which consists in centrally supporting the work-piece at one side, in centrally piercing or penetrating the work-piece at the other side, in providing a rolling support for said first-mentioned side, in applying rolling pressure to the pierced or penetrated side of the work-piece at a suitable radial distance from the axis thereof and under such rolling pressure causing metal to flow inwardly toward the axis of the work-piece and outward laterally around the pierced or penetrated portion of the work-piece to form the hub. 100

98. The method of forming a hub on heated work-pieces, which consists in centrally supporting the work-piece at one side, in centrally piercing or penetrating the work-piece at the other side, in supporting the work-piece at said first-mentioned side at a suitable radial distance from the axis of the work-piece, in applying rolling pressure to the pierced or penetrated side of the work-piece at a suitable radial distance from the axis thereof and under such rolling pressure reducing the thickness of the work-piece and causing metal from said reduced portion to flow inwardly toward the axis of the work-piece and outward laterally around the pierced or penetrated portion of the 110 work-piece, and in limiting the outward lateral flow of the metal to govern the length of the hub thus formed. 115

99. The method of rolling objects having each a hub from heated ingots, blooms, 120 125 130

- blanks or other work-pieces, which consists in centrally and rotatably supporting the work-piece in a fixed central position, in applying pressures to opposite sides of the work-piece at opposite points and on at least one side of the work-piece applying also pressure alternately toward the hub and toward the periphery of the work-piece to reduce the thickness of the metal. 5
100. The method of rolling or shaping hubs onto heated objects or work-pieces at one side thereof, which consists in centrally supporting the object on rotatable centers or rotatable supporting means in a fixed central position, in applying a roll against one side of the object and there retaining the same and by means of another roll acting against the opposite side of the object causing metal to flow toward the central portion of the object, and in confining the metal in its lateral flow at said central portion. 15
101. The method of piercing or centering and rolling or forming a hub portion on one side of heated work-pieces, which consists in moving or forcing a pair of aligned piercers or work-supporting centers against the work-piece at opposite sides thereof, in applying rolls against opposite sides of the work-piece, in rotating the work-piece with at least one of said rolls, in forcing or rolling one of said rolls into one side of the work-piece while rotating the work-piece and at the same time applying piercing pressure to said piercers or work-supporting centers and thereby pierce or penetrate the work-piece, and in confining the lateral outward flow of metal at the hub portion, said rolling and piercing causing metal in the central or hub portion of the work-piece to flow outward laterally within a confined region between at least one of said work-supporting centers and said last-mentioned roll to form a hub portion on one side of the work-piece. 25
102. The method to cause metal from the central portion of heated objects or work-pieces to flow outward laterally in forming a hub portion on one side of the work-pieces, which consists in moving or forcing a pair of aligned piercing or work-supporting centers against the work-piece at opposite sides thereof, in applying rolls against opposite sides of the work-piece, in rotating the work-piece with at least one of said rolls, in forcing or rolling one of said rolls into one side of the work-piece and moving said roll radially toward the axis of the work-piece, and in applying piercing or penetrating pressure to said piercers or work-supporting centers to pierce or penetrate the work-piece while rotating, said rolling and piercing causing metal in the central or hub portion of the work-piece to flow outward laterally against the peripheral face of at least one of said work-supporting centers 30
- and between the latter and said last-mentioned roll to form the hub portion on one side of the work-piece. 35
103. The method of forming a hub on heated work-pieces, which consists in centrally and axially and rotatably supporting the work-piece, in applying rolling pressure against one side of the work-piece and simultaneously therewith applying also pressure toward the axis of the work-piece to cause the work-piece to be reduced in thickness at the portion operated upon and also cause metal to be forced inwardly toward the axis of the work-piece to form a hub portion. 40
104. The method of rolling or forming a lateral extension or hub portion on heated work-pieces, which consists in applying a pair of supporting members centrally to the work-piece at opposite sides thereof to support the same, one of said members having a circumferential flange spaced from the side of the work-piece, in applying radial and lateral rolling pressures against one side of the work-piece and causing metal of 45 said last-mentioned side to flow against said circumferential flange while forming said lateral extension or hub portion. 50
105. The method of rolling or forming a lateral extension or hub portion on heated work-pieces, which consists in applying a pair of supporting members centrally against the work-piece at opposite sides thereof to support the same, one of said members having a stop portion spaced from the side of the supported work-piece, in applying radial and lateral rolling pressures against one side of the work-piece and thereby causing metal at said last-mentioned side of the work-piece to flow against said stop portion and against said rolling means and thus confine the metal between said supporting member and said rolling means, thereby forming said lateral extension or hub portion without leaving an undesirable raised portion or fin on the hub portion thus formed. 55
106. The method of rolling hubs onto heated objects or shaping hubs on said objects, which consists in rotatably supporting the object, in applying a roll against the outer peripheral face of the object at one side of its axis, in applying oppositely-arranged side rolls against opposite sides of the object at the other side of its axis diametrically opposite said face roll, in moving one of said side rolls toward the central portion of the object to cause metal at one side of the object to flow toward the central portion thereof and form a hub thereon while said face roll supports the object against the pressure of said last-mentioned roll toward the central portion. 60
107. The method of rolling hubs onto heated objects or shaping hubs on said ob- 65

- jects, which consists in rotatably supporting the object, in applying a rolling or pressure support against the peripheral face of the object at one side of its axis, and in applying combined lateral rolling pressures against opposite sides of the object at the other side of its axis and combining radial pressure with the lateral rolling pressure at one side of the object to cause metal at said 65 last-mentioned side of the object to flow toward the central portion of the object and form a hub thereon while said peripheral rolling support supports the object against said radial pressure.
108. The method of rolling hubs onto heated objects or shaping hubs on said objects, which consists in rotatably supporting the object, in applying a rolling or pressure support against the peripheral face of the 10 object at one side of its axis, and in applying combined lateral rolling pressures against opposite sides of the object at the other side of its axis and combining radial pressures with the lateral rolling pressures 15 at opposite sides of the object to cause metal at both sides of the object to flow toward the central portion of the object and form a hub thereon while said peripheral rolling support supports the object against 20 said radial pressures.
109. The method of rolling hubs onto heated objects or shaping hubs on said objects while rotatably supported, which consists in applying a roll against the outer 25 peripheral face of the supported object at one side of its axis, in applying oppositely-arranged side rolls against opposite sides of the object at the other side of its axis and in moving said side rolls toward the 30 central portion of the object to cause metal of the object to flow toward the central portion thereof and form a hub thereon while said face roll supports the object against the pressures of said side rolls toward the 35 central or hub portion.
110. The method of rolling or shaping a hub on heated work-pieces, which consists in supporting the work-piece on rotatable centers or supporting means, in applying a 40 roll against the outer peripheral face of the work-piece at one side of its axis, in applying oppositely-arranged side rolls against opposite sides of the work-piece at the other side of its axis and therewith causing metal 45 at one or both sides of the work-piece to flow toward the center portion of the work-piece.
111. The method of rolling or shaping a hub on heated work-pieces, which consists in 50 rotatably supporting the work-piece, in applying oppositely-arranged side rolls against opposite sides of the work-piece at one side of its axis, in applying lateral pressure and radial pressure complementary 55 thereto to one or both of said rolls to cause 65 metal at one or both sides of the work-piece to flow toward the center portion thereof, and in applying rolling pressure against the peripheral face of the work-piece at the other side of its axis while applying said 70 radial pressure or pressures.
112. The method of rolling or shaping a hub on heated work-pieces, which consists in rotatably supporting the work-piece in a fixed central position, in applying rolling 75 pressure against the outer peripheral face of the work-piece at one side of its axis, and in applying rolling pressure with radial pressure complementary thereto against one or both sides of the work-piece at the other 80 side of its axis to cause metal at one or both sides of the work-piece to flow toward the center portion of the work-piece.
113. The method of rolling heated objects into bodies having each a central hub portion, which consists in rotatably supporting the object on rotatable centers or supporting means in a fixed central position and by 85 means of a roll acting against one side of the object reducing the thickness thereof, 90 in causing metal to flow toward the center or alternately toward the center and periphery of the object, in applying a second roll oppositely-arranged to said first-mentioned roll against the other side of the object and 95 there retaining said second roll during the action of said first-mentioned roll.
114. The method of rolling objects having each a hub from heated ingots, blooms, blanks or other work-pieces, which consists in 100 centrally and rotatably supporting the work-piece in a fixed central position, in applying rolling pressures to opposite sides of the work-piece at opposite points and on at least one side of the work-piece reducing 105 the thickness of the metal.
115. The method of rolling heated objects having each a hub portion, which consists in centrally and rotatably supporting the object, and by means of a longitudinally movable roll acting against the side of the object reducing the thickness thereof and causing metal to flow toward the center of the object. 110
116. The method of rolling or forming hubs onto heated ingots, blooms, blanks or other work-pieces, which consists in applying rolling pressure against at least one of the sides of the work-piece to compress the metal, in applying complementary pressure toward the axis of the work-piece to cause 115 metal to flow toward the central portion of the work-piece, and in limiting the lateral flow of the metal at the central portion of the work-piece.
117. The method of rolling or forming 120 heated car wheels into other objects, which consists in centrally supporting the car wheel on rotatable and axially independ- 125

ently movable work-supporting means in a fixed central position, in axially moving the so supported car wheel together with its supporting means while so supported into position to be operated on and when in such position and while so supported subjecting the car wheel to the action of rolls which roll the sides and peripheral portion of the car wheel to rudimentary form of the other object, and in then subjecting the so rudimentarily formed other object to the action of a finishing rolling process which rolls the so rudimentarily formed other object to the desired finished form or shape and to desired 15 finished diameter.

118. The method of rolling or forming heated car wheels into other circular objects, which consists in centrally and axially supporting the car wheel on rotatable and axially independently movable work-supporting means in a fixed central position, in axially moving the car wheel together with its supporting means while so supported into position to be operated on, in subjecting the 25 so supported car wheel to the action of rolling and undishing processes which rotate the car wheel, undish the same while rotating and roll the so undished car wheel, or a portion or portions thereof, to rudimentary 30 form or shape of the other object, and in then subjecting the so rudimentarily formed other object to the action of a finishing rolling process which rolls the so rudimentarily formed object to its desired finished form 35 or shape.

119. The method of rolling or forming heated car wheels into other circular objects, which consists in centrally and axially supporting the car wheel on rotatable and axially independently movable work-supporting means in a fixed central position, in axially moving the car wheel together with its supporting means while so supported into position to be operated on, and in subjecting 45 the so supported car wheel to the action of rolling and undishing processes which rotate the car wheel, undish the same while rotating and roll the so undished car wheel, or a portion or portions thereof, to the desired 50 form or shape of the other object.

120. The method of rolling or forming heated car wheels into other circular objects, which consists in centrally and axially supporting the car wheel on rotatable and axially independently movable work-supporting means in a fixed central position, in axially moving the car wheel together with its supporting means while so supported into position to be operated on, and in subjecting 55 the so supported car wheel to the action of rolls which roll the peripheral portion and the sides, or portion or portions of the sides of the car wheel to the desired form or shape of the other object.

121. The method of rolling or forming heated car wheels into other circular objects, which consists in centrally and axially supporting the car wheel on rotatable and axially independently movable work-supporting means in a fixed central position, in axially moving the so supported car wheel together with its supporting means while so supported into position to be operated on, and in subjecting the so supported car wheel to the action of rolls which roll the car wheel to the desired form or shape of the other object. 65 70 75

122. The method of making or rolling car wheels or other circular bodies, consisting in subjecting the heated ingot, bloom, blank or other work-piece to piercing or penetrating, and rolling processes which form an impression or a partly rudimentarily formed bore at one or both sides at the center of the work-piece simultaneously with the shaping 80 85 of the body.

123. The method of rolling heated work-pieces and at the same time piercing or penetrating or centering the same, which consists in moving or forcing under pressure a pair of aligned and suitably formed work-supporting centers against opposite sides of the work-piece and centrally supporting the same, in applying rolls against the work-piece and therewith rotating and rolling the 90 work-piece where desired, and in forcing either or both of said piercing or work-supporting centers into either or both sides of the work-piece during the rolling of the work-piece. 95 100

124. The method of rolling heated work-pieces and piercing or penetrating the same, which consists in forcing under pressure a pair of aligned and suitably formed work-supporting centers against opposite sides of the work-piece and centrally supporting the same, in applying rolls against the work-piece and therewith rotating and rolling the work-piece where desired, and in then or during said rolling process, piercing or 105 penetrating the work-piece by means of one or both of said work-supporting centers. 110

125. The method of rolling or forming the inner circumferential face or faces, or the inner circumferential portion or portions, of the marginal or rim portion of heated car wheels or other circular work-pieces, which consists in subjecting the work-piece to the action of rolling means and therewith rolling or forming said inner circumferential face or faces to conical or rudimentary form so that the face of said conical form is more inclined in the direction away from the adjacent web portion toward the periphery of the work-piece than the inclination of the inner circumferential face or faces the car wheel or other circular work-piece is to have when finished, and in then rolling or 115 120 125

forming the so conically or rudimentarily formed face or faces to finished form.

126. The method of rolling or forming, in an apparatus or mill for rolling car wheels or other circular bodies, the inner circumferential face or faces, or the inner circumferential portion or portions, of the marginal or rim portion of heated work-pieces which consists in rolling the said inner circumferential face or faces first to rudimentary form, and in then rolling the so rudimentarily formed face or faces to finished form.

127. The method of rolling to uniform and maximum density the metal in the rim portion, or the metal forming the rim portion of car wheels or similar objects having each a center portion and a web connecting said center portion with its said rim portion, during the rolling or forming or shaping of the car wheels or similar objects from heated ingots, blooms, blanks or other work-pieces, which consists in rotatably supporting the work-piece, in rolling said metal to uniform density with rolls situated in a plane passing laterally through the work-piece at one side of its axis, or at one side of its central portion, by rolling or forming with said rolls the inner circumferential face or faces of said rim portion sufficiently inclined outwardly toward the peripheral face of said rim portion simultaneously with rolling or shaping or reducing the metal of the web portion or the metal in part of the web portion of the work-piece to the thickness of the web and rolling said rim portion to desired lateral thickness, and the peripheral face of said rim portion to beaked or rudimentary form, and in then rolling said metal to maximum density with rolls situated in a plane passing laterally through the work-piece at another side of its axis or of its central portion by rolling or forcing with said last-mentioned rolls the metal or part of the metal forming said inclined face or faces of said rim portion toward the web and the periphery of said rim portion or into the web and the inner region of said rim portion of the work-piece or wheel or similar object, and said beaked or rudimentarily formed peripheral face to desired finished form.

128. The method of rolling the metal in the rim, or the metal forming the rim of car wheels or similar objects having each a center portion and a web connecting said center portion with its said rim, during the rolling or forming or shaping of the car wheels or similar objects from heated ingots, blooms, blanks or other work-pieces, which consists in rolling said metal with rolls situated in a plane passing laterally through the work-piece at one side of its axis, or at one side of its central portion, so as to assure compression of said metal to uniform density

by rolling or forming with said rolls the inner circumferential faces of said rim sufficiently inclined outwardly toward the peripheral face of said rim simultaneously with rolling the web portion or a part of the web portion of the work-piece to the thickness of the web and rolling said rim to desired lateral thickness, and the peripheral face of said rim to beaked or rudimentary form, and in then rolling said metal to maximum or to practically maximum density with rolls situated in another plane passing laterally through the work-piece at another side of its axis or of its central portion by rolling with said last-mentioned rolls the metal or part of the metal forming said inclined faces of said rim toward a plane passing circumferentially through the periphery of said rim between said inclined faces and outwardly toward the peripheral face of said rim; and said beaked or rudimentarily formed peripheral face to desired finished form.

129. The method of rolling the metal in the rim, or the metal forming the rim of car wheels or similar objects having each a center portion and a web connecting said center portion with its said rim, during the rolling or forming or shaping of the car wheels or similar objects from heated ingots, blooms, blanks or other work-pieces, which consists in rotatably supporting the work-piece, in rolling said metal with rolls situated in a plane passing laterally through the work-piece at one side of its axis, or at one side of its central portion, so as to assure compression of said metal to uniform or to practically uniform density by rolling or forming with said rolls so situated the inner portion or portions of said rim to sufficiently conical form, and rolling or shaping or reducing with said rolls the web portion or a part of the web portion of the work-piece to the thickness of the web, and rolling with said rolls said rim to its desired lateral thickness or limiting the lateral flow of metal in said rim, and rolling the peripheral face of said rim to beaked or rudimentary form, and in then rolling said metal to maximum or to practically maximum density by rolling or forcing the metal or part of the metal in said conically formed portion or portions of said rim toward the medial region of the rim and the adjacent web portion of the work-piece, wheel or similar object, and by rolling said beaked or rudimentarily formed peripheral face of said rim to finished form or shape.

130. The method of rolling the metal in the marginal portion or rim, or the metal forming the marginal portion or rim of car wheels or similar objects having each a center portion and a web connecting said center portion with its said rim, during the rolling or forming or shaping of the car

- wheels or similar objects from heated ingots, blooms, blanks or other work-pieces, which consists in rotatably supporting the work-piece, in rolling said metal with rolls 5 situated in a plane passing laterally through the work-piece at one side of its axis, or at one side of its central portion, so as to assure compression of said metal to uniform density by rolling or forming with said rolls 10 so situated the web portion or a part of the web portion of the work-piece to the thickness of the web and the inner circumferential face or faces of said rim sufficiently oblique outwardly toward the peripheral 15 face of said rim from a plane or planes passing circumferentially through the periphery of said rim at the side or sides of the web adjacent said rim, and rolling with said rolls said rim to desired lateral thickness, and the peripheral face of said rim to beaked or rudimentary form, and in then rolling said metal so as to assure compression of the same to maximum or to practically maximum density by rolling said 20 obliquely formed inner circumferential face or faces of said rim to reduce the obliquity thereof and thereby force the metal or part of the metal forming said oblique face or faces toward said last-mentioned plane or 25 planes and toward the peripheral face of said rim and by rolling said beaked or rudimentarily formed peripheral face of said work-piece or wheel or similar object to desired finished form.
- 30 131. The method of rolling to uniform and maximum density, or practically so, the metal in the marginal portion or rim, or the metal forming the marginal portion or rim of car wheels or similar objects having each 35 a center portion and a web connecting said center portion with its said rim, during the rolling or forming or shaping of the car wheels or similar objects from heated ingots, blooms, blanks or other work-pieces, 40 which consists in rolling said metal to uniform or to practically uniform density by rolling or forming the inner circumferential face or faces of said rim sufficiently inclined outwardly toward the peripheral face of 45 said rim and by simultaneously rolling the web portion or a part of the web portion of the work-piece to the thickness of the web, and said rim to desired lateral thickness or maintaining the lateral thickness of said rim, 50 and by rolling the peripheral face of said rim to beaked or rudimentary form, and in then rolling said metal to maximum or to practically maximum density by rolling or 55 forcing the metal or part of the metal forming said inclined face or faces of said rim toward the web and the periphery of the rim or into the web and the inner region of said rim of said work-piece or wheel or similar object, and by rolling said beaked 60 or rudimentarily formed peripheral face of 65 said work-piece, wheel or similar object to finished form.
132. The method of rolling the metal in the marginal portion or rim, or the metal forming the marginal portion or rim of car 70 wheels or similar objects having each a center portion and a web connecting said center portion with its said rim, during the rolling or forming or shaping of the car wheels or similar objects from heated ingots, blooms, 75 blanks or other work-pieces, which consists in rolling said metal so as to assure compression of the same to uniform or to practically uniform density by rolling or forming, during the rolling process, the inner circumferential faces of said rim sufficiently inclined outwardly toward the peripheral face of 80 said rim, and by simultaneously rolling said rim to its desired lateral thickness or limiting with said rolls the lateral flow of 85 metal in said rim while at the same time rolling the peripheral face of said rim to beaked or rudimentary form, and in then rolling said metal to maximum or to practically maximum density by rolling or forcing the metal or part of the metal forming said inner inclined faces of said rim toward a plane passing circumferentially through the periphery of said rim between said inclined faces and outwardly toward the peripheral 90 face of said rim and by simultaneously forming or shaping the work-piece or wheel or similar object to dished form or shape simultaneously with rolling said beaked or rudimentarily formed peripheral face of said 95 work-piece or wheel or similar object to finished form.
133. The method of rolling the metal in the marginal portion or rim, or the metal forming the marginal portion or rim of car 100 wheels or similar objects having each a center portion and a web connecting said center portion with its said rim, during the rolling or forming or shaping of the car wheel or similar object from a heated ingot, bloom, blank or other work-piece, while the ingot, bloom, blank or other work-piece is rotatably supported, which consists in rolling said metal so as to assure compression of the same to uniform or to practically uniform density by rolling or forming the inner portion or portions of said rim to sufficiently 105 conical form simultaneously with rolling the web portion or a part of the web portion of the work-piece to the desired thickness of 110 the web and said rim to its desired lateral thickness and the peripheral face of said rim to beaked or rudimentary form, and in then rolling said metal to maximum or to practically maximum density by rolling or 115 forcing the metal or part of the metal in said conically formed portion or portions of said rim toward or into the medial region of said rim and adjacent web portion of the work-piece or wheel or similar 120 object.
134. The method of rolling the metal in the marginal portion or rim, or the metal forming the marginal portion or rim of car 125 wheels or similar objects having each a center portion and a web connecting said center portion with its said rim, during the rolling or forming or shaping of the car wheel or similar object from a heated ingot, bloom, blank or other work-piece, while the ingot, bloom, blank or other work-piece is rotatably supported, which consists in rolling said metal so as to assure compression of the same to uniform or to practically uniform density by rolling or forcing the metal or part of the metal in said conically formed portion or portions of said rim toward or into the medial region of said rim and adjacent web portion of the work-piece or wheel or similar 130 object.

object and by rolling the so beaked or rudimentarily formed peripheral face of said work-piece, wheel or similar object to finished form.

- 5 134. The method of rolling the metal in the rim or marginal portion, or the metal forming the rim or marginal portion of car wheels or similar objects having each a center portion and a web connecting said center portion with its said rim, during the rolling or forming or shaping of the car wheels or similar objects from heated ingots, blooms, blanks or other work-pieces, which consists in rotatably supporting the work-piece, in 10 15 20 25 30 35 40
- rolling said metal so as to assure compression of the same to uniform or to practically uniform density by rolling or forming the inner circumferential face or faces of said rim sufficiently oblique outwardly toward the peripheral face of said rim from a plane or planes passing circumferentially through the periphery of said rim at the side or sides of the web adjacent said rim simultaneously with rolling said web portion or a part of said web portion of the work-piece to the desired thickness of the web and said rim to its desired lateral thickness and the peripheral face of said rim to beaked or rudimentary form, and in then rolling said metal so as to assure compression of the same to maximum or to practically maximum density by rolling said obliquely formed inner circumferential face or faces of said rim to reduce the obliquity thereof and thereby force the metal or part of the metal forming said oblique face or faces toward said plane or planes and toward the peripheral face of said rim and by rolling the so beaked or rudimentarily formed peripheral face of said work-piece or wheel or similar object to finished form.

135. The method of rolling the metal in the rim, or the metal forming the rim of car wheels or circular objects having each a web formed integral with its said rim, during the rolling or forming or shaping of the car wheel or circular object from a heated ingot, bloom, blank or other work-piece, while the ingot, bloom, blank or other work-piece is rotatably supported, which consists in subjecting said metal to the action of rolls which roll or form the inner circumferential face or faces of said rim sufficiently inclined outwardly toward the peripheral face of said rim so as to cause the metal to flow in the proper direction to assure compression of the metal in said rim and adjacent web portion to uniform or to practically uniform density simultaneously with rolling or forming or reducing the web portion or a part of the web portion of the work-piece to desired thickness and rolling the peripheral face of said rim to beaked or rudimentary form.

136. The method of rolling the metal in the rim, or the metal forming the rim of car wheels or similar objects having each a web formed integral with its said rim, which consists in rotatably supporting the heated blank or other work-piece, in subjecting said metal to the action of rolls which roll or form the inner circumferential face or faces of said rim sufficiently inclined outwardly toward the peripheral face of said rim so as to cause the metal to flow in the proper direction to assure compression of the metal in said rim to uniform density simultaneously with rolling or forming or reducing the web portion or a part of the web portion of the work-piece to desired thickness and said rim to desired lateral thickness and the peripheral face of said rim to beaked or rudimentary form.

137. The method of rolling the metal in the rim, or the metal forming the rim of car wheels or circular objects having each a web formed integral with its said rim, which consists in rotatably supporting the heated blank or other work-piece, in subjecting said metal to the action of rolls which roll or form the inner circumferential face or faces of said rim sufficiently inclined outwardly toward the peripheral face of said rim so as to cause the metal to flow in the proper direction to assure compression of the metal in said rim and adjacent web portion to uniform density, or practically so, simultaneously with rolling or forming or reducing the web portion or a part of the web portion of the work-piece to desired thickness of the web and said rim to desired lateral thickness and rolling the peripheral face of said rim to beaked or rudimentary form, and in then rolling or forcing the metal or part of the metal forming said inclined face or faces of said rim toward the web portion and the periphery of said rim or into the web portion and the inner portion of said rim of said work-piece or wheel or circular object, and rolling said so beaked or rudimentarily formed peripheral face to finished form or shape.

138. The method of rolling the metal in the rim and adjacent web portion, or the metal forming the rim and adjacent web portion of car wheels or similar objects having each a web formed integral with its said rim, during the rolling or forming or shaping of the car wheels or similar objects from heated ingots, blooms, blanks or other work-pieces, while the ingot, bloom, blank or other work-piece is rotatably supported, which consists in subjecting said metal to the action of rolls which roll or form or reduce the web portion or a part of the web portion of the work-piece to the thickness of the web, and which roll said rim to its desired lateral thickness or limit the lateral flow of metal in said rim, and which roll or form the

- inner circumferential face or faces of said rim sufficiently inclined outwardly toward the peripheral face of said rim so as to cause the metal to flow in the proper direction to assure compression of the metal in said rim and adjacent web portion to uniform density, or practically so, and which roll the peripheral face of said rim to beaked or rudimentary form, and in then subjecting said metal to the action of finishing rolls which roll or force the metal or part of the metal forming said inclined face or faces of said rim toward the web portion and the periphery of said rim or into the web portion and the inner region of said rim of said work-piece or wheel or similar object and roll said so beaked or rudimentarily formed peripheral face to finished form.
139. The method of rolling to uniform and maximum density, or practically so, the metal in the rim or the metal forming the peripheral face of the rim of heated work-pieces or car wheels or similar objects, which consists in rolling said metal, during the rolling process, to uniform or to practically uniform density by rolling or forming the peripheral face of said rim to completely beaked or rudimentary form, and in then rolling said metal to maximum or to practically maximum density by rolling or forcing the metal forming the so completely beaked or rudimentarily formed peripheral face toward the inner portion of said rim to form the finished peripheral face of said rim.
140. The method of rolling to uniform maximum density, or practically so, the metal in the rim or the metal forming the peripheral face of the rim of heated work-pieces or car wheels or similar objects, which consists in working said metal to uniform or to practically uniform density by rolling or forming, during the rolling process, the peripheral face of said rim to completely beaked or rudimentary form, and in then working said metal to maximum density, or practically so, by rolling the metal or part of the metal forming the so completely beaked or rudimentarily formed peripheral face toward the inner portion of said rim simultaneously with rolling the peripheral face of said rim to finished form or shape.
141. The method of rolling to uniform and maximum density, or practically so, the metal in the rim, or the metal forming the peripheral face of the rim of heated work-pieces or car wheels or other similar objects, which consists in rolling or forming said metal at the peripheral face thereof to completely beaked or rudimentary form, and in then rolling or forcing the metal or part of the metal forming the so completely beaked or rudimentarily formed peripheral face toward the inner portion of said rim to form the finished peripheral face of said rim.
142. The method of rolling to uniform maximum density the metal in the rim, or the metal forming the peripheral face of the rim of heated work-pieces or car wheels or other similar objects, which consists in rolling or forming said metal at the peripheral face thereof, during the rolling process, to completely beaked or rudimentary form, and in then rolling or forcing the metal or part of the metal forming the so completely beaked or rudimentarily formed peripheral face toward the inner portion of said rim to form the finished peripheral face of said rim simultaneously with rolling said peripheral face of said rim to finished form or shape.
143. The method of rolling to uniform and maximum density, or to practically uniform and maximum density, the metal in the rim or the metal forming the peripheral face of the rim of heated work-pieces or car wheels or other similar objects, which consists in rolling or forming said metal, during the rolling process, at the peripheral face thereof to completely beaked or rudimentary form, and in then rolling during said operating process the so completely beaked or rudimentarily formed peripheral face of said rim to finished form or shape.
144. The method of rolling metal of a heated work-piece to the form or shape of the marginal portion, or rim and adjacent web portion of car wheels or similar objects having each a web formed integral with its said rim, which consists in rolling said metal, during the rolling process, with rolls situated in a plane passing laterally through the work-piece at one side of its axis, or at one side of its center portion, so as to cause the metal to flow in the proper direction to assure compression of the metal in said rim and adjacent web portions to uniform density, or practically so, by rolling or forming with said rolls so situated the inner circumferential face or faces of said rim sufficiently inclined outwardly toward the peripheral face of said rim simultaneously with rolling or forming or reducing the web portion or a part of the web portion of the work-piece to the desired thickness of the web and rolling with said rolls said rim to desired lateral thickness or limiting the lateral flow of metal in said rim, and rolling the peripheral face of said rim to beaked or rudimentary form.
145. The method of rolling the metal in the rim, or the metal forming the rim of car wheels or similar objects having each a web formed integral with its said rim, during the rolling or forming or shaping of the car wheels or similar objects from heated ingots, blooms, blanks or other work-pieces, while the ingot, bloom, blank or other work-piece is rotatably supported, which consists

- in working said metal with rolls situated in a plane passing laterally through the work-piece at one side of its axis, or at one side of its center portion, by rolling or 5 forming with said rolls so situated, during the rolling process, the inner circumferential face or faces of said rim sufficiently inclined outwardly toward the peripheral face of said rim so as to cause the metal to flow 10 in the proper direction to assure compression of the metal in said rim to uniform density, or practically so, and rolling with said rolls the rim to its desired lateral thickness, and the peripheral face of said rim to 15 beaked or rudimentary form.
146. The method of rolling the metal in the rim and adjacent web portion, or the metal forming the rim and adjacent web portion of car wheels or similar objects having each a web formed integral with its said rim, during the rolling or forming or shaping of the car wheels or similar objects from heated ingots, blooms, blanks or other work-pieces, while the ingot, bloom, blank 20 or other work-piece is rotatably supported, which consists in rolling said metal with rolls situated in a plane passing laterally through the work-piece at one side of its axis, or at one side of its center portion, by 25 rolling with said rolls so situated the web portion or a part of the web portion of the work-piece to the thickness of the web, and said rim to its desired lateral thickness or limiting with said rolls the lateral flow of 30 metal in said rim, and rolling or forming with said rolls the inner circumferential face or faces of said rim sufficiently inclined outwardly toward the peripheral face of said rim so as to cause the metal to flow in 35 40 the proper direction to assure compression of the metal in said rim and adjacent web portion to uniform or to practically uniform density, and rolling the peripheral face of said rim to beaked or rudimentary form,
- 45 and in then subjecting said metal to the action of finishing rolls which roll or force the metal or part of the metal forming said inclined face or faces of said rim toward the web and the periphery of said rim or into 50 the web and the inner region of said rim of the work-piece or wheel or similar object, and rolling the so beaked or rudimentarily formed peripheral face to finished form.
147. The method of rolling to uniform 55 and maximum density, or practically so, the metal in the rim, or the metal forming the rim of car wheels or similar objects having each a web formed integral with its said rim, during the rolling or forming or shaping of 60 the car wheels or similar objects from heated ingots, blooms, blanks or other work-pieces, which consists in rotatably supporting the work-piece, in subjecting said metal to the action of rolls situated in a plane passing laterally through 65 70 75 80 85 90 95 100 105 110 115 120 125
- laterally through the work-piece at one side of its axis, or at one side of its center portion, and therewith rolling or forming the inner circumferential face or faces of said rim sufficiently inclined outwardly toward the peripheral face of said rim so as to cause the metal to flow in the proper direction to assure compression of the metal in said rim and adjacent web portion to uniform density, or practically so, and simultaneously therewith rolling or shaping or reducing with said rolls the web portion or a part of the web portion of the work-piece to desired thickness of the web, and rolling said rim to its desired lateral thickness, and rolling the peripheral face of said rim to beaked or rudimentary form, and in then subjecting said metal to the action of finishing rolls situated in a plane passing laterally through the work-piece at another side of its axis or of its center portion which roll or force the metal or part of the metal forming said inclined face or faces of said rim toward the web and the periphery of said rim or into the web and the inner region of said rim of the work-piece or wheel or similar object, and roll the so beaked or rudimentarily formed peripheral face of said work-piece, wheel or similar object to finished form.
148. The method of rolling the metal in the rim, or the metal forming the rim of car wheels or similar objects having each a web formed integral with its said rim, during the rolling or forming or shaping of the car wheels or similar objects from heated ingots, blooms, blanks or other work-pieces, which consists in rolling said metal to uniform or to practically uniform density by rolling or forming the inner circumferential face or faces of said rim sufficiently inclined outwardly toward the peripheral face of said rim simultaneously with rolling or forming or reducing the web portion or a part of the web portion of the work-piece to the thickness of the web, and in then rolling or forcing the metal or part of the metal forming said inclined face or faces of said rim toward the web and the periphery of said rim, or into the web and inner rim portion of the work-piece, wheel or similar object.
149. The method of rolling the metal in the rim, or the metal forming the inner circumferential face or faces of the rim of car wheels or similar objects having each a web formed integral with its said rim, which consists in rotatably supporting the heated ingot, bloom, blank or other work-piece, in subjecting said metal to the action of rolls situated in a plane passing laterally through the work-piece at one side of its axis, or at one side of its center portion, and therewith rolling or forming or shaping, during the rolling process, the inner circumferential face or faces of said rim sufficiently inclined

outwardly toward the peripheral face of said rim so as to cause the metal to flow in the proper direction to assure compression of said metal to uniform or to practically uniform density.

150. The method of rolling the metal in the rim, or the metal forming the inner circumferential face or faces of the rim of car wheels or similar objects having each a web formed integral with its said rim, during the rolling or forming or shaping of the car wheels or similar objects from heated ingots, blooms, blanks or other work-pieces, which consists in subjecting said metal to the action of rolls which roll or form the inner peripheral face or faces of said rim sufficiently inclined outwardly toward the peripheral face of said rim so as to cause the metal to flow in the proper direction to assure compression of said metal in said rim to uniform or to practically uniform density simultaneously with rolling or shaping or reducing the web portion or a part of the web portion of the work-piece to desired thickness of the web.
151. The method of rolling the metal in the rim, or the metal forming the inner circumferential face or faces of the rim of car wheels or similar objects having each a web formed integral with its said rim, during the rolling or forming or shaping of the car wheel or similar object from a heated ingot, bloom, blank or other work-piece, while the work-piece is rotatably supported, which consists in subjecting said metal to the action of rolls and therewith rolling or forming the inner peripheral face or faces of said rim sufficiently inclined outwardly toward the peripheral face of said rim so as to assure compression of said metal in said rim and adjacent web portion to uniform or to practically uniform density simultaneously with rolling the web portion or a part of the web portion of the work-piece to desired thickness of the web.
152. The method of rolling or forming the inner rim and adjacent web portion of car wheels or similar objects having each a web formed integral with its said rim, during the rolling or forming or shaping of the car wheel or similar object from a heated ingot, bloom, blank or other work-piece, which consists in rotatably supporting the work-piece, in rolling the metal forming said inner rim and adjacent web portion to uniform or to practically uniform density by rolling or forming the inner circumferential face or faces of said rim sufficiently inclined outwardly toward the peripheral face of said rim simultaneously with rolling or shaping or reducing the web portion or a part of the web portion of the work-piece to desired thickness of the web, and in then rolling or forming the metal or part of the metal forming said inclined face or faces of

said rim toward the web and the periphery of said rim, or into the web and inner portion of said rim simultaneously with rolling the inner rim and adjacent web portions of said work-piece, or wheel or similar object to finished form or shape.

153. The herein described method of rolling the metal in the rim, or the metal forming the rim of car wheels or circular objects having each a web formed integral with its said rim, during the rolling or forming or shaping of the car wheel or circular object from a heated ingot, bloom, blank or other work-piece, which consists in first rolling said metal to uniform or to practically uniform density and in then rolling said metal to maximum or to practically maximum density.

154. The herein described method of rolling the metal in the rim, or the metal forming the rim of car wheels or similar objects having each a web formed integral with its said rim, during the rolling or forming or shaping of the car wheel or similar object from a heated ingot, bloom, blank or other work-piece, while the work-piece is rotatably supported, which consists in first rolling said metal to uniform or to practically uniform density, and in then rolling said metal to maximum or to practically maximum density simultaneously with rolling said rim to finished form or shape.

155. The herein described method of rolling the metal in the rim and adjacent web portion, or the metal forming the rim and adjacent web portion of heated work-pieces or car wheels or similar objects, which consists in first rolling said metal to uniform or to practically uniform density, and in then rolling said metal to maximum or to practically maximum density.

156. The herein described method of rolling the metal in the rim and adjacent web portion, or the metal forming the rim and adjacent web portion of heated work-pieces or car wheels or similar objects, which consists in first rolling said metal to uniform or to practically uniform density, and in then rolling said metal to maximum or to practically maximum density simultaneously with rolling said rim to finished form or shape.

157. The method of rolling or forming the marginal or rim portion and adjacent web portion of heated car wheels or other work-pieces, which consists in centrally and rotatably supporting the work-piece in a fixed central position, in applying rolling pressures or rolling means simultaneously against all surfaces situated in a plane passing laterally through said rim and adjacent web portions of the so supported work-piece and therewith rotating the work-piece and rolling said rim to rudimentary form, and in then applying rolling pressures or roll-

ing means against said so rudimentarily formed rim and adjacent web portions and rolling the same to desired finished form.

158. The method of rolling or forming 5 the marginal or rim portion of heated car wheels or other work-pieces, which consists in centrally and rotatably supporting the work-piece in a fixed central position, in applying rolls positioned in a plane passing 10 laterally through the work-piece at one side of its axis, simultaneously against all the surfaces of said rim portion situated in said plane and therewith rotating the work-piece and rolling or forming said rim to rudimentary 15 form, and in then applying rolling pressures or rolling means against said so rudimentarily formed rim portion and rolling the same to desired finished form.

159. The method of rolling the marginal 20 portion, or the rim and adjacent web portion of car wheels or similar objects having each a web formed integral with its said rim, during the rolling or forming of the car wheel or similar object from a heated 25 ingot, bloom, blank or other work-piece, which consists in rotatably supporting the work-piece in a fixed central position, in subjecting the metal for said marginal portion to the action of rolls situated in a plane 30 passing laterally through the work-piece at one side of its axis and therewith rolling or forming, during the rolling process, said rim and adjacent web portion simultaneously 35 on all its surfaces situated in said plane to rudimentary form, and in then rolling with rolls 40 situated in another plane passing laterally and radially through the work-piece at another side of its axis the so rudimentarily formed rim to finished form.

160. The method of rolling the marginal portion, or the rim and adjacent web portion of car wheels or similar objects having each a web formed integral with its said 45 rim, during the rolling or forming of the car wheel or similar object from a heated ingot, bloom, blank or other work-piece, which consists in rotatably supporting the work-piece in a fixed central position, in subjecting the metal for said marginal portion 50 to the action of rolls situated in a plane passing laterally through the work-piece at one side of its axis, or at one side of its center portion, and therewith rolling or 55 forming said rim and adjacent web portion simultaneously on all its surfaces situated in said plane to rudimentary form.

161. The method of rolling the marginal portion, or the rim and adjacent web portion 60 of car wheels or similar objects having each a web formed integral with its said rim, during the rolling or forming of the car wheel or similar object from a heated ingot, bloom, blank or other work-piece,

which consists in rotatably supporting the work-piece in a fixed central position, in subjecting the metal for said marginal portion to the action of rolls situated in a plane passing laterally through the work-piece at one side of its axis, or at one side of its central portion, and therewith rolling or forming said rim and adjacent web portion simultaneously on all its surfaces situated in said plane to rudimentary form, and in then rolling the so rudimentarily formed rim and adjacent web portion to finished form.

162. The method of rolling the marginal portion, or the rim and adjacent web portion of car wheels or similar objects having each a web formed integral with its said rim, during the rolling or forming of the car wheel or similar object from a heated ingot, bloom, blank or other work-piece, which consists in rotatably supporting the work-piece in a fixed central position, in subjecting the metal for said marginal portion to the action of rolls situated in a plane passing laterally and radially through the work-piece at one side of its axis and therewith rolling or forming said rim and adjacent web portion simultaneously on all its surfaces situated in said plane to rudimentary form, and in then rolling with rolls situated in another plane passing laterally and radially through the work-piece at another side of its axis the so rudimentarily formed rim to finished form.

163. The method of rolling the marginal portion, or the rim and adjacent web portion of car wheels or similar objects having each a web formed integral with its said rim, during the rolling or forming of the car wheel or similar object from a heated ingot, bloom, blank or other work-piece, which consists in rotatably supporting the work-piece in a fixed central position, in subjecting the metal for said marginal portion to the action of rolls situated in a plane passing laterally and radially through the work-piece at one side of its axis and therewith rolling or forming said rim and adjacent web portion simultaneously on all its surfaces situated in said plane to rudimentary form.

164. The method of rolling the marginal portion, or the rim and adjacent web portion of car wheels or similar objects having each a web formed integral with its said rim, during the rolling or forming of the car wheel or similar object from a heated ingot, bloom, blank or other work-piece, which consists in rotatably supporting the work-piece in a fixed central position, in subjecting the metal for said marginal portion to the action of rolls situated in a plane passing laterally and radially through the work-piece and therewith rolling said rim and adjacent web portion simultaneously on

all its surfaces situated in said plane to rudimentary form, and in then rolling the so rudimentarily formed rim to finished form.

165. The method of rolling car wheels or circular objects having each a center portion, a rim and a web connecting said center portion with its said rim, during the rolling or forming or shaping of the car wheels or circular objects from heated ingots, blooms, blanks or other work-pieces, which consists in rotatably supporting the work-piece in a fixed central position, in subjecting the work-piece to the action of rolls situated in a plane passing laterally and radially through the work-piece at one side of its axis and therewith rolling a portion or portions of the work-piece as and where desired and the rim and adjacent web portion of the work-piece simultaneously on all its surfaces situated in said plane to rudimentary form.

166. The method of rolling car wheels or circular objects having each a center portion, a rim and a web connecting said center portion with its said rim, during the rolling or forming or shaping of the car wheels or circular objects from heated ingots, blooms, blanks or other work-pieces, which consists in rotatably supporting the work-piece in a fixed central position, in subjecting the work-piece to the action of rolls situated in a plane passing laterally and radially through the work-piece at another side of its axis the so rudimentarily formed rim to finished form.

167. The method of rolling car wheels or circular objects having each a center portion, a rim and a web connecting said center portion with its said rim, during the rolling or forming or shaping of the car wheels or circular objects from heated ingots, blooms, blanks or other work-pieces, which consists in rotatably supporting the work-piece in a fixed central position, in subjecting the work-piece to the action of rolls situated in a plane passing laterally through the work-piece at one side of its axis, or at one side of its center portion, and therewith rolling a portion or portions of the work-piece as and where desired and the rim and adjacent web portion of the work-piece simultaneously on all its surfaces situated in said plane to rudimentary form, and in then rolling with rolls situated in another plane passing laterally through the work-piece at another side of its axis, or at another side of

its center portion, the so rudimentarily formed rim to finished form.

168. The method of rolling car wheels or circular objects having each a center portion, a rim and a web connecting said center portion with its said rim, during the rolling or forming or shaping of the car wheels or circular objects from heated ingots, blooms, blanks or other work-pieces, which consists in rotatably supporting the work-piece in a fixed central position, in subjecting the work-piece to the action of rolls situated in a plane passing laterally through the work-piece at one side of its axis, or at one side of its center portion, and therewith rolling a portion or portions of the work-piece as and where desired and the rim and adjacent web portion of the work-piece simultaneously on all its surfaces situated in said plane to rudimentary form.

169. The method of rolling car wheels or similar objects from heated ingots, blooms, blanks or other work-pieces, which consists in rotatably supporting the work-piece in a fixed central position, in subjecting the work-piece to the action of rolls situated in a plane passing laterally through the work-piece at one side of its axis, or at one side of its center portion, and therewith rolling a portion or portions of the work-piece as and where desired and the rim and adjacent web portion of the work-piece simultaneously on all its surfaces situated in said plane to rudimentary form.

170. The method of rolling car wheels or similar objects from heated ingots, blooms, blanks or other work-pieces, which consists in rotatably supporting the work-piece in a fixed central position, in subjecting the work-piece to the action of rolls situated in a plane passing laterally and radially through the work-piece at one side of its axis, or at one side of its center portion, and therewith rolling a portion or portions of the work-piece as and where desired and the rim and adjacent web portion of the work-piece simultaneously on all its surfaces situated in said plane to rudimentary form.

171. The method of rolling car wheels or similar objects from heated ingots, blooms, blanks or other work-pieces, which consists in supporting the work-piece in a fixed central position, in subjecting the work-piece to the action of rolls situated in a plane passing laterally through the work-piece at one side of its axis, or at one side of its center portion, and therewith rolling a portion or portions of the work-piece as and where desired and the rim and adjacent web portion of the work-piece simultaneously on all its surfaces situated in said plane to rudimentary form, and in then rolling the so rudimentarily rolled rim to desired finished form.

172. The method of rolling car wheels or similar objects from heated ingots, blooms, blanks or other work-pieces, which consists in supporting the work-piece in a fixed central position, in subjecting the work-piece to the action of rolls situated in a plane passing laterally and radially through the work-piece at one side of its axis and therewith rolling a portion or portions of the work-piece as and where desired and the rim and adjacent web portion of the work-piece simultaneously on all its surfaces situated in said plane to rudimentary form, and in then rolling the so rudimentarily rolled rim to desired finished form.
173. The method of rolling car wheels or similar objects from heated ingots, blooms, blanks or other work-pieces, which consists in supporting the work-piece in a fixed central position, in subjecting the work-piece to the action of rolls situated in a plane passing laterally through the work-piece at one side of its axis, or at one side of its center portion, and therewith rolling the work-piece simultaneously on all its surfaces from its hub portion out situated in said plane to rudimentary form, and in then rolling the so rudimentarily rolled rim to desired finished form.
174. The method of rolling car wheels or similar objects from heated ingots, blooms, blanks or other work-pieces, which consists in supporting the work-piece in a fixed central position, in subjecting the work-piece to the action of rolls situated in a plane passing laterally and radially through the work-piece at one side of its axis and therewith rolling the work-piece simultaneously on all its surfaces from its hub portion out situated in said plane to rudimentary form, and in then rolling the so rudimentarily rolled rim to desired finished form.
175. The method of rolling or forming the web and the marginal portion or rim of car wheels or circular objects having each a center portion or hub, and a web connecting said center portion with its said rim and dishing the wheel or other object, during the rolling or forming of the car wheels or circular objects from heated ingots, blooms, blanks or other work-pieces, which consists in rotatably supporting the work-piece, in subjecting the work-piece at its opposite sides to the action of lengthwise movable and laterally oppositely-arranged rotating shouldered side rolls which rotate the work-piece and by moving the same lengthwise forward or backward, or forward and backward, roll and reduce the thickness of the metal in the web portion of the work-piece to desired thickness of the web, and which roll the portion of the work-piece between their shoulders and the periphery of the work-piece to the lateral thickness of the finished rim and also maintain said lateral thickness during the operating process, while simultaneously with or during part of said action of said side rolls, a peripheral face beaking or face roughing roll positioned between said side rolls may begin to act or may be acting against and roll or work the metal in the peripheral face of the work-piece and together with said rolling rolls roll said peripheral face to beaked or rudimentary form, and in then subjecting the so rolled work-piece to the action of finishing rolling process or processes which roll and reduce the thickness of the metal in the remainder of the web portion of the work-piece to the desired thickness of the web and the inner circumferential face or faces of said rim to desired forms or shapes and said so beaked or rudimentarily formed peripheral face to desired finished form or shape.

177. The method of rolling or forming the web and the marginal portion or rim of car wheels or circular objects having each a center portion or hub, and a web connecting said center portion with its said rim, during the rolling or forming of the car wheels or circular objects from heated ingots, blooms, blanks or other work-pieces, which consists in rotatably supporting the work-piece, in

0 subjecting the work-piece at its opposite sides to the action of lengthwise movable and laterally oppositely-arranged rotating edging and web rolling rolls which rotate the work-piece and by moving the same

15 lengthwise forward or backward, or forward and backward, roll and reduce with their web rolling portions the thickness of the metal in the web portion of the work-piece to desired thickness of the web, and

20 which with their edging roll portions roll the portion of the work-piece between their web rolling portions and the periphery of the work-piece to the lateral thickness of the finished rim and also maintain said lateral

25 thickness during the operating process, and which with their said web rolling portions also roll the inner circumferential face or faces of the rim to rudimentary form, while simultaneously with or during part of said

30 action of said rolling rolls, a peripheral face beaking or face roughing roll positioned between said rolling rolls may begin to act or may be acting against and roll or work the metal in the peripheral face of the work-

35 piece and together with said rolling rolls roll the peripheral face of the work-piece to beaked or rudimentary form, and in then subjecting the so rolled work-piece to the action of finishing rolling process or

40 processes which roll the so rudimentarily formed inner circumferential face or faces of the rim and said so beaked or rudimentarily formed peripheral face to desired finished forms or shapes.

45 178. The method of forming a rim on heated ingots, blooms, blanks or other work-pieces, which consists in applying rolling pressure laterally against at least one side of the work-piece to compress the metal, in

50 causing metal to flow toward the periphery of the work-piece by applying also pressure in such direction, and in limiting the lateral flow of the metal at the rim portion of the work-piece.

55 179. The method of rolling or forming heated ingots, blooms, car wheel blanks, or other work-pieces into car wheels or similar bodies, which consists in applying rolling pressures or rolling means against exposed surfaces of the work-piece and therewith first rolling or forming or shaping the hub and adjacent web portions, and in then rolling and forming the remainder of the web portion and the rim portion of the work-piece to desired forms or shapes.

180. The method of rolling or forming heated work-pieces into car wheels or similar bodies while the work-piece is rotating, which consists in first rolling and forming the central or hub portion of the work-piece 70 as desired, and in then rolling and forming the web and the marginal or rim portion of the work-piece to the desired forms or shapes.

181. The method of rolling heated objects at their marginal or peripheral portions, which consists in rotatably supporting the object in a fixed central position, in applying a pair of oppositely-arranged shouldered rolls with their peripheral faces 80 against the marginal portion of the object at opposite sides thereof so as to rotate the object and also prevent lateral and inward flow of the metal thereof, in applying rolling pressure against the object at its peripheral face to completely beak the same, and in then applying rolling pressure against the so completely beaked peripheral face at another point to roll said so completely beaked peripheral face into desired 90 finished shape.

182. The method of rolling heated objects at their marginal or peripheral portions, which consists in rotatably supporting the object in a fixed central position, in applying rolling pressure against opposite sides of the object at its marginal portion to rotate the same and prevent lateral and inward flow of the metal thereof, in applying rolling pressure against the object at its peripheral face to completely beak the same, and in then applying rolling pressure against the so completely beaked peripheral face at another point of the object to roll said so completely beaked peripheral face 100 into desired finished shape or form.

183. The method of rolling heated work-pieces to desired size and to true circular form, which consists in applying a pair of longitudinally movable and oppositely-arranged shouldered rolls laterally against opposite sides of the work-piece at its marginal portion so as to rotate the work-piece and also prevent lateral and inward flow of the metal thereof, in applying rolling pressure against the work-piece at one point of its peripheral face to completely beak said peripheral face of the work-piece, and in then applying rolling pressure against the so completely beaked peripheral face at another point of the work-piece to roll said beaked face to desired shape with a flanged tread simultaneously with rolling the work-piece to exact size and to true circular form. 115

184. The method of rolling extended marginal or peripheral portions of heated objects, which consists in centrally and rotatably supporting the object, in applying the peripheral faces of a pair of oppositely-arranged laterally swinging side rolls against 125

- opposite sides of the object at one side of its axis, or at one side of its center portion, in causing said side rolls to operate against the inner peripheral face or faces of the 5 extended marginal or peripheral portion of the object simultaneously with applying a peripheral face shaping or face finishing roll between said pair of side rolls against the peripheral face of the object to coact 10 with said side rolls to roll said inner peripheral face or faces of said marginal portion, and the peripheral face of the object to desired forms or shapes, while a pair of oppositely-arranged edging side rolls applied laterally to opposite sides of the 15 object at another side of its axis or of its center portion roll the lateral edges or sides of said extended marginal or peripheral portion to desired width.
185. The method of rolling the marginal or peripheral portion of heated car wheel blanks or other work-pieces having each a hub portion, a rudimentary rim portion and a web connecting said hub and rudimentary 20 rim portions, which consists in centrally and rotatably supporting the work-piece, in rolling the work-piece at its rudimentary rim portion while so supported by applying thereto a pair of oppositely-arranged rotating side rolls at one side of the center portion of the work-piece, in swinging or moving said side rolls against said rudimentary rim portion, in applying a face shaping or face finishing roll against the 25 peripheral face of the work-piece between said rotating side rolls to coact with the latter to roll the inner peripheral face or faces of the rim portion to desired shape, and the peripheral face of the work-piece to 30 the shape of a flanged tread or to any other desired shape simultaneously with applying a pair of oppositely-arranged edging rolls to opposite sides of the work-piece at another side of its center portion and there- 35 with roll or limit the lateral flow of metal in the rim portion.
186. The method of rolling the marginal or peripheral portion of heated work-pieces having each a hub portion, a rim portion and 40 a web connecting said hub and rim portions, which consists in rotatably supporting the work-piece in a fixed central position during the rolling process, in applying a pair of laterally oppositely-arranged rolls to opposite sides of the work-piece at one side of its center portion and swinging said rolls against the inner rim portion, in rotating the work-piece with at least one of said rolls, in applying a peripheral face shaping or 45 face finishing roll against the peripheral face of the work-piece between said pair of rolls to coact with the latter and roll the inner rim and adjacent web portions of the work-piece to desired shape and the peripheral face of the work-piece with a flanged

tread or to any other desired shape simultaneously with applying a pair of oppositely-arranged edging rolls laterally against opposite sides of the work-piece at another side of the center portion thereof to operate upon 70 the opposite sides of said rim portion and roll the same to desired width.

187. The method of rolling or forming a web on heated ingots, blooms, blanks or other work-pieces, which consists in supporting the work-piece on rotatable centers, in arranging a pair of oppositely-arranged peripheral face rolls at desired equal radial distances from the axis of the work-piece and thus retaining said face rolls, in applying a pair of longitudinally movable and oppositely-arranged side rolls to opposite sides of the work-piece and at opposite sides of one of said peripheral face rolls, in applying pressure laterally to said side rolls to 85 reduce the thickness of the work-piece and in moving said side rolls longitudinally or radially with respect to the work-piece, forward or backward, or forward and backward, that is, toward the center or hub portion and toward the rim portion or periphery of the work-piece to form a web while or during the latter part of said action of said side rolls said peripheral face rolls are in contact with the peripheral face of the 90 work-piece.

188. The method of rolling or forming a web on heated ingots, blooms, blanks or other work-pieces, which consists in rotatably supporting the work-piece, in applying a pair of oppositely-arranged tread or peripheral face rolls against the peripheral face of the work-piece for supporting the work-piece against opposite radial pressures caused during the web rolling process, and 100 in applying oppositely-arranged longitudinally movable web rolls laterally to opposite sides of the work-piece and operating them longitudinally in contact with the opposite sides of the work-piece to reduce the 110 thickness of the metal of the work-piece where desired and to roll the web of the work-piece to desired thickness.

189. The method of rolling or forming a web on heated ingots, blooms, blanks or 115 other work-pieces, which consists in centrally and rotatably supporting the work-piece, in applying rolling pressure against opposite sides of the work-piece combined with pressure exerted radially, or substantially radially to form a web on the work-piece, and in retaining rolling pressure against the peripheral edge of the work-piece while operating against the sides of the work-piece.

190. The method of rolling or forming a web on heated objects, which consists in rotatably supporting the object, in applying a pair of oppositely-arranged tread or peripheral face rolls against the peripheral face of 130

the object at equal radial distances from the axis of the object so that said axis is always retained centrally between the axes of said face rolls during the rolling process, 5 in applying longitudinally movable and laterally oppositely-arranged shouldered rolls at opposite sides of both the object and one of said face rolls and operating them in contact with the opposite sides of the object to 10 reduce the thickness of the metal of the web portion of the object between said shouldered rolls to desired thickness, in moving said shouldered rolls longitudinally forward or backward, or forward and backward, that is, 15 radially, or substantially so, with respect to the work-piece to cause metal from the web portion of the object to flow toward the center or hub portion and toward the rim or periphery of the object while the object is 20 supported at its peripheral face by said oppositely-arranged face rolls, and in resisting with said face rolls the radial outward pressure caused by said shouldered rolls.

191. The method of rolling or forming a 25 web on heated objects, which consists in rotatably supporting the object, in applying rolling pressure against the peripheral face of the object, in applying lateral rolling pressures against opposite sides of the object 30 with complementary pressure exerted radially, or substantially so, to cause metal of the object to flow toward the center or toward the periphery, or alternately toward the center and periphery of the object, in re- 35 sisting the radial pressures at the periphery of the object caused by the radial or substantially radial pressures exerted at opposite sides of the object, and in confining the lateral outward flow of metal at the marginal portion of the object when causing the 40 metal to flow toward the periphery of the object.

192. The method of rolling or shaping 45 heated ingots, blooms, blanks or other work- pieces into bodies having each a hub portion, a rim portion, and a web connecting said hub and rim portions, which consists in applying rotatable work-supporting centers centrally against opposite sides of the 50 work-piece, in moving a pair of oppositely- arranged peripheral face rolls together and at equal radial distances from the axis of the work-piece toward and against the peripheral face of the same, in applying a 55 pair of longitudinally movable and laterally oppositely-arranged edging and web rolls against opposite sides of the work-piece and at opposite sides of one of said peripheral face rolls and in moving said edging and web rolls longitudinally, that is, alternately toward the hub portion and toward the periphery of the work-piece to 60 reduce the thickness of the web portion and form or shape the hub portion and the inner rim portion and together with said face

rolls roll the marginal or peripheral portion of the work-piece to desired finished shape or form.

193. The method of rolling heated ingots, 70 blooms, blanks or other work-pieces into objects having each a hub portion, a rim portion and a web connecting said hub and rim portions, which consists in supporting the work-piece centrally on rotatable centers or supporting means and rolling the same in 75 the following manner; first,—in applying against opposite sides of the work-piece at one side of its axis, or at one side of its center portion, a pair of longitudinally movable and laterally oppositely-arranged edging and web rolls having each a web reducing roll part and an edging roll part, in moving said rolls longitudinally, that is, radially or approximately radially with respect to the work-piece, alternately toward the hub 80 portion and toward the peripheral or rim portion of the work-piece to reduce the thickness of the metal in the web portion of the work-piece and to cause metal to flow toward the hub portion and toward the rim 90 portion of the work-piece, in continuing the metal in its lateral flow in the hub portion and in the rim portion of the work-piece, and in applying a peripheral face roll against the peripheral face of the work- 95 piece between said edging and web rolls to coat with the latter and roll a rudimentary rim and adjacent web portion; second,—in applying a pair of oppositely-arranged side or finishing rolls to opposite sides of the 100 work-piece at another side of its axis or of its center portion and moving the same toward and against said so rudimentarily formed rim portion, in applying a peripheral face shaping or face finishing roll between said side or finishing rolls against the peripheral face of the so rudimentarily formed rim to coat with said last-mentioned rolls and roll said so rudimentarily formed rim and adjacent web portion to desired finished forms or shapes while said edging and web rolls with their edging roll parts limit the lateral flow of metal in the rim or roll the rim to desired width or lateral thickness.

194. The method of rolling or shaping 115 heated objects into circular form, which consists in centrally and rotatably supporting the object, in applying a pair of laterally oppositely-arranged rolls against opposite sides of the object at one side of its axis, in retaining one of said rolls against one of said sides, in positively rolling the other of said rolls against the other side of the object to roll the same as and where desired, and in applying rolling pressure against the peripheral face of the object.

195. The method of rolling heated ingots, 120 blooms, blanks or other work-pieces into circular form, which consists in rotatably sup- 125

- porting the work-piece, in applying a roll to one of the sides of the work-piece to roll said side as and where desired, in retaining another roll against the other side of the work-piece to roll said other side and support the work-piece against lateral pressure caused by said first-mentioned roll, and in applying a pressure roll against the peripheral face of the work-piece.
196. The method of rolling heated objects into circular form, which consists in rotatably and centrally supporting the object, in applying a longitudinally movable roll or rolls laterally against one of the sides of the object to roll one of the side surfaces to desired shape, and in applying rolling pressure against the peripheral face of the object.
197. The method of rolling circular objects having each a hub, from heated ingots, blooms, blanks or other work-pieces, which consists in centrally and rotatably supporting the work-piece, in applying opposite rolling pressures to opposite sides of the work-piece and on at least one side of the work-piece reducing the thickness of the metal where desired, in confining the lateral flow of metal at both the center or hub portion and the peripheral or rim portion of the work-piece, in applying a rolling stop to determine the diameter of the object and roll the peripheral face thereof, and in rolling the work-piece to the thickness or thicknesses of the finished object.
198. The method of rolling heated ingots, blooms, blanks or other work-pieces into circular form with a hub portion, which consists in supporting the work-piece on rotatable centers or rotatable supporting means, in applying a roll against the outer peripheral face of the work-piece at one side of its axis, in applying a pair of longitudinally movable oppositely-arranged side rolls laterally against opposite sides of the work-piece at the other side of its axis, in laterally retaining one of said pair of side rolls against the work-piece where applied, in reducing the thickness of the work-piece with the other of said pair of side rolls and causing metal to flow toward the central or hub portion of the work-piece, and in rolling the peripheral face of the work-piece with said face roll to circular form.
199. The method of rolling, reworking or reforming the peripheral face, or the peripheral portion of heated work-pieces into the form or shape of the peripheral face of car wheels or other circular objects, which consists in supporting the work-piece, in rotating the work-piece, in subjecting the so rotating work-piece to the action of two or more rolls, in first rolling with one of said rolls said peripheral face to completely beaked or rudimentary form, and in then rolling with the other roll or rolls the so completely beaked or rudimentary formed peripheral face to desired finished form.
200. The method of rolling, reworking or reforming the peripheral face, or the peripheral portion of heated work-pieces into the form or shape of the peripheral face of car wheels or other circular objects, which consists in rotating the work-piece, in compressing the metal at the peripheral face of the work-piece by the action of rolls which first roll the total peripheral face of the work-piece to completely beaked or rudimentary form, or to approximately the finished form, and in then rolling the so completely beaked or so completely rudimentarily formed peripheral face to desired finished form.
201. The method of rolling the peripheral face of heated objects, which consists in supporting the object at its central portion on rotatable centers or supporting means in a fixed central position, in positioning a tread or peripheral face roll a distance from the axis of the object equal to the radius the object is to have when finished, in retaining said face roll at said distance during the rolling process, and in applying a pair of oppositely-arranged longitudinally movable rolls laterally to opposite side of the object and at opposite sides of said face roll to operate against a portion or portions of the object and roll a portion or portions of its opposite sides as and where desired and operate against the inner portion or portions of the rim to force the metal in the rim toward and against said peripheral face roll and to coat with said peripheral face roll to roll the rim portion of the object to desired form or shape and to desired diameter.
202. The method of rolling, reworking or reforming the peripheral face, or the peripheral portion of heated work-pieces into the form or shape of the peripheral face of car wheels or other objects, which consists in rotatably supporting the work-piece, in subjecting the peripheral face of the rotating work-piece to the alternate action of roughing and finishing rolls to first roll the total peripheral face of the work-piece into preliminary or rudimentary shape and then roll the so preliminary or rudimentarily rolled shape of the peripheral face of the work-piece into the desired finished shape of the tread of a car wheel having a flange, or into any other desired shape.
203. The method of rolling the peripheral face of heated objects, which consists in supporting the object at its center portion in a fixed central position on rotatable and axially independently movable work-supporting means, in applying one or more rolls to rotate the object, in applying a pair of oppositely-arranged tread or peripheral face rolls against the peripheral face of the ob-

ject and in causing said rolls to act together or alternately on the object to roll said face to the desired shape.

204. The method of rolling the peripheral face of heated objects, which consists in rotatably supporting the object at its center portion in a fixed central position, in applying a pair of oppositely-arranged tread or peripheral face rolls against the peripheral face of the object and in feeding or moving 10 said rolls alternately or independently of each other during the rolling process toward and from the axis of the object to roll said peripheral face to desired shape and diameter.

205. The method of rolling the peripheral face of heated objects, which consists in rotatably and centrally supporting the object in a fixed central position, in positioning a 20 pair of oppositely-arranged tread or peripheral face rolls equal distances from the center of the object equal to the radius the object is to have when finished, in retaining said face rolls at said distances during the 25 rolling process, in applying oppositely-arranged longitudinally movable rolls to opposite sides of both the object and one of said face rolls to roll a portion or portions of the object as and where desired and 30 to coact with said peripheral face rolls to roll the peripheral face of the object to desired form or shape and to desired diameter.

206. The method of rolling the peripheral face of heated objects, which consists in rotatably supporting the object in a fixed central position, in applying a peripheral face roll movable toward, against and away from the peripheral face of the object against the peripheral face of the rotating 40 object to roll said peripheral face to desired shape and diameter, and in indicating the change or changes in diameter of the object during the rolling process by means of an indicator operatively connected with 45 said face roll and traveling with said movements thereof.

207. The method of rolling the peripheral face of heated objects, which consists in centrally and rotatably supporting the object in a fixed central position, in applying 50 a peripheral face roll, movable toward, against and away from the peripheral face of the object, against said peripheral face to roll the same to desired diameter, and in indicating the desired finished diameter of 55 the object with an indicating device operatively connected with said face roll.

208. The method of rolling the peripheral face of heated objects to desired diameter, 60 which consists in centrally and rotatably supporting the object, in applying a peripheral face roll to the peripheral face of the object to roll the latter to desired shape and diameter and which face roll is movable toward, against and away from said 65

peripheral face and is also movable with either the circumferential reduction or circumferential enlargement of said peripheral face, and in indicating during the rolling process the change or changes in the increasing or in the diminishing diameters of the object and also indicating the finished diameter of the object by means of an indicating finger or pointer of an indicator operatively connected with said face roll and traveling with said movements thereof.

209. The method of rolling the peripheral face of heated objects or work-pieces to desired diameter, which consists in rotatably supporting the work-piece, in subjecting the work-piece to the action of rolls which rotate the work-piece, and in subjecting the peripheral face of the rotating work-piece to the action of rolling means operatively connected with indicating means which roll the peripheral face of the work-piece to desired diameter and simultaneously indicate the change or changes in diameter of the object during the rolling process.

210. The method of rolling the peripheral face of heated objects or work-pieces to desired diameter, which consists in supporting the work-piece, in subjecting the peripheral face of the supported work-piece to the action of rolling means operatively connected with indicating means which roll the peripheral face of the work-piece to a predetermined diameter indicated by said indicating means.

211. The method of rolling the peripheral face of heated objects or work-pieces, which consists in rotatably supporting the work-piece, in rotating the work-piece and in subjecting the rotating work-piece to the action of rolling means operatively connected with indicating means which roll the peripheral face of the work-piece to desired diameter and simultaneously therewith indicate the progressively diminishing diameters of the work-piece.

212. The herein described method of rolling the peripheral face of heated objects or work-pieces to desired diameter, which consists in rotatably supporting the work-piece in a fixed central position, in rotating the work-piece, in subjecting the peripheral face of the rotating work-piece to the action of rolling means operatively connected with indicating means, consisting of a peripheral face roll which operates against the peripheral face of the work-piece and which is movable toward and against and away from said peripheral face and is also movable with either the circumferential reduction or circumferential enlargement of said peripheral face and which rolls said face to desired diameter, and of an indicator which, during the rolling of said peripheral face by means of an indicating finger or pointer of said indicator operatively connected with

said face roll and traveling with said movements of said face roll, indicates the change or changes in diameter of said object or work-piece.

- 5 213. The method of rolling the peripheral face of heated objects or work-pieces, which consists in rotatably supporting the work-piece, in rotating the work-piece and in subjecting the rotating work-piece to the action 10 of rolling means operatively connected with indicating means which roll the peripheral face of the work-piece to desired diameter and simultaneously therewith indicate the increasing diameter or diameters of the 15 work-piece, said indicating means being operated by the movements of said rolling means.

214. The method of rolling the peripheral face of heated objects or work-pieces, which 20 consists in rotatably supporting the work-piece, in subjecting the supported work-piece to the action of rolling means operatively connected with indicating means which rotate and roll the work-piece as and 25 where desired and the peripheral face of the work-piece to desired diameter and simultaneously indicate by a dial the change or changes in diameter of the object or work-piece during the rolling processs.

- 30 215. The method of rolling the peripheral face of heated objects or work-pieces to desired diameter, which consists in rotatably supporting the work-piece, in subjecting the work-piece to the action of rolling means 35 operatively connected with indicating means which rotate the work-piece and roll a portion or portions of the work-piece as and where desired and the peripheral face of the work-piece to desired shape and diameter 40 and simultaneously indicate at a glance the radial position, or the change or changes in the radial position of said face roll from the axis of the work-piece during the rolling process.

- 45 216. The method of rolling the peripheral face of heated objects or work-pieces to desired diameter, which consists in supporting the work-piece, in subjecting the work-piece to the action of rolling means operatively 50 connected with indicating means which roll the work-piece as and where desired and the peripheral face of the work-piece to desired form or shape and diameter and simultaneously indicate at a glance the circumferential reduction or circumferential enlargement of the work-piece during the rolling process.

- 55 217. The method of dishing heated car wheels or other work-pieces, which consists 60 in centrally, axially, and rotatably supporting the work-piece at its center or hub portion, in supporting the work-piece at its marginal or peripheral portion, and in applying dishing pressure axially to the central portion of the work-piece while the

work-piece is being rotated and is supported at its marginal or peripheral portion against said dishing pressure.

218. The method of dishing heated objects or work-pieces, which consists in centrally 70 and axially supporting the work-piece on rotatable and axially independently movable piercers or work-supporting devices, in applying rolls to opposite sides of the marginal or peripheral portion of the work-piece and therewith rotate the work-piece and retain the marginal portion of the work-piece in true alinement, in exerting dishing pressure axially in one direction on said work-supporting devices to cause 80 said devices with the center portion of the work-piece to move axially and dish the work-piece to desired dish while the work-piece is rotated and its marginal portion is retained against said axial movement of its 85 center portion.

219. The method of dishing, undishing, or redishing heated car wheels or other work-pieces, which consists in centrally engaging the work-piece at opposite sides, in rotating 90 the work-piece, in marginally engaging the work-piece at opposite sides, and in applying dishing, undishing or redishing pressure axially in one direction to the central portion of the work-piece to dish, undish or 95 redish the work-piece while the same is rotating and while the marginal portion of the work-piece is retained against said dishing, undishing or redishing pressure.

220. The method of dishing, undishing, or 100 redishing heated car wheels or other work-pieces, which consists in centrally supporting and rotating the work-piece, in marginally supporting the work-piece, and in applying dishing, undishing or redishing 105 pressure axially in one direction to the central portion of the work-piece to move said central portion axially to dish, undish or redish the work-piece while the same is rotating and while its marginal portion is 110 retained against said axial movement of its center portion.

221. The method of dishing or undishing 115 heated car wheels or other work-pieces, which consists in centrally supporting and rotating the work-piece, in applying engaging means to the work-piece at its marginal or peripheral portion, and in applying dishing or undishing pressure laterally in one direction with said engaging means to the 120 marginal or peripheral portion of the work-piece to move said marginal or peripheral portion laterally to dish or undish the work-piece while the same is rotating and while its central portion is retained against said 125 lateral movement of its marginal or peripheral motion.

222. The method of dishing heated work-pieces or car wheels or similar objects, which consists in axially and rotatably sup- 130

- porting the work-piece, in rotating the work-piece, in engaging the work-piece at its marginal or peripheral portion and applying dishing pressure laterally in one direction to said marginal or peripheral portion to dish the work-piece while the same is rotating and while the central portion of the work-piece is retained against said dishing pressure.
223. The method of undishing a heated dished circular object and rolling the same after being undished, which consists in centrally and axially supporting the object at its center portion on rotatable and axially movable work-supporting means, in applying rolls against the marginal or peripheral portion of the object to laterally support and roll and rotate the object, in exerting axial pressure on said work-supporting means while the object is rotated and so laterally supported to cause said work-supporting means to move in one direction and force the central or hub portion of the object into undished position, and in rolling the object where desired to desired form or shape after the undishing operation.
224. The method of undishing, rolling, redishing and again rolling heated dished circular objects, which consists in centrally and axially supporting the object at its center portion on rotatable and axially movable work-supporting means, in applying rolls against the marginal portion of the object to laterally support and rotate and roll the object, in exerting axial pressure on said work-supporting means to cause the same to move axially in one direction and undish the object while the same is so rotated and so laterally supported, in rolling the so undished object where desired to desired form or shape, and in exerting axial pressure on said work-supporting means while the object is so rotated and so laterally supported at its marginal or peripheral portion so as to cause said work-supporting means to move axially in one direction and redish the so rolled object to desired dish, and in finally rolling said marginal or peripheral portion by means of said rolls as and where desired after the dishing operation.
225. The method of undishing, rolling, redishing and again rolling heated dished circular objects, which consists in centrally and rotatably supporting the object, in applying rolling means against the marginal portion of the object to laterally support and rotate and roll the object, in exerting axial pressure in one direction against the center portion of the object while the latter is so rotated and so laterally supported to move the central portion of the object axially in one direction and thereby undish the same, in applying pressure to said rolling means to roll the so undished object where desired to desired form or shape, in exerting axial pressure in the opposite direction against the center portion of the object while the latter is so rotated and so laterally supported to move the central portion of the object in the other direction and thus redish the so rolled object to desired dish, and in finally rolling the marginal or peripheral portion of the object as desired after the dishing operation.
226. The method of dishing heated car wheels or other work-pieces, which consists in axially supporting the work-piece on rotatable and axially movable work-supporting means, in applying side rolls to opposite sides of the marginal or peripheral portion of the work-piece and a peripheral tread or face roll against the peripheral face of the work-piece between said side rolls to coat therewith and together cause the work-piece to rotate and maintain or roll its marginal or peripheral portion in true alinement and shape, in exerting axial pressure on said work-supporting means while said side rolls and peripheral roll are in action so as to cause said work-supporting means with the center or hub portion of the work-piece held in alinement therewith to move axially and dish the work-piece to desired dish, and in maintaining said side rolls and peripheral roll in action after the dishing process.
227. The method of dishing car wheels or the like, which consists in rotating the heated car wheel, in applying centrally thereto at opposite sides thereof pressure elements movable together in the direction of the axis of said car wheel, and in supporting the car wheel against lateral movement at its marginal portion.
228. The method of dishing heated car wheels or similar bodies, which consists in axially supporting the work-piece on rotatable and axially movable work-supporting means, in applying rolls to opposite sides of the marginal portion of the work-piece, in rotating the work-piece, and in applying pressure longitudinally to said axially movable work-supporting means.
229. The method of dishing heated car wheels or similar bodies, which consists in axially supporting the work-piece on rotatable and axially movable work-supporting means, in rotating the work-piece, in causing said axially movable work-supporting means to move together in one direction, and in applying rotating rolls to opposite sides of the marginal portion of the work-piece to cause the same to rotate and to retain the marginal portion of the work-piece or car wheel or similar body in true alinement.
230. The method of dishing car wheels or the like, which consists in supporting the heated work-piece axially by applying alined axles to opposite sides thereof and causing said axles to move together in one

direction, and in applying rotating rolls to opposite sides of the marginal portion of the work-piece to cause the latter to rotate and to retain the marginal portion of the work-piece in true alinement.

231. The method of dishing heated objects having each a rim and a web portion, which consists in applying rotatable and axially movable centers or work-supporting means centrally to the object, in the use of two sets of rolls adapted to be applied to the marginal or peripheral portion of the object, in subjecting the object to the action of one set of said rolls to marginally support and rotate the object and roll the inner peripheral surface of the rim and adjacent web portion to a rudimentary shape having extra metal on the inner rim portion required to make the greater radial length of the web in its dished form, in then exerting axial pressure on said work-supporting means to cause the same to move axially and dish the object to desired dish while the object is so rotated and so laterally supported at its marginal or peripheral portion, and in applying the other set of said rolls against the so rudimentarily shaped inner peripheral surface of the rim and adjacent portion of the web at another point of said marginal or peripheral portion of the object and roll said extra metal from the inner rim portion onto the web portion during said dishing operation.

232. The method of dishing heated objects having each a rim and a web portion, which consists in centrally and rotatably supporting the object, in applying rolling pressure to the object at opposite sides thereof and at one side of the axis of the object to marginally support and rotate the object and roll the inner peripheral surface of the rim and the adjacent portion of the web of the object to rudimentary shape having extra metal on the inner rim portion, in then exerting axial pressure in one direction to the center or center portion of the object to dish the object to desired dish while rotated and laterally supported at its marginal portion and in applying rolling pressure against the so rudimentarily shaped inner peripheral surface of the rim and adjacent portion of the web at another point of said marginal portion and roll said extra metal from the rim portion onto the web portion during the dishing operation.

233. The method of dishing heated objects or work-pieces, which consists in centrally, axially, and rotatably supporting the work-piece, in applying rotating rolls to opposite sides of the marginal or peripheral portion of the work-piece and therewith causing the marginal portion of the work-piece to be retained in true alinement while at the same time said rolls rotate the work-piece, in exerting dishing pressure on one

of said rolls to cause said marginal portion of the work-piece with the other of said rolls to move in the direction of or parallel to the axis of the work-piece and dish the work-piece to desired dish while the work-piece is rotating and while the center portion of the work-piece is retained against said movement of said marginal portion.

234. The method of dishing, undishing or redishing heated car wheels or other work-pieces, which consists in centrally engaging the work-piece at opposite sides, in rotating the work-piece, in marginally engaging the work-piece at opposite sides, and in applying lateral pressure in one direction to the marginal portion of the work-piece to move said marginal portion into the position of a dished, undished or redished work-piece while the same is rotating and while the central portion of the work-piece is retained against said lateral movement of its marginal portion.

235. The method of dishing, undishing or redishing heated work-pieces, which consists in applying engaging means centrally to opposite sides of the work-piece, in applying marginal engaging means to opposite sides of the work-piece, in rotating the work-piece, and in forcing one of said engaging means axially, or laterally, in one direction while retaining the other engaging means immovable in such direction.

236. The method of dishing, undishing or redishing heated work-pieces, which consists in applying engaging means centrally to opposite sides of the work-piece, in applying engaging means marginally to opposite sides of the work-piece, in rotating the work-piece, and in moving said engaging means relatively in the direction of or parallel to the axis of the work-piece.

237. The method of dishing, undishing or redishing heated work-pieces, which consists in applying engaging means centrally to one side of the work-piece, in applying rotating engaging means marginally to the other side of the work-piece, and in moving said engaging means relatively in the direction of or parallel to the axis of the work-piece.

238. The method of dishing, undishing or redishing heated work-pieces, which consists in applying engaging means centrally to one side of the work-piece, in applying rotating engaging means marginally to the other side of the work-piece, and in moving one of said engaging means in the direction of or parallel to the axis of the work-piece while the work-piece is rotating and while retaining the other engaging means against said movement.

239. The method of rolling and dishing, redishing or undishing heated objects, which consists in rotatably supporting the object, in applying lateral pressure means against

- opposite sides of the object at its center and at its marginal portion, in rotating the object and in exerting pressure laterally in one direction by means of one of said pressure means while retaining the other in a fixed rotatable position. 70
240. The method of dishing, undishing or redishing heated objects, which consists in rotating the object and subjecting the same while rotating to the action of dishing, undishing or redishing means, and therewith dish, undish or redish the object while the same is rotating. 75
241. The method of undishing heated objects, which consists in applying rolls against the marginal or peripheral portion of the object and rotating and laterally supporting the object with said rolls at its said marginal or peripheral portion, and in exerting undishing pressure axially against the central portion of the object in one direction while the object is so rotating and is so laterally supported at its marginal or peripheral portion to force the central portion of the object into the position of an undished object. 80
242. The method of undishing heated objects, which consists in rotatably supporting the object, in applying rolls against the marginal or peripheral portion of the object and therewith rotating the same, and in exerting undishing pressure with said rolls in one direction parallel or practically parallel to the axis of the object to cause said marginal portion of the object while the same is rotating to move parallel to or coaxial with the axis of the object into the position of an undished object while the central portion of the object is retained against said movement of said marginal portion. 85
243. The method of undishing heated objects, which consists in supporting the object at its center portion on axially movable supporting means, in supporting and rotating the object at its marginal or peripheral portion, and in exerting pressure lengthwise or axially in one direction by means of said supporting means to force the central portion and web into undished position. 90
244. The method of dishing heated objects having each a rim and a web, which consists in centrally and marginally supporting the object and rotating the same, and in exerting pressure laterally against the object in one direction either at the central point or marginally. 95
245. The method of dishing heated objects having each a rim and adjacent web portion, which consists in centrally and marginally supporting the object, in rotating the object, and in exerting pressure laterally at the margin or rim of the object while retaining the central portion of the object in a fixed rotatable position. 100
246. The method of dishing heated ob- 105
- jects having each a rim and a web, which consists in rotating the object, in centrally and marginally supporting the object, and in exerting pressure laterally at the center of the object while retaining the marginal portion of the object in a fixed rotatable position. 110
247. The method of dishing and rolling car wheels or the like to true circular form after dishing, which consists in rotating the heated car wheel, in applying pressure to the central portion of the car wheel in one direction to dish the same, in supporting and retaining the marginal portion of the car wheel in true alinement while dishing the same, and in applying rolling pressure to the peripheral face of the car wheel after the dishing operation. 115
248. The method of dishing heated objects and rolling the same at their marginal or peripheral portion to desired form or shape after dishing, which consists in centrally and axially supporting the object on rotatable and axially movable centers or work-supporting means, in applying rolling pressures against opposite sides of the object at its marginal or peripheral portion to laterally support and cause the object to rotate, in exerting axial pressure on said work-supporting means while the object is rotated and laterally supported at its marginal portion so as to cause the work-supporting means to move axially and dish the object to desired dish, and in applying rolling pressure against the peripheral face of the object complementary to the rolling pressure applied to the opposite sides of the object and roll the marginal or peripheral portion of said object to desired form or shape after dishing. 120
249. The method of rolling heated objects at their marginal or peripheral portion, then dishing the objects and finally rolling the same at their marginal or peripheral portion, which consists in centrally and axially supporting the object on rotatable and axially movable centers or supporting means, in applying rolls against the object at its marginal or peripheral portion to marginally support and rotate and roll the object to desired form or shape, in exerting axial pressure on said supporting means while the object is so rotated and so laterally supported at its marginal portion to cause the supporting means to move axially and dish the object to desired dish, and in operating said rolls against the marginal or peripheral portion of the object to roll the same to desired form or shape after dishing. 125
250. The method of rolling, dishing and rolling heated objects after dishing, which consists in rotatably supporting the object, in laterally supporting the object at its marginal portion, in rotating and rolling the object where desired to desired form or shape, 130

in dishing the object to desired dish while the same is rotated and laterally supported at its marginal or peripheral portion, and in rolling the so dished object.

251. The herein described method of dishing car wheels or other work-pieces, consisting in rotating the heated work-piece and in dishing the same during rotation and rolling metal from its inner rim portion onto its web portion while dishing the work-piece to make up the additional length of the web in the dished wheel.

252. The herein described method of dishing car wheels or other work-pieces, consisting in rotating the heated work-piece and in dishing the same during rotation simultaneously with rolling or working metal from its inner rim portion onto its web portion.

253. The method of dishing car wheels or other work-pieces, which consists in dishing the heated work-piece while rotating the same and during the dishing working metal from its inner marginal or inner rim portion onto its web portion to make up the additional length of the web in the dished work-piece.

254. The method of dishing car wheels or other work-pieces, which consists in dishing the heated work-piece while rotating the same and during the dishing working metal from its inner marginal or inner rim portion onto its web portion.

255. The herein described method of dishing heated work-pieces or car wheels or similar objects, consisting in subjecting the work-piece to dishing and rolling processes which dish the same during rotation and roll metal from its inner rim portion onto its web portion while dishing the work-piece to make up the additional length of the web in the dished wheel.

256. The method of rolling car wheels from heated ingots, blooms, blanks or other work-pieces, which consists in centrally and rotatably supporting the work-piece, in subjecting the work-piece while so supported to the action of rolls rolling the work-piece into the form of a rudimentary car wheel, and in then rolling said so rudimentarily formed car wheel to the desired form and shape of the finished car wheel.

257. The method of rolling heated ingots into car wheels, which consists in rotatably supporting the object and subjecting the object to the action of a set of roughing rolls and a set of finishing rolls to first roll the object into a rudimentary car wheel with hub, web and rudimentary rim portion, and to then roll said rudimentary car wheel to the desired finished form or shape.

258. The method of rolling heated objects into car wheels, which consists in rotatably supporting the object, in applying a set of roughing rolls to the sides and peripheral

face of the object at one point thereof to roll the object into a rudimentary car wheel with hub, web and rudimentary rim portion, and in applying a set of finishing rolls at another point of the object to roll said rudimentary car wheel to desired finished form or shape.

259. The method of rolling heated objects into circular bodies, which consists in rotatably supporting the object, in subjecting the object to the alternate actions of roughing and finishing rolls to first roll the object into desired preliminary form and to then roll the so preliminarily formed object into the desired finished form or shape.

260. The herein described method of making car wheels or other circular bodies, consisting in subjecting the heated work-piece to the action of rolls and therewith rolling and forming alternately the hub to desired form, the web to desired thickness, the rim to desired lateral thickness and the inner circumferential face or faces of the rim to rudimentary form and its outer or peripheral face to beaked or rudimentary form, and in then subjecting the so rolled work-piece to the action of finishing rolling and dishing processes which roll said rudimentarily formed rim to finished form simultaneously with shaping or dishing the work-piece to dished form.

261. The method of rolling and dishing heated work-pieces having each a hub portion, a rudimentary rim portion and a web connecting said hub and rim portions, into car wheels, which consists in rotatably supporting the work-piece, in applying a pair of oppositely-arranged rolling rolls against opposite sides of the rudimentary rim portion of the work-piece to rotate and roll the same as and where desired, in applying a peripheral tread or face shaping roll between said pair of rolling rolls to coat with the latter to roll said rudimentary rim into desired finished form or shape, and in dishing the work-piece at the same time while the work-piece is rotating to desired dish, and if desired in also rolling the marginal or peripheral portion of the work-piece as desired after dishing.

262. The method of rolling or forming car wheels or similar bodies, which consists in rotatably supporting the heated work-piece, in subjecting the so supported work-piece to the action of rolls to roll or form the work-piece to desired undished form, and in then subjecting the so formed work-piece while the same is rotating to the action of dishing means and thereby dish the same to the desired form or shape of the dished car wheel or other similar dished body.

263. The method of rolling or forming car wheels from heated car wheel blanks or other work-pieces, which consists in rotatably supporting the work-piece, in applying rolling means to the work-piece to roll or

form the work-piece into the form of an undished object, and in then subjecting the so formed object while the same is rotating to the action of dishing means and thereby 5 dish the same to desired dish of the car wheel.

264. The method of rolling heated objects into circular form with a hub portion, which consists in rotatably supporting the object, 10 in applying rolling pressures laterally against the sides of the object, in applying pressure at one side of the object in radial, or substantially radial lines complementary to the pressure exerted laterally, and in confining the lateral flow of metal at the inner 15 limits of said radial flow of metal.

265. The method of rolling heated objects into circular form with a hub portion, which consists in rotatably supporting the object, 20 in applying rolling pressure laterally against one side of the object, and pressure radially, or substantially radially, complementary to the lateral pressure to form the hub portion, and in confining the lateral 25 flow of metal at the hub portion.

266. The method of rolling heated objects into circular form with a hub portion, which consists in applying shouldered centers or 30 piercers axially, or substantially so, against the object, in applying rolling pressures laterally against the sides of the object, in applying pressures against the object in radial, or substantially radial lines complementary to the pressures exerted laterally to 35 force metal at opposite sides of the object against the peripheral face or faces of said centers or piercers and against the shoulders thereof.

267. The method of rolling heated objects 40 into circular form with a hub portion, which consists in applying a shouldered center or piercer axially, or substantially so, against the object, in applying lateral pressure against one side of the object at a radial distance from said center or piercer, and in 45 applying pressure against the object in radial, or substantially radial lines complementary to the pressure exerted laterally, to force metal at said side of the object against the peripheral face of said center or piercer 50 and against the shoulder thereof.

268. The method of rolling or forming car wheels or similar objects from heated ingots, blooms, blanks or other work-pieces 55 having each about the volume or weight of the finished rolled car wheel or other finished rolled object, which consists in centrally piercing or penetrating or centering and rotatably supporting the work-piece, in applying oppositely-arranged longitudinally 60 movable rolls laterally against opposite sides of the work-piece and moving said rolls in radial or in practically radial lines with respect to the work-piece, or substantially 65 so, forward or backward, or forward

and backward to cause metal to flow in the directions of said movements and roll or form the web and alternately the hub and rim, in simultaneously with or during said action of said rolls causing a face roll positioned between said rolls to act against the peripheral face of the work-piece and roll the same to desired shape or form and also limit the radial flow of metal toward the periphery of the work-piece, and in limiting 70 the lateral flow of metal in said rim with said first-mentioned rolls.

269. The method of rolling or forming car wheels or other circular objects from heated ingots, blooms, blanks or other work-pieces having each about the volume or weight of the finished rolled car wheel or other finished rolled object but being larger in diameter than the finished rolled car wheel or other finished rolled object is to 80 be, which consists in centrally piercing or penetrating or centering and rotatably supporting the work-piece, in applying laterally oppositely-arranged longitudinally 85 movable edging and web rolls against opposite sides of the work-piece and moving said rolls longitudinally, that is, in radial lines with respect to the work-piece, or substantially so, forward or backward, or forward and backward to cause metal to flow in the 90 directions of such movements to form the web, the hub and the inner circumferential face or faces of the rim, in simultaneously with or during the action of said edging and web rolls causing a face roll positioned between said edging and web rolls to act against the peripheral face of the work-piece and together with said edging and web rolls roll or work the metal in the rim 95 and adjacent web portions of the work-piece simultaneously upon all its surfaces situated in a plane passing laterally through the work-piece and at the same time cause metal to be forced toward the inner region of the rim and toward the axis of the work-piece simultaneously with rolling the work-piece to desired diameter.

270. The method of rolling or forming car wheels or other circular bodies from heated ingots, blooms, blanks or other work-pieces having each about the volume or weight of the finished rolled car wheel or other finished rolled object but being smaller in diameter than the finished rolled wheel or other finished rolled object is to be, which 100 consists in centrally piercing or penetrating or centering and rotatably supporting the work-piece, in applying laterally oppositely-arranged longitudinally 105 movable edging and web rolling rolls to opposite sides of the work-piece and forcing or rolling said rolls laterally into the sides of the work-piece and also moving said rolls longitudinally, that is, in radial lines with respect to the work-piece, or substantially so, forward or 110

115 forward or backward, or forward 120

125

130

- backward, or forward and backward to cause metal to flow in the directions of said movements and form the web, the hub and the inner circumferential face or faces of the rim and also roll the opposite sides of the marginal or rim portion, or limit the lateral flow of metal in the marginal or peripheral portion of the work-piece, thereby causing the desired amount of metal to flow toward the periphery of the work-piece to enlarge its diameter, and simultaneously with or during the action of said edging and web rolling rolls causing a face rolling roll positioned between said edging and web rolling rolls to act against the peripheral face of the work-piece and together with said edging and web rolling rolls roll the rim of the work-piece to desired form or shape and to desired diameter.
271. The method of rolling or forming car wheels or other circular bodies from heated ingots, blooms, blanks or other work-pieces, which consists in centrally piercing or penetrating or centering the work-piece at its opposite sides to form therein a rudimentary bore, or a part or parts thereof and also support the work-piece, in simultaneously applying opposite rolling pressures laterally against opposite sides of the work-piece between its axis and periphery to roll and rotate the work-piece and together with rolling pressures applied radially toward the axis of the work-piece while so rolling and rotating the work-piece causing metal from the rolled region together with metal from the pierced or penetrated region to flow outward laterally at the central portion of the work-piece and form the hub, or a part thereof, and in applying radial pressure against the peripheral face or tread portion of the rotating work-piece to roll said peripheral face to desired form or shape.
272. The method of making or rolling or forming car wheels or the like from heated ingots, blooms, blanks or other work-pieces, which consists in centrally piercing or penetrating the work-piece to form a rudimentary bore, or a part or parts thereof, in applying rolls to opposite sides of the work-piece to rotate and roll the same, in moving said rolls in radial lines, or substantially so, to cause metal to flow in the directions of such movements, in applying a peripheral face roughing roll to the peripheral face of the work-piece to roll the same into rudimentary form or shape, in applying pressure in one direction to the hub portion of the work-piece thus far formed and retaining the marginal portion of the work-piece in alinement, and in finally applying a peripheral face finishing roll against the so rudimentarily shaped peripheral face of the work-piece and finishing the same to desired finished form or shape.

273. The method of making or rolling car wheels or the like from heated ingots, blooms, blanks or other work-pieces, which consists in centrally piercing or penetrating the work-piece to form a rudimentary bore, or a part or parts thereof, in applying rolling pressures to the sides of the work-piece to rotate and roll the same, in applying pressures in radial lines, or substantially so, complementary to said rolling pressures to cause metal to flow in the directions of said radial pressures, in applying rolling pressure to the peripheral face of the work-piece to roll the same into rudimentary form or shape, in applying pressure in one direction to the hub portion of the car wheel or the like thus far formed and in retaining the marginal portion of the car wheel or the like thus far formed in alinement to cause said car wheel or the like to be dished, and in finally applying rolling pressures to the so rudimentarily shaped peripheral face of the car wheel or the like and finish the same to desired form or shape.

274. The method of rolling the marginal or rim portion of heated work-pieces having each a central portion, a rim portion and a web connecting said central and rim portions, into a car wheel having a rim with flanged tread, which consists in rotatably supporting the work-piece, in applying a pair of oppositely-arranged side rolls to opposite sides of the rim portion of the work-piece at one point of its rim portion, in applying a peripheral tread or face shaping roll between said side rolls to coat with the latter and roll the inner peripheral face or faces of said rim portion to desired form or shape and the peripheral face of the work-piece to the desired finished form or shape of a flanged car wheel tread, and at the same time applying a pair of oppositely-arranged edging rolls to opposite sides of the work-piece at another point of its rim portion to operate upon the edges of the rim and roll the same to its desired width while said side rolls and peripheral roll are in action, and in simultaneously dishing the work-piece to desired dish.

275. The method of rolling the marginal or peripheral portion of heated work-pieces having each a hub portion, a rudimentary rim portion and a web connecting said hub and rim portions, and dishing the work-piece, which consists in axially supporting the work-piece on rotatable and axially movable work-supporting means, in applying oppositely-arranged side rolls to opposite sides of the work-piece against its rudimentary rim portion to laterally support the work-piece at its said rim portion and rotate and roll the work-piece, in applying a tread or peripheral face roll against the peripheral face of the work-piece between said side rolls to coat with the latter and together

roll the work-piece at its marginal or rudimentary rim portion to desired form or shape, and in simultaneously exerting axial pressure in one direction on said work-supporting means while the work-piece is being rotated and rolled and laterally supported at its marginal or rim portion so as to cause said work-supporting means with the center or hub portion of the work-piece held in alignment therewith to move axially and dish the work-piece to desired dish.

276. The method of rolling or forming car wheels or similar bodies from heated ingots, blooms, blanks or other work-pieces, which consists in centrally piercing or penetrating the work-piece at its opposite sides to form a rudimentary bore, or a part or parts thereof, in the use of the metal from the pierced or penetrated region to form another part of the work-piece or wheel or similar body, in applying opposite rolling pressures laterally to opposite sides of the work-piece between its axis and periphery, in simultaneously applying pressures toward the axis of the work-piece complementary to said lateral rolling pressures to cause metal from the rolled region to flow toward the central portion of the work-piece and thus together with metal from said pierced portion complete the hub, and in applying pressure to the peripheral face of the rotating work-piece to roll the same to desired form or shape.

277. The method of rolling or forming car wheels or other circular bodies from heated ingots, blooms, blanks or other work-pieces, which consists in centrally piercing or penetrating or centering the work-piece at its opposite sides to form a rudimentary bore, or a part or parts thereof and cause metal to flow away from the pierced region to form another part of the work-piece or wheel or circular body, in applying oppositely-arranged longitudinally movable shouldered rolls laterally against opposite sides of the work-piece at points between the axis and periphery of the work-piece to roll and rotate the same, in moving said shouldered rolls longitudinally, that is radially with respect to the work-piece, or substantially so to cause metal to flow toward the hub portion or toward the rim portion, or in so moving said shouldered rolls forward and backward to cause metal to flow toward the hub and toward the rim portion of the work-piece, in confining the metal in its lateral flow at the hub portion and at the rim portion, and in applying rolling pressure between said shouldered rolls to the peripheral face of the work-piece to roll the same to desired form or shape.

278. The method of piercing and rolling heated ingots, blooms, blanks or other work-pieces into the form of wheels or circular objects having each a hub, a web and a rim,

which consists in centrally piercing or penetrating the work-piece, in applying longitudinally movable and laterally oppositely-arranged rolls against opposite sides of the work-piece and moving said rolls longitudinally forward and backward, that is, in radial lines with respect to the work-piece, or substantially so to cause metal to flow in the directions of such movements to form the hub, the web and the inner circumferential face or faces of the rim, in limiting the lateral flow of the metal in the rim by means of said rolls, in limiting the lateral outward flow of metal in the hub portion, in limiting the flow of the metal toward the periphery, and in rolling the peripheral face of the work-piece to desired form.

279. The method of rolling heated work-pieces to desired size and to true circular form, which consists in centrally supporting the work-piece on rotatable supporting means in a fixed central position, in applying a pair of laterally oppositely-arranged and longitudinally movable edging and web rolls against opposite sides of the work-piece at its marginal portion to rotate the work-piece and prevent lateral flow of metal, and in applying rolling pressure to the work-piece at its peripheral face between said edging and web rolls to condense the metal and together with said edging and web rolls reduce or increase the diameter of the work-piece and roll the same to desired size and to a true circle or circles.

280. The method of rolling heated work-pieces having each a rim to desired diameter, which consists in centrally supporting the work-piece on rotatable supporting means in a fixed central position, in applying the peripheral faces of a pair of laterally oppositely-arranged and radially-positioned longitudinally movable shouldered rolls against opposite sides of the work-piece so as to rotate the same and to prevent lateral outward flow and undesired radial inward flow of the metal in the rim of the work-piece, and in applying rolling pressure against the peripheral face of the work-piece between said shouldered rolls to condense the metal and together with said shouldered rolls reduce or increase the diameter of the work-piece and roll the same to desired diameter.

281. The method of rolling or forming or shaping heated ingots, blooms, blanks or other work-pieces into car wheels or circular bodies having each a hub portion, a rim or flanged rim portion and a web connecting said hub and rim portions, which consists in rotatably supporting the work-piece, in applying against the opposite sides of the work-piece at one side of its axis, or at one side of its center portion, a pair of lengthwise movable oppositely-arranged edging and web rolling rolls arranged with their axes

parallel or inclined to the sides of the work-piece, in rolling or forcing said rolls laterally into the sides of the work-piece and moving said rolls lengthwise forward or backward, or forward and backward to roll or form the hub, or part thereof, the web and the inner circumferential face or faces of the rim portion and roll the rim portion to its desired lateral thickness and also maintain said lateral thickness during the operating process, and in causing a face beaking or face roughing roll positioned between said edging and web rolls to act against the outer peripheral face of the rim portion of the work-piece and together with said edging and web rolls roll the total outer peripheral face of the rim portion of the work-piece to beaked or rudimentary form, and in then applying a peripheral face finishing roll against the so completely beaked peripheral face of the work-piece at the other side of its axis, or at the other side of its hub portion, and therewith roll said completely beaked peripheral face to the shape of a flanged tread or to any other desired suitable shape.

282. The method of rolling or shaping heated car wheel blanks or other work-pieces into car wheels or circular bodies having each a hub portion, a rim or flanged rim portion and a web connecting said hub and rim portion, which consists in rotatably supporting the work-piece, in applying a pair of longitudinally movable oppositely-arranged rotating side rolls laterally against opposite sides of the work-piece and operating them to roll or form or shape the hub as desired, the web to desired thickness, the inner circumferential face or faces of the rim to desired form or shape and the lateral thickness of the rim to desired thickness, in simultaneously with or during the action of said side rolls causing a face beaking or face roughing roll positioned between said side rolls to act against the peripheral face of the work-piece and together with said side rolls so roll said inner circumferential face or faces and said lateral thickness of the rim of the work-piece and roll its peripheral face to completely beaked or rudimentary form, and in then applying a peripheral face finishing roll against said so completely beaked or rudimentarily formed peripheral face and rolling said face to the desired shape of a flanged tread or to any other desired suitable shape.

283. The method of rolling or forming car wheels or circular objects having each a hub portion, a rim or flanged rim portion and a web connecting said hub and rim portions, from heated ingots, blooms, blanks or other work-pieces having each a thickness which is less than is the length of the hub in the finished rolled wheel or other finished rolled object, which consists in axi-

ally moving and forcing under power or pressure a pair of aligned and rotatably mounted and axially independently movable piercers or work-supporting members against the work-piece at opposite sides thereof so as to support the work-piece during the hub rolling or hub forming process, in applying lengthwise movable oppositely arranged rotating side rolls against opposite sides of the work-piece arranged with their axes inclined or parallel to the sides of the work-piece and positioning said side rolls at a proper radial distance or distances from the axis of the work-piece, in forcing or rolling said side rolls laterally into the sides of the work-piece and also moving them lengthwise in a direction toward the axis of the work-piece while rotating the work-piece and at the same time applying piercing pressure to said piercing or work-supporting members so as to pierce or penetrate or center the work-piece and firmly support the same during the further operating process and said rolling and piercing process cause metal from said rolled and pierced portions of the work-piece to flow outward laterally between said work-supporting members and said side rolls and thus roll or form the hub to desired form or shape and to desired length, in moving said side rolls lengthwise toward the peripheral portion of the work-piece, in simultaneously with or during said action of the side rolls causing a face or tread shaping roll positioned between said side rolls to act against the peripheral face of the work-piece and together with the side rolls roll said rim portion of the work-piece to desired form or shape.

284. The method of rolling or forming car wheels or circular bodies having each a hub portion, a rim or flanged rim portion and a web connecting said hub and rim portion, from heated ingots, blooms, blanks or other work-pieces having a thickness which is the same or somewhat greater than is the length of the hub in the finished rolled wheel or other finished rolled body, which consists in axially moving and forcing under power or pressure a pair of aligned and rotatably mounted and axially independently movable piercers or work-supporting centers against the work-piece at opposite sides thereof and also centrally support the same, in applying longitudinally movable oppositely-arranged rotating side rolls laterally against opposite sides of the work-piece at a proper radial distance or distances from the axis of the work-piece, in forcing said rotating side rolls laterally into the sides of the work-piece to desired depth or depths while rotating the work-piece, in applying piercing or centering pressure to said piercing or work-supporting centers, while the work-piece is rotating, to pierce or penetrate or center the work-piece and to

gether with said side rolls cause metal in the central portion of the work-piece to flow outward laterally between said piercers or supporting centers and said side rolls and thus complete the hub, and in applying a peripheral face or tread shaping roll to the peripheral face of the work-piece between portions of said rotating side rolls and together with said rotating side rolls rolling the marginal or peripheral portion of the work-piece to desired form or shape.

285. The method of rolling or forming car wheels or other circular bodies from heated ingots, blooms, blanks or other work-pieces, which consists in subjecting the work-piece to the action of oppositely-arranged piercers or work-supporting centers provided with circumferential flanges or shoulders and which piercers or centers centrally pierce or penetrate the work-piece at its opposite sides to form the rudimentary bore, or a part or parts thereof, of predetermined depth or depths and also support the work-piece and so that when so pierced or penetrated and supported said shoulders of said piercers or centers are spaced from the sides of the work-piece the proper distances or somewhat more than the proper distances required to make up the length which the hub of the wheel is to have when finished, in applying oppositely-arranged longitudinally movable side rolls laterally to opposite sides of the work-piece to rotate and to reduce the metal in the work-piece at the points of contact of said side rolls, in moving said side rolls lengthwise in either direction, or alternately in both directions, to cause metal to flow toward the central portion and then toward the peripheral portion of the work-piece, in limiting the lateral outward flow of metal in the center or hub portion with the shoulders of said piercers or centers and in the peripheral portion of the work-piece with said side rolls, and in applying rolling pressure to the peripheral face of the work-piece to roll the same to desired form or shape.

286. The method of rolling heated ingots, blooms, blanks or other work-pieces into objects having each a hub portion, a rim portion and a web connecting said hub and rim portions, which consists in supporting the work-piece centrally on rotatable centers or supporting means in a fixed central position, in applying laterally against opposite sides of the work-piece a pair of oppositely-arranged longitudinally movable edging and web rolls having each a web reducing roll part and an edging roll part and having their axes parallel or inclined to the sides of the work-piece, in moving said edging and web rolls longitudinally, that is, radially or approximately radially with respect to the work-piece, alternately toward the hub portion and toward the peripheral

portion of the work-piece to cause the web reducing roll parts of said rolls to reduce the thickness of the web portion of the work-piece to form the web and to cause metal to flow toward the axis of the work-piece to form the hub and toward the periphery of the work-piece to form the rim portion, in limiting the lateral flow of metal in the portion of the work-piece between the web reducing roll parts of said edging and web rolls and the periphery of the work-piece and operating upon opposite sides of said portion of the work-piece by means of the edging roll parts of said edging and web rolls, in applying a peripheral face roll between said edging and web rolls to coact with the latter to completely shape the rim and peripheral face of the work-piece to desired form, and in confining the metal in its lateral flow at the hub.

287. The method of rolling car wheels or other circular bodies from heated ingots, blooms, blanks or other work-pieces, which consists in moving and forcing a pair of alined and rotatably mounted piercers or work-supporting members against or into the opposite sides of the work-piece to centrally pierce or penetrate or center the work-piece and also to support the same during the rolling or operating process, in applying a pair of oppositely-arranged longitudinally movable roughing rolls laterally against opposite sides of the work-piece and operate them to roll the web and hub portions as desired and the inner circumferential face or faces of the rim portion to rudimentary forms or shapes, in simultaneously with or during the action of said roughing rolls causing a face beaking or face roughing roll positioned between said roughing rolls to act against the peripheral face of the work-piece to roll said face to completely beaked or rudimentary shape, and in then applying a pair of oppositely-arranged finishing rolls laterally to opposite sides of the work-piece to roll the so rudimentarily shaped inner circumferential face or faces of the rim to finished forms or shapes and a peripheral face finishing roll against the so beaked or rudimentarily formed peripheral face of the work-piece to roll the same to the desired form or shape.

288. The method of rolling car wheels or other circular bodies from heated ingots, blooms, blanks or other work-pieces, which consists in centrally piercing or penetrating or centering the work-piece with alined oppositely-arranged rotatably mounted and axially movable piercing or work-supporting means and also supporting the work-piece thereon, in applying a pair of oppositely-arranged longitudinally movable roughing rolls laterally against opposite sides of the work-piece and a face beaking or face roughing roll to the peripheral face

of the work-piece to roll or form the work-piece or a portion or portions thereof as and where desired and the marginal portion or rim and adjacent web portion of the work-piece to rudimentary form, and in then applying a pair of oppositely-arranged finishing rolls to the opposite sides and a peripheral face finishing roll to the peripheral face of the so rudimentarily formed rim and adjacent web portion of the work-piece and roll said so rudimentarily formed rim and adjacent web portion of the work-piece to the desired form or shape of the rim of a car wheel with a flanged tread or to any other suitable desired form or shape.

289. The method of rolling car wheels or similar bodies from heated ingots, blooms, blanks or other work-pieces, which consists in centrally piercing or penetrating the work-piece to form the rudimentary bore of the car wheel, or a part or parts thereof, in applying oppositely-arranged longitudinally movable side rolls laterally to opposite sides of the work-piece to roll and rotate the work-piece and moving said rolls longitudinally, or substantially so, to cause metal in the work-piece to flow in the directions of such movements, or substantially so, in applying a peripheral face beaking or face roughing roll to the peripheral face of the work-piece to roll said face to a beaked or rudimentary shape, and in then applying oppositely-arranged finishing side rolls to opposite sides of the work-piece to roll the inner peripheral surface or surfaces of the rim and adjacent web portion to desired forms or shapes and a face finishing roll to the so beaked or rudimentarily rolled peripheral face of the work-piece to roll the same to desired form or shape of a flanged car wheel tread or to any other desired form or shape.

290. The method of making or rolling car wheels or similar bodies from heated ingots, blooms, blanks or other work-pieces, which consists in centrally piercing or penetrating the work-piece and forcing metal from the pierced or penetrated portion into another portion of the work-piece, in applying oppositely-arranged side rolls laterally to opposite sides of the work-piece and moving at least one of said rolls longitudinally in radial or approximately radial lines with respect to the work-piece to cause metal in the work-piece to flow in the directions of such movements and form the web, and alternately the hub and a rudimentary rim portion, in applying a peripheral face beaking or face roughing roll to the peripheral face of the work-piece to form in embryo the tread and flange of the car wheel or to form said face to rudimentary form or shape, and in then applying finishing side rolls to opposite sides of the work-piece to roll the web or part thereof and the inner peripheral surface of the rim of the work-

piece to desired form or shape and applying a peripheral face finishing roll to the said embryonically or rudimentarily formed peripheral face of the work-piece to roll said face to the form or shape of the flange and tread of the car wheel or to any other form or shape desired.

291. The method of rolling and indicating the desired limits of radial rolling at opposite sides of heated work-pieces while the work-piece is supported at its center portion on rotatable work-supporting means, which consists in applying laterally oppositely-arranged and longitudinally movable roll shafts having rolls at opposite sides of the work-piece, in forcing said rolls laterally into the metal of the work-piece by lateral movements of said shafts, in moving said rolls radially with respect to the work-piece by moving said shafts longitudinally and in indicating the extent of longitudinal movements of said shafts to determine the outer and inner limits of the radial movements of said rolls.

292. The method of rolling and indicating the desired limits of radial rolling operation on heated work-pieces while the work-piece is rotatably supported, which consists in applying a side roll to one of the sides of the work-piece, in moving said side roll radially with respect to the work-piece, and in indicating the extent of said radial movement of said roll.

293. The method of rolling and indicating the point of commencement and the desired limits of radial rolling operation on heated work-pieces while the work-piece is rotatably supported, which consists in applying a rolling element under pressure against one of the sides of the work-piece at a point a certain radial distance from the axis thereof, in moving said rolling element inwardly and outwardly from said point in radial, or substantially radial lines, in indicating at a distance from said rolling element the point of commencement of said radial operations and the outer and inner limits thereof.

294. The method of rolling or reworking new or worn heated car wheels, which consists in centrally supporting the car wheel in a fixed central position for rotation on a pair of aligned oppositely-arranged and axially independently movable supporting means, in applying longitudinally movable and oppositely-arranged rotating shouldered rolls laterally to opposite sides of the car wheel against the inner circumferential face or faces of its rim and in contact with the opposite sides of its rim and positioning a rolling stop member between said shouldered rolls to govern the extent to which the diameter of the wheel is to be enlarged, and in then moving said rolls longitudinally away from the axis of the car wheel to force metal in the rim toward and

against said rolling stop and rolling the wheel to such diameter and to true circular form while maintaining the required lateral thickness in the rim portion or while limiting the lateral flow of metal in the rim portion of the wheel with said shouldered rolls.

295. The method of reworking heated car wheels, which consists in centrally and rotatably supporting the car wheel, in applying rolls to the marginal portion of the car wheel and therewith rotate and laterally support the car wheel, in exerting axial pressure in the direction against the central or hub portion of the car wheel to force the hub of the car wheel into undished position while the car wheel is so rotated and so laterally supported at its marginal portion, in rolling the so undished car wheel where desired to desired form or shape, in exerting axial pressure against the central or hub portion of the car wheel in an opposite direction to force the hub of the so rolled car wheel into the desired dished position, and in rolling the marginal or rim portion of the car wheel with said rolls and retaining said portion in true alignment.

296. The method of rolling or reworking new or worn heated car wheels, which consists in centrally and rotatably supporting the car wheel on rotatable and axially or lengthwise independently movable forming and supporting means, in applying oppositely-arranged shouldered rolls laterally to opposite sides of the car wheel and against the rim and adjacent web portions and a tread or peripheral face roll between said shouldered rolls to coact with the latter and together roll the rim portion and the flanged tread of the latter to desired form or shape and to desired diameter.

297. The method of rolling or forming heated car wheels into other objects, which consists in centrally supporting the car wheel on rotatable and axially movable work-supporting means, in exerting pressure against the central or hub portion of the car wheel in the direction of its axis to force the hub of the car wheel into undished position, or into another desired axial or lateral position, in rolling the so formed car wheel where desired to desired form or shape.

298. The method of rolling, rerolling, reworking or reforming new or worn heated car wheels, which consists in reforming or reshaping the hub portion of the car wheel as desired and also supporting the car wheel on its hub portion, and in rolling the car wheel to the desired new form or shape of the new object.

299. The herein described method of rolling, rerolling, reworking or reforming new or worn heated car wheels, which consists in reforming or reshaping the hub portion of the car wheel as desired and also sup-

porting the car wheel on the peripheral face of its hub portion, and in rolling the car wheel to its desired new form or shape.

300. The herein described method of rolling, rerolling, reworking or reforming new or worn heated car wheels, which consists in centrally supporting the car wheel on alined, oppositely-arranged, axially independently movable and rotatable supporting means, and in undishing and rolling the car wheel to its desired new form or shape or to the desired new form or shape of a new object.

301. The herein described method of rolling, rerolling, reworking or reforming new or worn heated car wheels, which consists in centrally and rotatably supporting the car wheel on alined, oppositely-arranged, axially independently movable and rotatable supporting means and while so supported subjecting the car wheel from its hub portion outwardly to the action of rolls which roll the car wheel to its desired new form or shape or to the desired new form or shape of a new object.

302. The method of rolling or reworking new or worn heated car wheels having each extra metal in its hub portion and extra metal in its marginal or rim portion, which consists in subjecting the car wheel to the action of a pair of alined, oppositely-arranged and rotatably mounted compressing and central supporting means which center the car wheel and rotatably support the same and simultaneously with this centering process also force the extra metal in its hub portion toward the axis of its bore to make the bore smaller so that it may be rebored to its original diameter or to any other suitable diameter, and in subjecting the so supported car wheel to the action of rolls which roll the extra metal in its rim portion outwardly to describe a circle of increased diameter and simultaneously roll the peripheral face of the wheel to the original true form or shape having the flanged tread and also increase the car wheel to a larger diameter or to at least as large a diameter as the original diameter of the worn wheel while retaining the required lateral thickness or while limiting the lateral flow of metal in the rim portion of the wheel during the operating process.

303. The method of rolling or reworking new or worn heated car wheels too small in diameter for the intended use or which are reduced in diameter by wear, which consists in forcing the metal in its hub portion toward the axis of its bore to make the same smaller so that it may be rebored to its original diameter or to any other desired suitable diameter, and in rolling the metal in the marginal or rim portion of the car wheel outwardly away from the axis of the

work-piece so as to increase the diameter of the car wheel to a larger diameter or to at least that of the original diameter of the worn wheel simultaneously with rolling the peripheral face of the car wheel to desired form or shape while maintaining the required lateral thickness or while limiting the lateral flow of metal in the rim portion of the wheel.

304. The herein described method of utilizing worn heated car wheels, which consists in subjecting the hub portion of the car wheel to external or internal pressure so as to reduce or to enlarge the diameter of its hub and bore so that it may be rebored to the diameter of its original bore or to any other desired suitable diameter and also to centrally support the car wheel at its hub portion, and in then subjecting the car wheel while so supported to the action of rolls which roll the same as and where desired to the form or shape of the desired new object.

305. The method of utilizing worn car wheels, which consists in heating the car wheel, in reducing the diameter of its central bore or a part thereof and rotatably supporting the same, and in rolling the car wheel where desired to desired form or shape.

306. The method of utilizing worn car wheels, which consists in heating the car wheel, in exerting pressure against the external surface of the hub thereof to force

metal toward the axis of the hub and reduce the bore or a part or parts thereof, in applying pressure axially in one direction to the hub while retaining the marginal portion of the car wheel in a fixed rotatable position, and in rolling the car wheel where desired to desired form or shape.

307. The method of utilizing worn car wheels, which consists in heating the car wheel, in reducing or increasing the diameter of its central bore or a part thereof, in rotating and dishing the car wheel and in rolling the car wheel where desired to desired form or shape.

308. The method of utilizing worn car wheels, which consists in heating the car wheel, in reducing or increasing the diameter of its central bore or a part thereof, in rotating and undishing the car wheel and in rolling the car wheel where desired to desired form or shape.

309. The method of utilizing worn car wheels, which consists in heating the car wheel, in reducing or increasing the diameter of its central bore, in undishing the car wheel, in rolling the car wheel where desired, and in redishing the car wheel to the desired dish.

In testimony whereof, I have hereunto set my hand.

LOUIS F. DIETER.
